PRINTER REPERFORATOR

Edward F. Kleinschmidt, Wilmette, Hilding A. Anderson, Lake Zurich, David F. Frick, Palatine, Claytoe H. Clark, Mundelein, and Joseph F. Chinlund, Northbrook, Ill., assignors to SCM Corporation, Syracuse, N.Y., a corporation of New York

Filed July 24, 1959, Ser. No. 829,446
58 Claims. (Cl. 178—92)

This invention pertains to telegraph receiving apparatus and more particularly to a tape type receiving printer-reperforator combination capable of receiving code impulse combinations and recording visual representations of corresponding characters at any speeds up to at least 4500 operations per minute.

Although there are presently known many high speed printers as well as high speed reperforators, there are no printer-reperforators performing both functions at speeds higher than 600 operations per minute (368.1 operations per minute being the normal speed for telegraph apparatus). The primary purpose behind the development of the present invention and one which has been successfully accomplished by the invention was to provide a printer-reperforator apparatus that would punch a coded message on a tape, print this same identical message on one edge of the tape, and to accomplish both of these functions at the exceptionally high speed of 4500 operations per minute (this is 75 operations per second) and still retain reliability of operation over extended periods of time. It was desired to develop and construct such a high speed typing reperforator as a production model for use in fixed plant and military installations. In accomplishing this development, it was determined that selection and operation of the printing and perforating functions would be mechanical under the control of an electronic signal receiver and controller. Inasmuch as no previously known printer or reperforator has achieved the ultra-high speeds of mechanical operation necessary for successful existing practice of this invention, the majority of the functions and structural features of the mechanical printer-reperforator are unique and altogether different from mechanisms heretofore used to accomplish similar objectives. Also, the electronic receiver selector, storage unit and controller combination is unique, particularly in connection with its functioning and operation in combination with the mechanical perforating and printing mechanisms employed.

The mechanical printer-reperforator structure utilizes the transfer of energy between the structural components by elastic impact and reaction forces in each of the high speed motion transmitting mechanisms. The initial impetus is provided from rigid code rod elements mounted in rotating wheels, the force of which is transferred to operating elements which perform mechanical functions of printing-reperforating and tape feeding. Because of the extremely rapid selection and repositioning of the code rod elements, this invention deviates from the normal practice of using a selected number of code elements having permuted notches or some other form of mechanical signal representation, each of which code elements corresponds to one of the signal combination units of the Baudot code combination signal group. In this invention each of the Baudot codes is represented by an independent rigid code rod element and therefore we have thirty-two (32) of such rod elements. The code rod elements are selected by elastic impact plungers controlled by electro-magnets which receive signals from the electronic receiver selector and controlling unit. Elastic impact transfer of operational forces is correlated and coordinated with suitable shock absorbing means to prevent any vibratory or reaction bounce of the struc-

2

tural operating elements. In other words, once an element has performed its function cycle, it must immediately stop its movement and be ready for a next operation. Inasmuch as the machine selectively punches holes

5 in a strip of paper tape, the tape movement cannot be continuous, but must have a definite stop-start operation. Tape feed function and mechanism was one of the most difficult portions of the equipment to develop and is the one which actually places a limit on the upper speed 10 of machine operation. However, production apparatus, made according to the concepts of this invention, has been successfully operated up to 160 operations per second, step feeding message tape and printing and punching characters which occur in a favorable sequence.

15 The electronic receiver selector storage and controller unit is capable of operational speeds many times higher than that of the mechanical printer and therefore must have some form of built-in delay control. Means are provided for storing backed-up signals which, at times, 20 the printer will not be able to process because of an inherent range of operational functions between various ones of incoming signals to give a higher average number of operations per minute.

25 As will become clearly apparent in the detailed description of this invention, the mechanical operational time depends upon the sequence in which the characters corresponding to the Baudot code combination signals are being received. Some sequences of characters can be printed at maximum operational rates of 40 operations 30 per second whereas others can be received and processed by the mechanical mechanism at operational speeds of up to 160 operations per second. Accordingly, the electronic receiver selector and controller is arranged to receive at 75 operations per second, an average speed which 35 the mechanical printer-reperforator will normally be able to handle with a calculated back-up in the storage unit of no more than 20 characters. It is for this reason that a storage unit has been incorporated in the electronic mechanism. There are also means to bypass the storage 40 unit if the incoming signals are being received at a rate no greater than 40 operations per second which the mechanical unit can take under the most adverse conditions with no back-up of signals.

45 Accordingly, the principal object of the present invention resides in the provision of a novel combination receiver printer-reperforator machine capable of extremely high speeds of operation.

50 A further object of this invention resides in the provision of a novel printer-reperforator with mechanical elements capable of speeds of cyclic operation at least as high as 4500 cycles per minute, at the same time being devoid of shock and vibration because of a unique shock absorption feature coating with the cyclically operated mechanical elements.

55 Another object of the present invention resides in the provision of a punched tape with conventional teletype-writer characters printed on the upper leading edge surface of the paper tape, the tape being step fed out of the machine at rates as high as 4500 operations per 60 minute.

65 Still another object resides in the provision of a novel telegraph receiver-recorder apparatus having novel electronic receiving and control apparatus, novel mechanical high speed visual recording mechanism and a combination electronic-electrical-mechanical coincidence tie-in between the electronic control and mechanical recording.

A further object, in conjunction with the preceding object, resides in the provision of a mechanical recorder which has a range of maximum recording time depending 70 upon a best and a worst reception sequence of characters and an optionally connected electronic storage device within the electronic controller adapting the controller to

receive at a higher speed than the worst maximum recorder speed for the mechanical recorder, any back-up of signals between the recorder and controller being stored at random intervals in the electronic storage device.

Another object resides in providing novel telegraph apparatus for receiving electric code combination signal impulses and creating visual recorded manifestations of such code signal combination at speeds at least as high as 4500 operations per minute consisting of a novel electronic device for receiving incoming electrical signal impulses and converting such impulses to individual control signals, a novel mechanical printer-reperforator including a drive motor and independent character representing elements corresponding to each code combination representation of the received code signals, a selector device to select one of such code elements in accord with the control signal from the electronic device, and recording mechanism to be actuated by such selected code element for creating a recorded visual manifestation representative of the incoming signal combination.

A further object resides in providing a novel high speed printer-reperforator telegraph received, including an electronic unit capable of receiving groups of incoming electrical code signals in either sequential or simultaneous form and converting such signals to simultaneous output channels, an electronic controller unit including search registers dividing the impulses in the received code signal combination into two independent groups: a high speed mechanical printer-reperforator including a plurality of individual code representing elements corresponding to each code combination of the code being utilized by the receiver, the code elements being divided into a plurality of groups, a device for correlating each of the said groups of code elements with matching representations of one of the two groups of divided signals in the search register; a device for selecting one of the code elements from within any desired group of code elements in accord with a signal derived from the second of the two groups of divided signals in said search register; mechanism operated as a result of elastic impact forces derived from a selected code element for punching a corresponding code representation in a message tape, printing the corresponding character designation on said message tape, permitting said message tape to feed one step and retracting all operating mechanisms and a power device providing kinetic energy to all of said code elements.

Still another object resides in providing a novel high speed printer-reperforator receiving apparatus with an electronic control device for receiving Baudot code signal combination impulses and splitting each combination of impulses into two groups, one of which groups has four different impulse combination conditions and the second of such groups having eight different impulse combination conditions; a mechanical printer-reperforator with a power unit driving two rotating wheels including a plurality of coded elements representative of all possible Baudot code signal combinations, the code elements being divided into four simultaneously rotating groups, each group containing eight of the code elements spaced equi-angularly apart, a selector for each of the four groups of code elements capable of placing one of the eight code elements in its corresponding group into a selected position at a specific reference point in the 360° rotation cycle of the wheels, a device connecting between the four selectors and the controller whereby the first group of control signals in said controller determines which of the four selectors can be rendered operative, a coincidence device correlating reference points corresponding to the rotational angle positions of said four groups of code elements with the controller, the controller including register means for determining which of the eight angular positions of the groups of code elements corresponds to the one-out-of-eight code signals of the second group in said controller and enabling operation of the selector corresponding to the proper one-out-of-four code impulse com-

bination in the first group in the controller at the appropriate time when the code element corresponding to the received combination of code impulses passes the reference point of the operational selector; a recorder operated by the selected code element for creating a visual recorded representation on a message tape.

Another object resides in providing a novel mechanical telegraph recorder capable of operational rates up to 40-160 operations per second.

Still another object resides in the provision of a novel mechanical recorder selector mechanism consisting of a rotating code wheel carrying individual selectable and shiftable code rods, each of which mechanically represents a distinct code combination from the Baudot code.

Still another object resides in the provision of mechanism utilizing a novel method of elastic impact reaction as the motive forces to move recorder elements through their cycles of operational movement.

A still further object resides in the provision of a novel intermediate impact transfer lever punch operating mechanism.

A further object resides in a novel inertia operated print hammer assembly, with a low mass hammer head.

Still another object resides in providing a novel high-speed stepping type tape feed mechanism utilizing a minimum mass tape feed wheel and holding sprocket deriving rotation from a spring wire torsion shaft.

Still another object resides in the provision of a novel high speed double row type wheel assembly with novel axial shift mechanism.

A still further object resides in a novel ink ribbon feed and reversing mechanism. In conjunction with this object, a further object resides in providing a novel electronic feed and directional control over the ink ribbon feed mechanism.

A further object resides in the provision of a novel manually operated electronically controlled tape feed-out with automatic over-ride by any incoming signal without loss of such signal.

Still another object resides in providing a novel electronic circuit for control of auxiliary functions of a tape reperforator and printer.

A further object resides in the provision of novel electronic control circuits for energizing electromagnets controlling the figures "shift" and letters "unshift" function of a reperforator and printer.

Still a further object resides in the provision of a novel electronic control circuit for a signal ringing circuit.

Another object resides in the provision of a novel ribbon direction and feed control circuit which is effective to stop ribbon feed when no signals are received for a predetermined interval of time.

Further novel features and other objects of this invention will become apparent from the following detailed description, discussion and the appended claims taken in conjunction with the accompanying drawings showing a preferred structure and embodiment, in which:

GENERAL DESCRIPTION

In the high speed electronic mechanical printer-reperforator, all components are housed in a single unit 50 illustrated in FIGURE 1. This printer-reperforator unit 50, with reference to the schematic FIGURE 2, consists of several basic components some of which are electronic and others of which are electrical-mechanical. Actual printing and perforating operations are of a mechanical nature although powered by a continually operating elec-

tric motor. Mechanical code combination representations are contained on a plurality of code rods which, during the machine operation are in continuous rotation as distinguished from the normal start-stop operations of known printing-reperforators, used prior to this invention. The mechanical printing and punching components of reperforator unit 50 are coordinated with the electronic receiving and control components through an electronic coincidence circuit which actuates, in an electro-mechanical manner, selection of a code rod representative of a received electrical code signal combination.

In FIGURE 2, where the basic components of the control portion of reperforating unit 50 are illustrated schematically it will be seen that the incoming electrical manifestation of code combinations (the example used being the standard Baudot Code) may be received by a sequential to parallel convertor unit 52 through a two line sequential system or through a six signal line parallel system, five lines of which are for the different code manifestations and the sixth line for a control or sync signal. From convertor unit 52 the signals are electronically transferred to a controller unit 54 or to a storage unit 56, if the latter is being used. As will be described in detail hereinafter, use of storage unit 56 is optional and will depend on the line speed, i.e., the rate of incoming code combination signal impulses received by converter unit 52. As an example, a line speed of 40 or fewer operations per second is sufficiently low to assure that the worst time of sequential selection by the mechanical unit enables handling of the message without need for the storage unit. On the other hand, if the incoming rate is raised to 75 operations per second (o.p.s.), the contemplated design speed, the mechanical operating time requirements for certain character selection sequences in the mechanical operation exceeds the fixed 13.3 milliseconds between successive characters for a 75 o.p.s. rate. Utilization of the storage unit permits an intermittent back up in mechanical utilization of any signals from the controller, the sequence of which the mechanical part of the reperforator cannot process at the line frequency.

Electrical signals from controller unit 54 select a desired code rod, corresponding to the received code signal, in the printing-reperforating component 58. A tie-in control between the mechanical printer-reperforator component 58 and the controller 54 is provided through a rotary coincidence selector 60 operated in direct rotation relationship to rotation of the code rod wheels for the printer-reperforator component 58.

Operation of the complete machine 50 requires absolute correlation between the mechanical and electronic components. To obtain an ultra high speed (4500 o.p.m.) in the mechanical selection, printing, punching and tape feed, a plurality of small rigid code rod elements are mounted on a continuously rotating wheel. An operational theory of transfer of energy by elastic impact is also utilized to obtain rapid cyclic movements. These noted factors provide a very important advantage in that the code rod "wheel," if desired, can be, and in this invention has been, divided into two wheels, each wheel containing sixteen of the thirty-two code rod elements needed to represent individual code combinations of the Baudot code. Impact forces necessary to perform the printing, punching and tape feeding operations can all be derived from the kinetic energy of rotation of these operating wheels. Furthermore, because two wheels instead of one can be used, the diameter of the wheels has been reduced to the point where the velocity of the code rod elements mounted adjacent the rim of the wheels is sufficiently low so that the impact produced between a selected code rod and intermediate operating levers is not excessive. Finally, the electro-mechanical mechanism which selects and shifts a desired rod in an axial direction within either one of the operating wheels, can be controlled more easily by providing selecting devices on

each side of each wheel. This mechanical selecting arrangement enables a division of the 32-unit Baudot code into two wheels, each wheel with two groups, i.e., 4 groups of 8 units each, thereby increasing the mechanical selection operations per unit time by a factor of 4. Even so, if a larger code group such as a 64 character code is desired, then (1) four code wheels each carrying a 16 character group can be used or (2) means can be provided for shifting the type wheel which is provided with two rows of characters. This latter method is utilized and specifically described in the following description.

Having divided the Baudot code system into four groups of eight units, each group having the code rods corresponding to its included character unit equally circumferentially spaced around the peripheral rim of a code wheel, selection of a specific code rod element resolves into a combination of a one-out-of-four and a one-out-of-eight selection. The one-out-of-eight selection is directly related to eight angular positions of the eight code rods in each group about the 360° circumference of the associated code wheel. Although the four selection points for all four groups are mechanically offset as is apparent from FIGURE 2, they are coincided on a time basis by the displacement of the magnets and pick-up coils.

Coincidence of this angular phase relationship with specific code combinations is accomplished by an electronic-electrical-mechanical tie-in between the printer-reperforator and the electronic controller unit which compares and matches the last three units of a received five unit Baudot code combination with a corresponding three unit signal related to the code wheel eight position rotational phase. At every one of the eight phase positions of the code wheels, there are four code rod elements which could be selected. The electronic controller determines which one of the four code rods will be selected in accordance with a one-out-of-four signal represented by the first two impulses of a Baudot code.

FIGURE 3 is a chart illustrating all of the characters in the five unit Baudot code. In breaking this code into four groups (represented by FIGURE 4), it will be seen that is eight of the 32 code combination, the same first two impulses occur. In other words, in one group the first two code impulses are mark-mark impulses; in a second group the first two code impulses are mark-space impulses; in the third group the first two impulses are space-mark impulses; and in the fourth group the first two code impulses are space-space impulses. The eight characters in each of these four groups have eight different 3-unit code impulses constituting the last three code impulses of the Baudot code. These same eight different 3-unit code combinations appear in the same sequence in the arrangement of each of the four groups, this similarity being depicted in FIGURE 4. Variations of the code may be used. However, if the sequence of characters is changed in one group, it must be changed in every group.

The chart in FIGURE 6 is developed from the four groups shown in FIGURE 4, the four vertical rows of characters representing the four groups of code combinations represented by mark-mark, mark-space, space-mark and space-space. These four groups are the ones which will be controlled by the one-out-of-four selector in the electronic controller (see FIGURE 2). In FIGURE 6 the eight horizontal lines contain four characters, each of which is represented by the same 3-unit code combination of the last three code elements in the Baudot code. If all of the circular diagrams representing the four ends of the two code wheels were diagrammatically superimposed on a single center, we can obtain a picture of the four code rods for the four characters of each group, of the eight groups, being peripherally sequentially located within a forty-five degree sector. There are eight such sectors, each sector representing four code rods and any one of the four code rods can be selected at the position represented by the forty-five degree sector. To accurately

determine the eight positions of rotation of the code wheel or wheels, a rotating coincidence selector is rotated in direct relationship to rotation of the code wheels. The rotor of the coincidence selector includes permanent magnets operatively associated with fixed pick-up heads. As will be later described in detail, the output signal from the pick-up heads provide 3-unit code signals corresponding exactly to the last 3 code elements of the code combination in the Baudot code at each of the eight angular positions of the code wheels. Thus, insofar as the mechanical apparatus is concerned, we have a means for determining the exact point at which any one of the eight rotational angular positions passes a given point. If at that time we are able to select one of the four groups represented by the mark-mark impulses, mark-space impulses, space-mark impulses and space-space impulses, only one code combination character will be selected.

Returning now to FIGURE 1, the aforescribed components of printer-reperforator 50 are arranged in small compact subassemblies integrated in a unit occupying approximately one and one-half cubic feet and having a total weight of approximately 50 pounds. The printer-reperforator component 53 occupies the center and forward portions of unit 50, coincidence selector 60 being a mechanical portion of this component. Located at the rear-upper portion of reperforator 50 is a box containing converter unit 52 and controller unit 54. The lower base portion 61 of reperforator 50 has space for the storage unit 56 and a front chad drawer 62.

Incoming five unit Baudot code signals are received by the converter unit 52 and are then transmitted through the storage unit to the controller 54. However, when the storage unit is not used, a dummy plug permits the code signals to be transmitted directly to the controller.

The electronic five unit code signal is split into two groups in the search register, the first being indicative of the first two units of the code which is then applied as one input signal to a first "and" gate which drives one of four magnets, designated SM (space-mark), MM (mark-mark), SS (space-space) and MS (mark-space) in FIGURE 2. The last three units of the five unit incoming signal and the electrical phase position relationship of the code element carrying wheels of the mechanical printing and perforating unit 53 are composed by means of a one-out-of-eight "and" gate. The output signal from the one-out-of-eight "and" gate is applied as another of the input signals to the first "and" gate to operate the one selected magnet, SM, MM, SS or MS at the proper time interval in the cycle of rotation of the wheel carrying the code rods. From the time of this code rod selection, actual printing and perforating operations, which are essentially mechanical functions and will be described hereinafter, occur while the output of the electronic system is blocked for the next 5 milliseconds.

55 ELECTRONIC SELECTOR AND CONTROLLER DESCRIPTION

Block Diagrams

Turning now to FIGURES 7, 8 and 9, a functional block diagram of the electronic portion of the reperforator of the present invention is shown with the storage unit 56 as indicated in FIGURE 2 removed. In FIGURE 7, the sequential signal input line is connected to supply input signals to line oscillator 64, the function of which is to operate line gate 66 which provides a reproduced input signal having a sufficiently good wave shape to improve the reliability of operation of the electronic system. Also, as will be pointed out in the discussion in connection with FIGURE 10B, the line oscillator 64 and line gate 66 provide complete isolation of the electronic circuitry in the reperforator apparatus from the incoming lines.

An output signal from the line gate is applied on lead 67 to distributor 68 at the beginning of the reception of each five code element signal. The distributor 68 is advanced at a frequency determined by the frequency of

operation of time base generator 69, the output of which on lead 70 controls the advancement of the distributor to provide selective output signals on leads 71, 72, 73, 74 and 75 at time intervals corresponding to the time intervals of reception of the sequential five element code through line gate 66. The five electrical signal impulses of the code are also applied sequentially on lead 76 to one input of "and" gate 77. The other input signal to "and" gate 77 is on lead 134 from a 35μ second delay multivibrator 84 which is triggered by an output signal from time base generator 69. With the improved wave form provided at the output of line gate 66 and the precise timing of the control signal delayed by 35μ seconds from circuit 84, the output signal from "and" gate 77 is such as to assure reliable operation throughout the remaining circuitry.

The output signal from "and" gate 77 is applied as an input signal to each of the "and" gates designated 1, 2, 3, 4 and 5 respectively on lead 116. When the No. 1 code impulse appears on lead 76, only the No. 1 "and" gate is open while the Nos. 2, 3, 4 and 5 "and" gates remain closed. An electrical signal corresponding to whether the first code element is a mark or a space is thus transmitted to the No. 1 first register storage stage 78.

At the time the No. 2 code element appears on lead 116, the time base generator 69 has advanced distributor 68 to the point where the output signal from the distributor is on lead 72 which opens the No. 2 "and" gate to thereby permit the No. 2 first register storage stage 78 to receive a voltage corresponding to a mark or space signal in the No. 2 code element position. At this point in time, the "and" gates for the Nos. 1, 3, 4 and 5 code element signals remain closed.

Distributor 68 continues to advance in a cyclical manner providing a pulse shaped output signal on leads 73, 74 and 75 successively at time intervals corresponding to the appearance on leads 76 and 116 of the signals corresponding to the No. 3, 4 and 5 code elements. At the end of a cycle of operation, the first register storage stages 78 make available all five of the code signal elements of a single character of the Baudot code for simultaneous processing throughout the remainder of the electronic circuitry.

The time base oscillator 69 is a fixed frequency oscillator with separate plug-in RC combinations available to match the output frequency with the signal frequency used on the sequential line input to line oscillator 64. This enables the speed of the present invention to be matched with the message signal speed over the teletype line. After distributor 68 has completed one cycle, it initiates a stop bias signal to time base oscillator 69 whereby both remain in a rest condition until a new start signal is received over lead 67 from line gate 66.

The contents of the first storage register is read out in parallel. A read-out signal is provided on lead 82 from the first register read-out stage. This signal is generated during the sequential mode of operation at the time the stop bias signal is provided from the distributor to the time base oscillator 69 after the fifth signal code in it has been received. The actual read-out pulse is delayed slightly to assure that the No. 5 first register storage circuit has reached a stable status.

A sequential-simultaneous mode selector switch 80 is provided having a plurality of contacts which are mechanically interconnected. In FIGURE 7, these contacts are in a position adapted for receiving the sequential signal. The contacts of switch 80 when transferred to their alternate position adapt the present invention to receive the five code elements of the Baudot code simultaneously from five different signal channels along with a control or sync signal on the sixth signal channel as shown in FIGURE 7. When the simultaneous mode of operation is used, distributor 68, time base oscillator 69 and several of the associated circuits are not used. The input signal to "and" gate 77 from line gate 66 is continuously an open signal and the control sync triggers the 35μ second delay circuit to thus open "and" gate 77 al-

most immediately upon receipt of the incoming signal. The input signals on each of the lines marked 1 to 5 are then transmitted directly into the corresponding first register storage stages 78.

For the simultaneous mode of operation, the control or sync signal accompanying the Baudot code signals is applied through line sensing one shot multivibrator 84 which provides a 35μ second delay and through five millisecond delay one shot multivibrator 86 to the first register read-out stage. After the read-out signal on lead 82 is applied to each of the first register storage stages 78, these stages are in condition to receive the next incoming signal code elements. The signal transmission in the simultaneous mode may be at any speed up to the maximum design speed of the equipment and no adjustments or changes are required for varying signal transmission rates.

FIGURE 8 is a functional block diagram of the controller unit which contains five second register stages 88 that receive as input signals the output signals of the first register storage stages 78 from FIGURE 7. The controller unit of FIGURE 8 requires varying time increments for operation depending upon the particular sequence in which successive characters are received in the message. As will be explained below the controller unit is cleaned out to be ready for the next signal when it arrives.

After the code element signals are stored in the second register stages 88, a slightly delayed read-out sync signal is applied to the search register stage in the controller unit as shown in FIGURE 8 from lead 90 which is derived from the first register read-out stage of the receiver-selector unit shown in FIGURE 7. The output signal from the search register on lead 91 is applied to open the shaft position coincidence detector (one-out-of-eight) to condition this circuit so that upon the proper coincidence of signals from the Nos. 3, 4 and 5 second register stages 88 and the output from the pick-up coils from sections "A," "B" and "C," an output signal will appear on lead 92. Instantaneously upon receipt of the incoming signal to the second register storage stages 88, the outputs from the No. 1 and the No. 2 second register stages are applied to the one-out-of-four "and" gate to condition one of the selector magnets MM, MS, SM or SS to be selected at the moment when time coincidence is registered by the shaft coincidence detector.

The output signal from the 2 millisecond gate pulse generator is applied directly as the last input to the one-out-of-four "and" gate to thereby trigger the correct selector magnet. At the same time, this signal discards the code then stored in the second register storage stages 88 by triggering these stages back to a no signal condition to place the second storage register in a condition to receive the next coded signal.

The output signal from the 2 millisecond gate generator is further applied by lead 93 to a five millisecond feed delay stop gate which is a single shot multivibrator. The output signal from this circuit prevents the shaft position coincidence detector from registering a coincidence output signal during the 5 millisecond gating time interval to enable the mechanical apparatus to perform the functions of perforating and printing the previously transmitted signal on the tape. During this interval, the next coded signal is received by the second register storage stages 88 so that the controller unit is ready to supply the next signal to the mechanical unit as soon as the preceding character has been processed.

At the end of the 5 millisecond delay, the shaft position coincidence detector will be unblocked and the mechanical apparatus will be ready to process the next character. However, if the next coded signal is not yet present in the second storage register stages, the search register will provide on lead 91 an inhibit signal that prevents an output signal from appearing on lead 92 from the shaft position coincidence detector circuit.

One of the novel features of the present equipment is

the provision for manual tape feed-out, and an override feature which prevents further tape feed-out in event an incoming signal should appear. Manual depression of the tape feed-out push button 222 results in a transfer of the condition of the blank feed-out register circuit, which may be a bi-stable Eccles-Jordan type circuit, to provide an enabling signal to the shaft coincident detector whereby a coincidence is indicated at a position corresponding to a code having 5 spaces to thereby advance the tape once each rotation of the code wheel shaft 292. Each time an input signal is received, the 35μ second delay circuit 84 (see FIGURE 7) produces an output pulse on lead 94. This signal will appear on lead 94 (see FIGURE 8) as the input to the blank feed-out register stage to override the effect of the manual tape feed button 222 and stop the tape feed-out operation so that none of the incoming signals will be lost.

FIGURE 9 shows the circuit diagram for controlling operation of various other auxiliary functions in connection with the operation of the reperforator unit. The type wheel of the printer unit contains two rows of thirty-two characters each, one row being designated letters and the other row being designated figures. The type wheel is shifted axially via electro-magnets when current passes through one or the other of the electro-magnet coils and remains in the selected position until again shifted.

As is apparent from FIGURE 3, the code for both LTRS and FIG starts and ends with two marks, the sole difference being in the No. 3 code element. Code elements 3, 4 and 5 are used as inputs to multiple "and" gates stage 96 shown in FIGURE 9 to selectively energize either the FIGS SHIFT CURRENT AMPLIFIER 97 or the LTRS SHIFT CURRENT AMPLIFIER 98 to momentarily energize the corresponding FIGS or LTRS SHIFT magnets and shift the printing wheel accordingly.

With continued reference to FIGURE 9, the signal bell is operable when the printing wheel is in the figures position and the letter S is transmitted. The bell is caused to ring by the energization of the current coil of an electro-magnet by current amplifier 100 which is energized from the output of multiple "and" gate circuit 101. The inputs to multiple "and" gate circuit 101 include a signal indicating the first two code elements are mark-space and the outputs from the Nos. 3, 4 and 5 second register stages 88 corresponding to "S," which as shown in FIGURE 3, are mark-space-space. In addition to foregoing code elements, multiple "and" gate 101 also requires a signal from a case register memory stage which is a bi-stable device that supplies the necessary signal only when the figures shift magnet is the last to be energized and the type wheel is shifted from the figures row of characters.

One further auxiliary function is that of controlling the ribbon feed and its direction of feed. As it is desirable to have the ribbon feed only during periods of operation of the reperforator and printer unit to provide uniform wear on the ribbon, electronic circuit means are provided for selectively energizing the ribbon feed clutches, there being one for each direction of rotation of the ribbon feed spools as shown in FIGURE 9. Each time a character is punched or printed by the perforator unit, an output signal from the 2 millisecond gate pulse generator in the control unit shown in FIGURE 8 is applied through lead 93 to a one second sustained circuit shown in FIGURE 9. This circuit comprises a large condenser which discharges through a relatively large resistance and has a time constant sufficiently long so that its output signal is sufficient to operate "and" gates 102 and 103 for a period of about one second. In the event an operator is manually typing a transmitted signal, the ribbon feed will be continuous so long as letters are transmitted at a spacing of no greater than one second. Once an interval greater than one second occurs during which there is no signal received, "and" gates 102 and 103 are closed and the ribbon feed clutch magnets are de-energized to thereby stop the ribbon feed. As soon as a sig-

nal is received, "and" circuits 102 and 103 are immediately gated open and the ribbon feed clutch magnet is then again rendered operable.

In order to assure continuous feed of the ribbon in the desired direction, a ribbon direction register is provided which, as will be explained below, provides an output signal to only one or the other of the "and" circuits 102 and 103, depending upon the direction of the ribbon feed. The ribbon direction register thus serves as a memory to thereby cause the ribbon to continue movement in the same direction which it had been previously running.

Detailed Circuit Diagrams

A circuit diagram of a transistorized circuit of the receiver-selector, which largely is a sequential-to-parallel signal converter (see FIGURE 7) and of the controller (see FIGURES 8 and 9) is shown in FIGURES 10A, B, C, D, E and F. Where possible, reference numerals and block diagram labels used in FIGURES 7, 8 and 9 are used to identify corresponding parts in the detailed circuit diagram of FIGURE 10. While the drawings show the complete circuit of the reperforator, the following description will be directed to the principal parts only since the functions of the circuit components not mentioned will be obvious to those skilled in this art.

FIGURE 10A contains nine circuit stages surrounded by dotted lines plus at the bottom of the sheet the input terminals, sequential-simultaneous mode selector switch 80 and the line oscillator. Each of the circuit component designations that are inside a dotted line block represents the circuit components that are mounted on a card. In those instances where more than one circuit function is supplied by the components on a single card, the title block is divided with left hand title designating the function of the components in the upper portion of the dotted line block. Similar designations are used in the circuit diagrams of FIGURES 10B through 10F.

Referring first to FIGURE 10A, the sequential-simultaneous mode selection switch 80 is, in this figure, shown in the simultaneous signal reception position. The following description will assume switch 80 to be in its alternate position and the sequential input signals to be applied over leads 104 and 105 through R-F filter 106 to line oscillator 64 which comprises a transistor connected as a Hartley oscillator operating at a frequency of approximately 200 kc. This oscillator circuit is unique in the sense that it is powered wholly by the energy of the input signal. No power supply of D.C. connection is provided between transistor 64 and the remaining components in the perforator unit of the present invention. When a mark pulse appears, the energy in the pulse is sufficient to cause the circuit to begin oscillating immediately and when the pulse terminates, the oscillations terminate, the threshold voltage level being adjustable by potentiometer arm 107. Transformer 108 has its primary in the oscillator circuit and there is no D.C. connection between the primary and the remaining circuit. This provides a completely isolated secondary circuit in which coded signals of uniform amplitude are provided for further use in the reperforator unit.

R-F filter 106 is important in this equipment to prevent the 200 k.c. signal of oscillator 64 from appearing on the input signal line. Suitable impedances across leads 104 and 105 are provided to match the various different line currents that are likely to be encountered.

The secondary of transformer 108 contains a full wave rectifier bridge 109, the output of which is connected across RC network 110 and variable resistor 111 to ground. Variable resistor 111 serves as a bias control for the newly generated Baudot code signals which appear on lead 112 to be supplied to line gate 66 at the upper center of FIGURE 10A.

The output signal from line gate 66 is connected via lead 67 to the start amplifier 113 for the distributor shown in FIGURE 10B. In effect, start amplifier 113 produces

an output pulse on lead 114 everytime there is a mark to space transition, which occurs between the end of the stop pulse and the beginning of the start pulse. If the distributor is already in the midst of a cycle of operation, then the output pulse on lead 114 is discarded. If the distributor is at rest, then an output pulse on lead 114 starts the distributor through a cycle of operation.

A second output signal from line gate 66 appears on lead 76 which is connected through "and" gate 77 composed of diodes 115a and 115b. The output from "and" gate 77 appears on lead 116 to five diodes 117 which are part of the "and" gates associated with each of the first register storage stages 78, as is shown in FIGURE 7. Through this circuit, each mark pulse is applied by lead 116 to each first register storage stage 78, but is accepted by only the one stage which is opened by the output signal from the distributor which is shown in detail in FIGURE 10B.

The output signals from the distributor appear on leads 71, 72, 73, 74 and 75 respectively for the number 1, 2, 3, 4 and 5 code elements. The output signals from the first register storage stages 78 appear on leads marked in FIGURE 10A along the right margin ①, ②, ③, ④ and ⑤.

Since the five code elements of a sequential code occur at successive time intervals which depend upon the line speed of transmission, a time base generator 69 is provided for driving the distributor of FIGURE 10B. Generator 69 is basically a free running multivibrator having removable plug boards containing different sized capacitors and resistors for C-1, C-2 and R-1, R-2 to provide the proper frequency for the various different operational rates varying from 368.1 to 4500 operations per minute, i.e. about 6 to 75 operations per second.

Time base oscillator 69 is keyed on and off with the reception and completion of each sequential code by time base shut off circuit 118 which normally supplies a biasing signal through lead 119 to prevent oscillation by time base generator 69. Time base shut off circuit 118 receives its input signal on lead 120 from the distributor in FIGURE 10B. When the distributor in FIGURE 10B starts through a cycle of operation, a signal appears on lead 120 which produces the signal on lead 119 that unblocks time base generator 69. This unblocking signal continues until the distributor returns to its rest position at which time the blocking signal again appears on lead 120.

Referring now to FIGURE 10B, the distributor illustrated is a conventional beam switching tube which is commercially available. Other types of distributor circuits, such as the ring circuits used in counters which use either vacuum tubes or thyratrons may be used. The beam switching tube shown in FIGURE 10B was chosen primarily because the tube and its associated control circuits were readily available through commercial sources.

The tube has target elements designated T-0, T-1, T-2 . . . T-9. The electrode T-1 is connected to lead 71, electrode T-2 is connected to lead 72, electrode T-3 is connected to lead 73, electrode T-4 is connected to lead 74 and electrode T-5 is connected to lead 75. The remaining target electrodes T-6 through T-9 are not used in this equipment and are connected so that the beam in the tube advances without delay to its rest position on target electrode T-0.

On the righthand side of FIGURE 10B are a series of 10K and 100K load resistors which are connected to the several target electrodes as illustrated, and on the lefthand side of the figure are the screen grid resistors which are connected in a conventional manner. Since this type of tube and its control circuits are well known to those skilled in the art, the detailed functioning of the tube will not be described other than to describe that part of its operation which is unique with this equipment.

The input pulse from start amplifier 113 in FIGURE 10A is applied through lead 114 which extends on to FIGURE 10B, through capacitor 121 and lead 122 to the

beam switching tube grid element G-0. This causes the electron beam in the tube to advance off target electrode T-0. With the electron beam off electrode T-0, a voltage signal is produced on lead 120 which is supplied to time base shut-off stage 118 in FIGURE 10A to thereby provide the unblocking pulse on lead 119 to time base generator 69.

The output signal from time base generator 69 on lead 123 from time base generator 69 is applied upwardly along lead 123 to a distributor step delay stage. The output from the distributor step delay stage is on lead 124 and serves to trigger the beam switching tube (BST) driver stage, which is a bi-stable trigger circuit, into its alternate conductive state with each successive pulse on lead 124.

The input signal to time base generator 69 on lead 119 is through a variable resistance designated range control. The purpose of the range control adjustable resistance is to provide an initial delay before time base generator 69 starts operation so that the first output signal on lead 123 that causes the beam switching tube to be advanced will be timed properly to advance the beam in the beam switching tube in FIGURE 10B to target electrode T-1 near the middle of the time occurrence in the first code element in the transmitted code. As is apparent from FIGURE 11, a delay of about 3 milliseconds is provided where the equipment is operating at the rate of signal transmission of 75 operations per second and the total time available to send the start space, the five mark-space permutations of the Baudot code and the stop signal is slightly less than 14 milliseconds.

In FIGURE 11, a timing diagram is shown wherein the character "Y" has been transmitted. Each of the five code elements thus is present for a time interval of approximately two milliseconds as indicated in the top line of the timing chart. The second line shows the code element reversed so that the space code elements are indicated as a positive going pulse whereas the mark elements are indicated as a negative going pulse. The inverted wave form illustrated is available in the line gate stage 66 shown in the upper center of FIGURE 10A at a test point (TP)11.

The third wave form shown in FIGURE 11 is the output of the distributor start amplifier 113 in FIGURE 10A, the voltage wave form being that present at TP-6. As pointed out above, each time there is a transition from a mark to a space, there is an output signal from TP-6 (see start amplifier stage 113 on FIGURE 10A) on lead 114. However, the only signal which is used by the beam switching tube in FIGURE 10B is that signal which appears when the beam switching tube is in its rest position with the beam at target electrode T-0. Any other pulses applied to grid G-0 are ineffective.

The fourth chart in FIGURE 11 shows the output from time base generator 69. This output signal has a sharp negative going edge which is adjusted to be near the center of the time interval of each of the five code elements of the Baudot code. The first negative going pulse signal, however, is delayed by time base generator as explained above, before being applied to the beam switching tube driver through lead 124, by an amount to compensate for the width of the start space plus about the first half of the No. 1 code element in the Baudot code. The remaining output pulses from the time base generator 69 appear in a proper timed relationship to trigger beam switching driver circuit 125 at the proper time interval.

The output signal on lead 123 from time base generator 69 is applied as the input signal to 35 μ second delay single shot multivibrator on lead 137 through contact 136 (in its transferred position for the sequential mode of operation) of switch 80. The voltage waveform as shown in the fifth timing chart in FIGURE 11 is provided at the output of the 35 μ second delay multivibrator (TP-10). This signal is produced at the repetition rate

of the output signal of time base generator 69 and applied through lead 134 to diode 115b of "and" gate 77.

With continued reference to FIGURE 10A, the output leads 126 and 127 from the beam switching tube driver 125 are shown in FIGURE 10B to be connected through capacitors 128 and 129, respectively, to the beam switching tube grid G-EVEN and G-ODD so that the alternating signals produced by the beam switching tube driver on leads 126 and 127 advance the beam inside the beam switching tube in a counterclockwise manner with the beam stopping at the target electrodes T-1, T-2 through T-5 for time intervals sufficient to apply the necessary pulse on leads 71, 72, 73, 74 and 75, respectively, which time interval is determined by the repetition rate of time base generator 69. As is apparent from FIGURE 10A, the signals on leads 71 through 75 pass through the transferred contacts of mode selector switch 80 to one input of the "and" gates 117 and the first storage register stages 78 in a sequential manner to cause a voltage condition to be stored in the first register storage stages 78 associated with the leads marked ①, ②, ③, ④ and ⑤ which correspond respectively to the five signals comprising the incoming Baudot code signal.

When the beam in the beam switching tube advances to its rest position at target T-0, a blanking signal is provided on lead 120 to time base shut-off stage 118 to thereby block further output signals from time base generator 69. As shown in FIGURE 11, the output signal from time base shut-off stage 118 at TP-8 comprises a negative pulse which extends until the next start pulse is received on the next incoming code sequence.

A second output signal from time base shut-off stage 118 is provided on lead 130 which goes through the transfer switch contact 131 to lead 132. As shown in FIGURE 11, the output signal from TP-7 of the shift stage is a short negative going pulse which is applied to lead 82 (see FIGURE 10A) as a read-out pulse through the cathode of the diode in each of the five first register storage stages 78. This then makes available on the leads in FIGURE 10A at the right margin identified as ①, ②, ③, ④ and ⑤, a voltage impulse corresponding to the five code elements which have just been received.

Simultaneous Mode Of Operation

For the following description, it will be assumed that a simultaneous input signal is received on the simultaneous input terminals marked 1, 2, 3, 4, 5 and sync. The contacts of switch 80 for this mode of operation are in the position illustrated in solid lines so that the mark signals which are transmitted as positive pulses will be supplied to "and" gates 117 of the first register storage stages 78 on leads 71, 72, 73, 74 and 75. The first register storage stages 78 are not opened, however, until a control pulse is present on lead 116 through "and" gates 117. The control signal on lead 116 comes from the 35 microsecond delay single shot multivibrator 84 through lead 134. The other input to "and" gate 77 is held open by a continuous positive voltage on the anode of diode 115a resulting from contact 139 of switch 80 being connected to negative 7 volt bias.

The incoming sync signal is applied through lead 135, switch contact 136 and lead 137 to the 35 microsecond delay single shot multivibrator stage 84. The negative going output signal at TP-10 from 35 microsecond delay single shot multivibrator 84, in addition to being applied through "and" gate 77, is applied through lead 138 to the input of 5 millisecond delay stage 86.

The timing chart in FIGURE 12 shows the time relation of the output signal at TP-10 in the 35 microsecond delay single shot multivibrator stage 84 and the signal at the first register storage stages 78 which receive the coded signals at that time interval. At the end of 5 milliseconds, an output signal appears on lead 139, through switch contact 131 in its illustrated solid line

position and lead 132 to the shift stage. The output signal at TP-7 of the shift stage on lead 82 is provided, as in the case of the sequential input signal, to effect a read-out of the signals stored in the first register storage stages 78 by making the voltage levels stored available on the terminals ① through ⑤ at the righthand margin of FIGURE 10A.

Along with the output signals from the first register storage stages 78, the read-out signal on lead 82 is provided as a control pulse. When the storage unit is used, this pulse is used as a strobe pulse to effect the storage of signals on leads ① through ⑤ as will be described below in connection with the storage unit shown in FIGURES 15-19. When the storage unit is not used, the pulse on lead 82 is discarded, and instead, a slightly delayed pulse appearing on lead 90 is used in the control unit to be next described.

CONTROLLER UNIT

20 The controller unit circuit diagram is shown in FIGURES 10C, D, E and F. Referring first to that portion of the controller unit shown in FIGURES 10C and 10D, the five second register storage stages are shown along the left-hand margin of the two sheets containing those figures and the signal input terminal to each of the five stages is marked with the digit ① through ⑤ which corresponds to the code element which each stage receives. Each of the second register storage stages 88 comprises a bi-stable circuit of the Eccles-Jordan type so that once an input signal is received, the circuit maintains that status until a reset signal is applied on lead 93 through capacitors 140. In this particular circuit, a space is represented by no signal and a mark represented by a signal over input leads ① through ⑤.

35 Each of the second register storage stages 88 is supplied with a negative 4.5 volts on terminal 141 and a positive 4.5 volts at terminal 142. The reset pulse on lead 93 through capacitors 140 cause the righthand side of the circuit to conduct while current conduction through the lefthand side is blocked. If any code element in the Baudot code is a mark, a signal is received on the corresponding input lead marked ① through ⑤ to transfer the circuit in the particular second register storage stage 88 to its alternate condition whereby the lefthand side becomes conducting and the righthand side is cut off. A signal indicative of a space in the Baudot code comprises no signal whatsoever. Thus, if no signal is received, the second register storage stages 88 are in a space indicating condition which, as is apparent from FIGURES 4 and 6, is used to indicate a blank.

50 Referring now to FIGURE 10C, if the signal in the No. 1 second register storage stage 88 is a space, the lefthand side will be cut off thereby providing a negative voltage of about 3 volts on lead 143 to the cathode 144 of diode 145 of the mark-space pre-amp stage 146 as shown in the upper righthand portion of FIGURE 10D, and to cathode 147 of the mark-mark pre-amp. Diode 145 together with diode 148 and resistor 149 across which a positive pulse is applied through lead 93 from the 2 millisecond control gate pulse generator shown in the middle of FIGURE 10C comprise an "and" gate for the mark-space pre-amp. Analogous "and" circuits are provided for each of the three addition selector magnet pre-amps, viz. mark-mark (FIGURE 10D), space-mark and space-space (FIGURE 10C).

65 A positive pulse is applied through resistor 149 in each of the "and" gates of the above-identified pre-amp stages. This causes the anodes of the two diodes, viz. for example, diodes 145 and 148 in the mark-space pre-amp 146, to go positive and thus apply a positive signal on lead 93 to the mark-space pre-amp, only if the cathodes of diodes 145 and 147 are both at a positive potential. If either cathode is at a negative potential, the anode of that diode and hence conductor 151 cannot rise to a higher positive potential and the pulse is accordingly blocked from being transmitted along lead 151 to the pre-amp.

If a mark pulse appears at input ① of the No. 1 second register storage stage 88, the circuit will transfer to its other stable condition whereby a positive voltage of about 3 volts is applied on lead 143 to the cathode 144 of diode 145 in the mark-space pre-amp circuit 146 and to cathode 147 of the mark-mark pre-amp circuit both in FIGURE 10D.

A second output signal is supplied from the No. 1 second storage register on lead 152 which is applied to cathode 153 of the first diode in the space-space pre-amp, FIGURE 10C, and also to cathode 154 of the first diode in the "and" gate for the space-mark pre-amp shown in the upper righthand corner of FIGURE 10C. The signal on lead 152 is opposite in polarity to the signal on lead 143. Thus, when a space condition is indicated by the No. 1 second storage register, a positive voltage is applied on lead 152 to each of cathodes 153 and 154 of the space-space pre-amp and space-mark pre-amp respectively. If both of the other inputs are of proper polarity, an output signal from the pre-amp stage will be provided for a period of 2 milliseconds to energize the corresponding selector magnet coil.

The No. 2 second register storage stage operates in identically the same manner as does the No. 1 second register storage stage and is so wired with the selector magnet pre-amps that the positive voltage on lead 155 when a mark signal is present as the No. 2 code element is applied to cathode 156 of the second diode in the "and" gate of the space-mark pre-amp shown in the upper righthand corner of FIGURE 10C and to the cathode 157 of the second diode in the "and" gate of the mark-mark pre-amp in the lower righthand corner of FIGURE 10D.

When the No. 2 code signal of the incoming Baudot code is a space, the positive voltage on lead 158 of the No. 2 second register storage stage is applied to the cathode 159 of the second diode in the "and" gate for the space-space pre-amp shown on FIGURE 10C and through lead 158 to cathode 160 of diode 148 of the "and" gate for the mark-space pre-amp 146 shown in FIGURE 10D.

The four magnet coils designated M-S at the output of the mark-space pre-amp and M-M at the output of the mark-mark pre-amp of FIGURE 10D and S-M of the space-mark pre-amp and S-S of the space-space pre-amp of FIGURE 10C are momentarily supplied with a current from their corresponding pre-amp stages for a period of approximately 2 milliseconds to thus energize the one-out-of-four selector magnets which will be effective to cause the desired character to be printed and punched on the paper tape.

As is apparent from FIGURE 2, each of the four selector magnets has associated therewith eight code bar elements. These eight code bar elements are accessible from one end of a wheel which turns at a uniform angular velocity of approximately 3700 r.p.m. and a particular one of the code elements which is selected depends upon the precise moment of energization of whichever of the selector magnet coils S-M, M-M, M-S and S-S that is chosen.

Referring now to FIGURE 5, a series of pick-up coils 500, 501, 502, 503, 504 and 505 are illustrated in a physical position relative to the permanent magnets 488 A through L mounted on wheels which turn synchronously with the code rod wheel shaft 292. The four permanent magnets 488 on each of the three sections of the wheel are so related relative to the two fixed pick-up heads that currents are generated through the coils which correspond to the No. 3, No. 4 and No. 5 code impulses of the Baudot code so as to provide a gating signal which will energize one of the code bar selection magnets S-M, M-M, M-S and S-S of FIGURE 2 at precisely the correct moment.

In the position illustrated in FIGURE 5, an output signal will appear in the mark coil 504 in the "A" plane since a permanent magnet 488 is immediately adjacent pick-up coil 504 but no signal will appear from the space pick-up coil 505; similarly, in the "B" plane, an output

signal will appear from mark coil 502 but no signal will appear from space coil 503; and in the "C" plane, an output signal will appear from the mark coil 500 but none from the space coil 501. As the pick-up coils appear in the "A," "B" and "C" planes which correspond to the last three code impulses of Baudot code, it is possible at this point in time to select the code bar element corresponding to: "letters" if the first two Baudot code impulses are mark-mark; "X" if the first two code elements are mark-space; "V" if the first two code elements are space-mark; and "M" if the first two code elements are space-space.

As the code wheel shaft 292 rotates one-eighth of a revolution counterclockwise, an output signal will be obtained from the wheel in the "A" plane from mark coil 504 and none from the space coil 505. In the "B" plane, no signal will appear from the mark coil 502 at this position, but an output signal will appear from the space coil 503. In the "C" plane, no output signal will appear from the mark coil 500, but an output signal will appear from the space coil 501. Thus, at a position 45 degrees counterclockwise from that illustrated in FIGURE 5, an output signal will appear from the mark coil 504 and from the space coils 503 and 501 to indicate the No. 2 code position of the code wheel which makes available the code rods for the letters U, S, I and "space," depending upon whether the first two code elements are mark-mark, mark-space, space-mark or space-space respectively.

As is apparent from the chart in FIGURE 6, the mark coil 504 in the "A" plane will provide an output signal at each of the first four positions and then the space coil 505 in the same plane provides an output signal in the last four positions as the code wheel shaft makes one revolution. In the "B" plane, the mark coil 502 provides an output signal at the first, fourth, fifth and eighth positions whereas the space coil 503 provides an output signal at each of the second, third, sixth and seventh positions. In the "C" plane, the mark coil 500 provides output signals at the odd numbered positions whereas the space coil 501 provides output signals at the even numbered positions. Thus an output signal is provided from one or the other of the mark or space coils in each of the "A," "B" and "C" planes at each of the eight positions of the code rods around the code wheel shaft to thus provide three output signals indicative of the code wheel position at each of the 45° points on the code wheel.

The several pick-up coils 500-505 are shown at the bottom center in FIGURE 10C and numbered with the corresponding reference numerals. One terminal of each of the pick-up coils 500-505 is connected to a separate anode of a series of six diodes having their cathodes connected in parallel to thus form an "and" gate. In this gate circuit, the common cathode conductor 161 is held at a positive potential of approximately 0.2 volt so long as any one of the anodes of the diodes is connected through pick-up coils 500-505 to a positive voltage at the lower terminals of the resistor network 162. The upper terminal of each of the 15K resistors is connected to ground.

The upper terminal of each of the 22K resistors is connected to one or the other of the output terminals from each of the No. 3, No. 4 and No. 5 second register storage stages 88. When the No. 3 code signal is a space, a positive voltage of approximately 3 volts appears on lead 163 while a negative potential of about the same magnitude appears on the adjacent lead 164. The corresponding output leads 165 and 166 from the No. 4 second register storage stage shown in FIGURE 10D are connected to the next pair of terminals of resistor bank 162. Output leads 167 and 168 are connected from the No. 5 second register storage stage 88 to the third pair of resistors in the resistor bank 162.

When the input signals to Nos. 3, 4 and 5 second storage stages are all marks, then the lefthand side of each of the second storage register stages 88 for the

Nos. 3, 4 and 5 signals is conducting thereby providing a positive output signal of approximately 3 volts on leads 164, 166 and 168 respectively and negative voltage of approximately 3 volts on each of the leads 163, 165 and 167 respectively. The only time that a negative going output pulse can appear on the common cathode conductor 161 is when each of the anodes of the six diodes is made negative since so long as any anode is retained at the slightly positive potential, the voltage drop across that particular diode, being substantially zero in its forward direction, prevents the cathode from dropping to a negative value.

Three of the anodes are always connected to positive voltages in resistor bank 162 irrespective of whether the code signals are a mark or space, and it is necessary that the negative going voltage pulse supplied by each of pick-up coils 500-505 as the result of the rotation of a permanent magnet 488 as shown in FIGURE 5 past the pick-up coils to be present in the particular ones of the anode circuits which are connected to the positive voltage from the Nos. 3, 4 and 5 second register storage stages 88 before a coincidence can be indicated.

Under the assumed example where the positive voltages are supplied on leads 164, 166 and 168 corresponding to a mark signal in each of the No. 3, No. 4 and No. 5 second register storage stages, a coincidence will be indicated when a neutralizing voltage of negative polarity is provided by the corresponding pick-up coils 500, 502 and 504. This condition exists only at the position of the code rod selection shaft illustrated in FIGURE 5 where a permanent magnet 488 is in operative relation with each of the mark coils: 500 in the "C" plane, 502 in the "B" plane, and 504 in the "A" plane. At this point in time, a negative going coincidence indicating pulse is provided on conductor 161. A positive going pulse then appears on lead 92 as illustrated in the timing chart of FIGURE 13 and is applied to the input of the 2 millisecond control gate pulse generator. The output signal on lead 93 at test point (TP)30 shown also in FIGURE 13 is applied to resistors 149 in the "and" gates for each of the mark-space, mark-mark, space-mark and space-space pre-amp stages to thus trigger the one of the four stages which has a positive voltage applied to the cathodes of each of the diodes in the associated "and" gate into a conductive condition to thereby energize the corresponding selection magnet.

The leading edge of the output signal from the 2 millisecond control gate generator on lead 93 is applied as an input signal to the feed delay stop gate which is shown in FIGURE 10D at the upper center position. The output signal from left stage on lead 169 is applied as an inhibitor signal to the common cathode conductor 161. In its "no signal" condition, the voltage on lead 169 is approximately a negative 3 volts while the signal during the 5 millisecond gating period is a positive 3 volts. This positive voltage signal is sufficient to prevent conductor 161 from going negative even though a coincidence is registered by all of the anodes of the diodes connected to conductor 161.

The 5 millisecond delay provided by signal on lead 169 is necessary to assure that the mechanical functions of the reperforator and printing unit are completed before the next coincidence position can be detented. During the interim of this 5 millisecond delay, each of the second register storage stages 88 are triggered back to their "no signal" condition by the trailing edge of the 2 millisecond pulse from the 2 millisecond control gate pulse generator output lead 93.

The signal on lead 93 is also applied to the search register stage shown at the upper center of FIGURE 10C. The search register stage is a bi-stable circuit having a voltage output signal at test point (TP)31 which is shown in FIGURE 13. The positive voltage level of the signal at TP 31 on lead 170 is a positive 3 volts whereas the

negative going portion of the signal is a negative 3 volts. The output signal on lead 170 is applied to the common cathode conductor 161 of the "and" gate in the shaft position coincidence detector circuit and is effective to prevent a coincidence detection signal from being indicated when the search register has been triggered by the signal on lead 93 which causes the positive voltage to appear on lead 170.

The search register bi-stable circuit is triggered to its "read-out" condition by the sync input signal on lead 173 which is provided from the receiver-selector when no storage unit is present and from the storage unit when it is used. In FIGURE 10A, the read-out signal on lead 90 is delayed by 50 to 100 microseconds from the read-out signal on lead 82 which causes the signals stored in the first register storage elements 78 to be read out and applied to the second register storage circuits 88 shown in FIGURES 10C and 10D. The sync input signal from lead 90 of FIGURE 10A is then applied to lead 173 shown in FIGURE 10C to thereby trigger the search register to cause the voltage on lead 170 connected to the common cathode conductor 161 to be negative. Since the sync pulse on lead 173 to the search register trails the code element signals which are applied to the second register storage stages, the controller unit is ready to "read-out" by the time the search register triggers to unblock the shaft position coincidence detector circuit.

Summarizing then, an output signal from the shaft position coincidence detector circuit cannot be obtained within the first five milliseconds after a character is indicated and the code rod selected because of the inhibit voltage on lead 169 provided from the feed delay stop gate shown in FIGURE 10D. After this 5 millisecond delay, a coincidence signal still cannot be indicated until the search register is triggered to remove the positive voltage from lead 170. Since the sync input signal on lead 173 to the search register is delayed slightly behind the incoming code signals to the second register storage circuits 88, the search register does not open until after the second register storage stages have received the code elements of the next code character to be processed by the reperforator unit. As soon as the search register has triggered and the positive voltage on lead 170 is removed, the shaft position coincidence detector is ready to provide an output signal as quickly as the code wheel shaft rotates to a position so that the output signals from the pick-up magnets 500-505 register a coincidence with the No. 3, No. 4 and No. 5 code elements of the coded signal then in the second register storage stages 88.

As is apparent from FIGURE 13, at the time period of 2 milliseconds after a coincidence has been indicated by the shaft position coincidence detector, the signal which has been transferred to the mechanical portion of the reperforator unit through the selection of the corresponding code rod element is then discarded from the second register storage stages 88 and any time after the end of this 2 millisecond delay, the second register storage stages 88 are ready to receive the next incoming coded signal.

When the storage unit is used and when the incoming signal comprises two or more characters, which because of their physical position on the code wheel, cannot be selected within the time interval between transmission of the successive code elements so that there is a backlog of characters in the storage unit waiting to be processed by the machine, the next character can be pulled out of the storage unit and applied to the second register storage stages 88 immediately after the search register signal on lead 170 becomes positive. This signal is applied to the storage unit as indicated in FIGURE 10C to thus permit the storage unit to send the next character to be recorded to second register storage stages 88 in the controller unit of FIGURE 10C. Accompanying such signals is a signal on the sync input lead 173 to the search register to thereby trigger the search register to its operating condition again which conceivably could occur before the end of the 5

millisecond feed delay period expires. In that event, the positive voltage on lead 170 to the common cathode conductor 161 of the shaft position coincidence detector will be removed before the positive voltage on lead 169 from the 5 millisecond gate is removed so that immediately upon completion of the 5 millisecond period, the shaft position coincidence detector circuit will be capable of registering the next coincidence, which with a most favorable sequence of letters could be after $\frac{1}{6}$ of a revolution of the code wheel shaft 292.

With a favorable sequence of letters, it is possible to process characters through the reperforator and printing unit of the present invention at the rate of over 2 for each rotation of the code wheel shaft 292. This corresponds to a rate of about 160 characters per second.

In FIGURE 21, a timing chart is shown wherein the top row of numbers represents milliseconds during the operation of the machine at its top design speed of 75 operations per second. This chart shows that with the best sequence of characters, the rate of selection is such that every twelfth code bar can be selected which corresponds to a selection of a new character about once every six milliseconds. However, with the worst sequence of characters, the time period between two successive characters may be more than twenty-one milliseconds.

To prevent the loss of any transmitted characters, it is necessary to operate at a rate slower than 50 operations per second, which would correspond to 20 milliseconds per operation. To increase the speed of operation of the present invention to 75 operations per second, which it is capable of doing successfully, a storage unit, which will be described below and which is of the type that holds the code signals representing the characters received in their proper sequence, is provided to make the code signals available to the second register storage stages 88 at whatever rate the reperforator and printing unit can process the information.

From the foregoing, it is apparent that the output signals from the storage unit may be called for with time intervals between the successive signals varying from 6 milliseconds to 21.5 milliseconds.

At rates of signal transmission less than about 48 operations per second where the storage unit is not used, a coincidence signal cannot be provided from the shaft position coincidence detector so long as the search register stage of FIGURE 10C indicates that there is no signal stored in the second register storage stages 88. Thus the controller unit stands ready to receive signals at any frequency less than the maximum range for which it is designed and thus receive hand typed messages where there may be delays of up to several seconds between successive characters.

AUXILIARY FUNCTIONS

Manual Tape Feed-Out

Tape feed-out is effected through a push button 222 shown in FIGURE 1 which is manually operable to advance the tape for the purpose of removing the tape from the machine after a signal has been received. In FIGURE 10D, the tape feed-out button operates switch contact member 222 to transfer it to its alternate position when it is manually depressed. This applies a negative potential of 4.5 volts on lead 171 to trigger the tape feed-out register to its alternate conduction condition.

The output signal on lead 174 from the tape feed-out register varies from a positive 3 volts to a negative 3 volts on the depression of switch contact 222. When a positive 3 volts appears on lead 174, this voltage is applied to the cathode 175 of the diode 176 having its anode connected to lead 170 on which lead the output signal from the search register appears. When the output signal on cathode 175 is a positive voltage, it does not interfere with the previously described operation of the circuit. However, when the output voltage on lead 175 is a negative 3 volts, this has the effect of removing from lead

170 the positive 3 volts supplied as a blanking or inhibit signal which prevented the shaft position coincidence detector circuit from registering a coincidence during the time intervals when there is no code signal stored in the second register storage stages 88. The effect of the negative 3 volts on cathode 175 is to cancel the inhibit voltage on lead 170 and thus permit the shaft position coincidence detector to register coincidence in its usual manner, assuming the inhibit signal on lead 169 from the 5 millisecond feed delay stop gate is not present.

Since no signal is stored in any of the second register storage stages 88, each is in a space condition and the space-space selector magnet will be energized at the time when the cycle of rotation corresponds to the No. 6 position of the code wheel, which corresponds to all spaces as shown in the chart of FIGURE 6. This will be effective to punch a blank and will advance the tape one position for each revolution of rotation of the code wheel shaft 292.

If an incoming signal appears on the input line at the time when the tape feed-out button is depressed, at the time the signal is being stored in the first register storage stages 78 of the receiver-selector unit shown in FIGURE 10A, output signal from the 35 microsecond delay multivibrator on lead 138 causes the 5 millisecond delay circuit to operate and the output signal on lead 94 of that circuit which comprises a negative going pulse is applied to lead 94 and through the resistor capacitor shown in the upper lefthand corner of FIGURE 10D to lead 171 to thereby immediately trigger the tape feed-out register back to its normal condition. This removes the voltage from lead 175 so that the positive voltage on lead 170 from the search register will stop further output signals from common cathode conductor 161. The shaft position coincidence detector will then be incapable of indicating a further coincidence until after the input signal is applied to the second register storage stages 88 and the search register is transferred so that the positive inhibit voltage on lead 170 is again replaced by the negative voltage permitting the coincidence pulse on conductor 161 to be produced.

By the foregoing combination of circuit elements, the very first incoming signal which is received during a time interval when the manual tape feed-out button is depressed will be processed by the tape perforator unit of the present invention. In the prior machines of this type, the first signal has been used to disenable the manual tape feed-out button control and hence was lost and not printed or punched in the tape.

Letters Unshift and Figures Shift

The "figures shift" pre-amp stage 97 is shown at the lower righthand corner of FIGURE 10C and the "letters unshift" pre-amp 98 is shown in the center of the left-hand side of FIGURE 10E. As is apparent from the code element chart in FIGURE 6, the two code signals are identical except for the third code element. In the fifth position of the code wheel chart of FIGURE 6, the "figures" code consists of mark-mark-space-mark-mark whereas the code element for "letters" in the first position comprises five marks. With the No. 4 and No. 5 code elements being the same, the positive voltage signal present on lead 166 from the No. 4 second register storage stage 88 and the voltage signal present on lead 168 from the No. 5 second storage stage 88 are applied as the input signal to the "and" gate diodes 178 of the figures "shift" pre-amp stage and diodes 179 of the "and" gate in the input to the letters "unshift" pre-amp stage 98 in FIGURE 10F.

As is apparent from FIGURE 6, the No. 1 and No. 2 code elements for both letters and figures are mark-mark. Thus a signal is taken from the mark-mark pre-amp stage shown in FIGURE 10D on lead 177 and applied as an input signal to the case shift gate 181 on FIGURE 10E. The other two inputs to case shift gate 181 are applied

on leads 163 and 164 from the No. 3 second storage register stage 88 shown in FIGURE 10C, the positive pulse being present on lead 164 to thereby provide an output signal on lead 182 when the No. 3 code element is a mark which is applied resistor 183 to thus energize the "unshift" current coil of the magnet associated with the printing wheel to thus move the printing wheel to its "letters" printing position.

In the event that the output signal on lead 163 from the No. 3 second register storage stage 88 in FIGURE 10C is positive corresponding to a No. 3 code element that is a space, then the positive output signal from the case shift gate 181 in FIGURE 10E will be on lead 184 which is applied as the input signal to the figures "shift" magnet to be energized to shift the printing wheel to its "figures" position.

As will be explained below, the printing wheel is mounted on a shaft which is cam driven to one or the other of the two printing positions and stays in whichever position it is last placed until again shifted. At the upper lefthand corner of FIGURE 10F is a case register memory stage which comprises a bi-stable circuit having an input signal on lead 185 which comes from the letters "unshift" pre-amp stage 98 in FIGURE 10E and a second input lead 186 which extends from the correspondingly numbered output lead from the figures "shift" pre-amp stage in FIGURE 10C. The output signal on lead 187 is accordingly a minus 3 volts when the letters "unshift" magnet was last to be energized and a plus 3 volts when the figures "shift" magnet was last to be energized.

Signal Bell

The reperforator and printing unit of the present invention is provided with means for ringing a bell when the figures "shift" signal was received subsequent to a letters "unshift" signal and when the signal corresponding to S is received. The bell pre-amp stage is shown in the upper righthand corner of FIGURE 10E. On lead 164 of the "and" gate to the signal bell pre-amp stage 100 shown in FIGURE 10E, a positive input signal is applied from lead 164 from the No. 3 second storage register stage 88 in FIGURE 10C when the third code element is a mark signal. A positive input signal is applied on lead 165 to the other diode of the "and" gate for signal bell pre-amp 100 from the output lead of the No. 4 second register storage stage 88 in FIGURE 10C when the No. 4 code element is a space.

The input signal to resistor 189 of the "and" gate in the input of the signal bell pre-amp 100 is on lead 190 which comes from the output of the bell gate shown in the upper lefthand corner of FIGURE 10E.

The input signal to the bell gate on lead 188 is supplied from the output lead 188 of the mark-space pre-amp stage 146 in FIGURE 10D. The signal input for the No. 5 code element is on lead 167 from the output of the No. 5 second register storage stage 88 in FIGURE 10D. In order that an output signal will appear on lead 190 from the bell gate, there must also be the positive input signal on lead 187 from the output of the case register memory stage shown in FIGURE 10F which indicates that the figures "shift" had been energized subsequent to the energization of the letters "unshift" magnet. The input signal on lead 190 to the signal bell pre-amp stage thus occurs only when the figures "shift" has occurred subsequent to the last letters "unshift" signal and the letter S is transmitted. Only under those circumstances can the bell magnet coil be energized.

Ribbon Feed Drive

One of the ribbon feed clutch coils E-1 and E-2 shown on the righthand side of FIGURE 10F is normally continuously energized during operation of the machine to thereby provide for continuous drive of the ribbon in one or the other direction. An input control signal is sup-

plied across resistors 191 or 192 depending upon the direction of the ribbon feed. The signals applied to resistors 191 and 192 come from leads 193 and 194 respectively which are connected as the output leads from the ribbon direction register shown at the lower lefthand corner of FIGURE 10E. The ribbon direction register is a bi-stable circuit substantially identical to the bi-stable circuits used in the second register storage stages 88 and provides a positive voltage of approximately 3 volts on one of the leads and a negative voltage of approximately 3 volts on the other lead. The circuit receiving the negative voltage is cut off while the circuit receiving the positive voltage is caused to energize the selected associated ribbon feed clutch magnet E-1 or E-2.

The input signals to the ribbon direction register are applied over leads 195 and 196 to a normally positive voltage terminal. Two ribbon reverse sensing micro-switches S-1 and S-2 are provided, which momentarily close when one or the other of the ribbon spools is substantially empty to thereby reverse the direction of ribbon feed by means of the application of a negative potential applied through the closed micro-switch from a negative voltage terminal which is connected to one terminal of each of the two switches S-1 and S-2. Once a ribbon direction is established, the ribbon continues to feed in that direction until a reverse sensing micro-switch is closed to reverse the ribbon feed direction.

To stop the ribbon feed during long periods of no signal transmission of reception by the reperforator and printer unit of the present invention, a circuit is provided which prevents either of the ribbon feed clutch magnet coils E-1 or E-2 from being energized after a time interval of approximately 1 second has lapsed subsequent to the receiving of a signal from the incoming line. This circuit comprises a ribbon feed sustain circuit driver shown at the lower lefthand corner of FIGURE 10F which receives an input signal on lead 93 which contains the two millisecond control pulse provided at each time a coincidence is registered on common cathode conductor 161. The ribbon feed sustain circuit driver is a single shot multivibrator having an output pulse of approximately 30 milliseconds in duration which appears on lead 197. This pulse is applied as the input signal to the 1 second ribbon feed sustain circuit shown in the lower righthand corner of FIGURE 10E. This circuit provides an output signal on lead 198 of about plus 4 volts which is applied to the cathodes of diodes 199 in the input circuits to each of the ribbon feed clutch pre-amp stages.

Each time a pulse is received over input lead 197 to the one second ribbon feed sustain circuit, the 20 micro-farad condenser is charged sufficiently so that it will require a time period of about 1 second before the voltage level decays to the point where the transistor 200 conducts whereby the output voltage on lead 198 becomes approximately a negative 4 volts. When a negative voltage is applied to the cathodes of diodes 199 in the ribbon feed clutch pre-amp stages, both pre-amp stages are cut off and neither ribbon feed clutch coil E-1 or E-2 can be energized.

As soon as the next incoming signal is received by the controller unit and a coincidence is indicated, the output signal from the ribbon feed sustain circuit driver on lead 197 recharges the condenser in the 1 second ribbon feed sustain circuit to thereby provide a positive voltage on lead 198 and unlock the ribbon feed clutch pre-amp stages. One or the other of the ribbon feed clutch pre-amp stages is then conductive depending upon the output signal provided by the ribbon direction register on leads 193 and 194.

STORAGE UNIT

The storage unit is illustrated in FIGURES 14-19. As the sequence of the characters received over the incoming transmission line is random and as the rate that 75 characters can be processed by the reperforator and

printing unit of the present invention depends upon the sequence of the characters, the use of the storage unit of the type herein described makes possible the operation of the equipment at an average speed of nearly 50% greater than the slowest speed which would have to be used in the event that no storage unit is provided to prevent the loss of certain characters in the transmitted message.

It is possible that certain sequences of letters may be processed by the mechanical part of the apparatus at the rate of approximately 160 operations per second, that is one selection for every $\frac{3}{8}$ revolution of the code bar selection wheel. However, with certain adverse sequences, the code bar selection wheel may have to be searched for $1\frac{1}{4}$ revolutions, as is apparent from FIGURE 21. The extra $\frac{1}{4}$ revolution is necessary since the first twelve characters following selection may not be used because the mechanical functioning of the apparatus requires a minimum of 4 or 5 milliseconds to complete an operation. Therefore, under the worst conditions a printing rate of about 50 operations per second is maximum.

A mathematical determination of the probability of error has shown that a storage capacity of only 20 characters is adequate to realize a mean selection rate in excess of 75 operations per second. Therefore, 20 signal storage channels are shown in FIGURE 14, each having a storage capacity for 6-bit characters.

The 5 input signal elements plus the sync pulse are supplied to the storage unit in parallel and processed to the storage unit simultaneously as evident from FIGURE 14.

An input distributor is provided for selectively opening the various signal storage channels 1 through 20 in a sequential manner. A gating circuit is provided so that when the beam switching tube opens a particular channel, the 6 input pulses are applied to this storage channel and the distributor is then advanced to the next successive channel. The input distributor advances one position for each character received and at the rate of the incoming signal. The control signal on the sixth wire which serves as a syn pulse and causes the input distributor to advance immediately after its accompanying 5 unit signal is sent to the signal storage channel.

In the particular embodiment described, a beam switching tube identical to that shown in FIGURE 10A has been used as the input distributor. As this tube has only 10 target electrodes and as 20 signal storage channels are required, the various signal storage channels have been grouped in pairs and a decade selector gate circuit provided to select alternately all the odd-numbered and then all the even-numbered signal storage channels. Upon reaching the No. 7 terminal of the beam switching tube, the decade selector is triggered to provide a signal which then transfers the operation from odd to even or from even to odd. The beam switching tube, however, could advantageously be replaced by other types of known distributors employing thyratrons or vacuum tube trigger circuits to eliminate the use of the decade selector gating stage.

The output signal from the storage unit in FIGURE 14 is applied as the input signal to the second register storage stages 88 in FIGURES 10C and 10D. The storage unit must be of the first-in, first-out type since it is essential that the signals be supplied from the storage unit in the same sequence or order in which they are received. Therefore, the output distributor, which is totally independent of the input distributor, must search the various storage channels for stored signals in the same order in which the input distributor places them in the storage unit.

When the output distributor finds a storage channel with a signal stored, the output distributor serves to discharge or read-out all six of the individual storage signal elements simultaneously. Once a signal is found by the read-out distributor, a blanking pulse is provided from the search register to prevent the distributor from ad-

vancing to the next storage channel until after the code rod is selected.

The output distributor is operated at a relatively high frequency, for example at a frequency of about 1 kilocycle, so that once it catches up with the input distributor, it can pass the input distributor position and rapidly advance through each of the other 20 storage channels to again return to the particular storage channel where the next signal code elements have been stored. Thus, if the input signals were coming in at a high speed, they will be stored in channels 1, 3, 5 . . . . As soon as the unit is ready to process the next character, the output distributor will stop at the storage channels 1, 3, 5 . . . in the same sequence and will be advanced at a rate exactly equal to the maximum speed at which the mechanical apparatus can process the characters. The output distributor only becomes free-running when it is completely caught up with the input signals.

Suitable blocking pulses are provided during the time period required to place a signal in one of the storage channels which prevents the output distributor from removing a signal from any storage channel. Also, a similar blocking signal is provided each time the output distributor advances to allow the circuits to reach a stable or quiescent state before attempting to read-out a stored signal.

Referring now to FIGURE 15, the input distributor in the upper lefthand corner and the output distributor in the upper righthand corner are each illustrated as having 20 switching positions for purposes of simplification of this description. Each storage channel is illustrated in a vertical column and comprises a control stage A-A and 6 storage stages B¹, B², B³, B⁴, B⁵ and B⁶. The second storage channel is similarly designated and as each of the 20 storage channels are identical, only 5 are diagrammatically illustrated in this figure.

The No. 1 input signals are applied in parallel to each of the first code element storage stages having the superscript 1. Each of the remaining code elements 2-5 are applied in parallel to the corresponding code element storage stages having the correspondingly numbered superscripts. The sync signal on lead 6, which is always a negative pulse, is applied to the storage element having the superscript 6.

When a signal is supplied to the storage unit, the input distributor is in a condition providing an input gating signal to the next open storage channel. In the embodiment illustrated in FIGURE 15, the distributor is shown in a position whereby the No. 3 storage channel is open and no input signal can be provided to the remaining 19 storage channels. Thus, the input signal applied through the leads marked 1 through 6 is stored in the No. 3 channel and the input distributor is then advanced to its next position corresponding to the No. 5 channel.

When the output distributor advances to the No. 3 channel, a signal is provided to the control circuit represented by the block A₃ which then produces a read-out signal that is provided simultaneously to each of the storage stages in the third signal storage channel to thus provide an output signal on leads 1 through 6 near the center of FIGURE 15 and which are inscribed in a square. These output signals are then inverted and supplied to the second register storage stages 88 in the controller unit of FIGURES 10C and 10D.

A blocking signal is supplied to the output distributor to prevent it from advancing to the next signal storage stage until after the signal from the third storage channel has been processed by the mechanical unit. This blocking pulse is supplied from the search register of the controller unit and when the search register is restored to its non-operating condition by the trailing edge of the 2 millisecond pulse which was initiated by the output signal of the shaft position coincidence circuits, the blocking signal is removed from the output distributor of the storage unit so that the distributor moves to the next storage channel, which in the illustrated example will be

the No. 5 storage channel. If there is a signal in the No. 5 storage channel, the distributor stops until that signal is processed by the mechanical unit. If there is no signal in the No. 5 storage channel and no further signals are being received by the storage unit, the output distributor will continue to advance at its cyclic rate of approximately 1 kilocycle until the next incoming signal is received.

FIGURE 16 is a block diagram of the logic used in a single channel of the storage unit. The incoming coded signals are provided at the upper input leads 1 through 6 while the output signals are taken from the lower leads marked 1 through 6. The gate pulse from the input distributor is applied on lead 1601 and the read-out or gating pulse from the output distributor for removing signals from the signal storage channel is provided on lead 1602.

In FIGURE 17, the lower circuit B is a detailed circuit of each of the stages "B" shown in FIGURE 15 and of each of the six stages represented by the logical symbols in FIGURE 16. The circuit for providing the read-in and read-out signals on leads 1601 and 1602 respectively is designated A. All of the 20 signal storage channels are identical.

The incoming signals supplied to the basic storage circuit comprise negative going pulses having a zero signal reference level of about positive 2 volts and a lower voltage level of about a negative 17 volts. These pulses are applied to anode 1702 of diode 1704. On lead 1601, the read-in pulse is a similar negative going pulse having a reference voltage of about ground level and a negative pulse having an amplitude of about a minus 17 volts. When both negative going pulses appear simultaneously, a negative charge is stored on capacitor 1705.

The anode of diode 1703 is connected to read-out pulse line 1602 which is normally supplied with minus 17 volts and there is accordingly no discharge path for the negative voltage stored on capacitor 1705.

When it is desired to read-out the signals stored in the storage unit, a positive voltage pulse is applied on lead 1602 which discharges capacitor 1706 through diode 1708 and provides a positive pulse on output lead 1710 which indicates that the signal code element in that particular stage of the storage unit was a mark. If the code element is a space, there is no input signal on lead 1 and accordingly no output signal after the read-out pulse is supplied.

The input signal to the control circuit A from the input distributor is on lead 1712. Diode 1714 serves as a gate to block any input signal when a positive signal is applied to the input terminal on the anode 1716 of diode 1714. Where a 10 position beam position switching tube is used as a distributor for a 20 signal channel storage unit, the decade selector gate shown in FIGURE 14 is provided to alternately gate open the even numbered signal storage channels and then the odd numbered signal storage channels. A positive impulse is applied to the anode 1716 of diode 1714 to prevent the associated read-in circuit from being triggered by the input pulse on lead 1712 from the input distributor.

A similar read-out pulse is applied to control circuit A on lead 1718 from the read-out distributor. Diode 1720 is provided to block the input signal to the read-out lead at certain time periods during the operation of the storage unit through the application of a positive voltage potential on the input lead 1722. Control circuits which will be described in connection with the circuit shown in FIGURE 19 are provided to supply blanking pulses during the 600 microseconds required for supplying an input signal to a storage channel to thereby prevent the output distributor from scanning into a signal storage channel which is receiving a signal and also for a period of 75 microseconds during the transition of the output distributor between adjacent output terminals.

Referring now to FIGURE 18, the input signals to the storage unit appear, on the lines marked ①, ②, ③, ④, ⑤

and sync input. These signals are supplied directly from the correspondingly designated terminals from the first register storage stages shown in FIGURE 10A. The sync signal is that which is used as the read-out signal for the first register storage stages 78 and is supplied from lead 82.

With continued reference to FIGURE 18, the input signals corresponding to the coded elements in the Baudot code are applied to the No. 1, No. 2, No. 3 and No. 4 circuits shown in this figure and to the No. 5 read-in circuit shown in FIGURE 19. Each of these read-in circuits comprises a single shot multivibrator providing a negative output pulse of 500 microseconds duration when the corresponding code element is a mark and no output pulse when the corresponding code element is a space. In the overall system, the output signals from the read-in single shot multivibrator stages are applied to correspondingly numbered leads shown in FIGURE 15 as the input signals to the several storage channels.

Referring now to FIGURE 19, the sync input signal from lead 82 of FIGURE 10A is applied to a similar single shot multivibrator providing a negative output pulse of 500 microseconds duration which is applied in each instance as a mark in the No. 6 position in the signal storage channel. The output signal from the sync input stage on lead 1900 is applied as the input signal to the read-in pulse generator stage which comprises a single shot multivibrator having as an output signal on lead 1902 a positive going pulse of 600 microseconds duration. This pulse is applied through lead 1904 to the input beam switching tube driver stage on FIGURE 18. The trailing edge thereof, being a negative going pulse, is effective to trigger the beam switching driver tube. The trailing edge occurs about 100 microseconds subsequent to the trailing edge of the pulses of the several coded signal elements. Thus the input distributor is advanced immediately subsequent to the placement of the coded signal elements in the signal storage channels.

The read-in decade selector stage shown in FIGURE 19 receives an input signal on lead 1906 each time the beam in the beam switching tube passes a particular pre-designated target electrode. This causes the decade selector circuit, which is basically a bi-stable circuit, to trigger from one conduction condition to its alternate conduction condition. One of the output leads is connected to the odd numbered signal storage channels and the other output lead is connected to the even numbered signal storage channels. Whichever lead contains the positive going output signal is effective to block each of the signal storage channels to which it is connected, thereby causing the distributor to complete one cycle of operation using the even numbered signal storage channels and on the next cycle of operation to use the odd numbered signal storage channels. This circuit is required only because beam switching tubes which are commercially available have only 10 target electrodes and by the use of such decade selectors, it makes it possible for the distributor for the beam switching tube to serve 20 separate signal storage channels. If other types of electronic distributors are used, such a decade selector would not be required.

60 The output distributor for the storage unit is driven by the output beam switching tube driver in a conventional manner and similar to that described in connection with FIGURES 10A and 10B. The input signal to the output beam switching tube driver is supplied on lead 1908 from an output terminal on read-out scanning signal generator which in this particular embodiment is a free-running multivibrator operating at a frequency of approximately 1 kilocycle.

65 The output signal on lead 1908 from the read-out scanning signal generator is also applied as an input signal to a 75 microsecond pulse gate generator which may comprise a single shot multivibrator that provides a positive going output signal pulse having a duration of 75 microseconds. This pulse appears on lead 1910 and is applied

as an input signal to the "or" read-out gate shown also in FIGURE 19.

The main input signals to the read-out gate come from the output terminals 1912 and 1914 of the read-out decade selector circuit. This circuit has an input signal on lead 1916 which is derived from the read-out beam switching tube from a predetermined target electrode so that this circuit, which is a bi-stable circuit, is triggered to its alternate conducting condition once each revolution of the beam switching tube. The output signals on leads 1912 and 1914 are alternatively positive or negative depending upon the conduction of the circuit.

Also applied as an input signal to the "or" read-out gate is the positive going output signal of 600 microseconds in duration on lead 1902 from the read-in pulse generator. The output signals from this read-out gate are applied on lead 1920 to the odd signal storage channels and on lead 1922 to the even numbered signal storage channels. This read-out gate circuit is an "or" gate whereby the voltage on the output leads 1920 and 1922 will be positive if a positive input signal is applied on either of input lead 1910 from the 75 microsecond pulse gate generator or lead 1902 from the read-in pulse generator. Also, the output signal will be a positive voltage level on lead 1920 if the input signal from the read-out decade selector on lead 1914 is positive and the output signal on lead 1922 will be positive if the signal on lead 1912 is positive.

As explained in connection with FIGURE 17, a positive input voltage on the anode of diode 1720 will prevent a read-out signal from occurring even though the read-out distributor may pass the particular storage stage. Therefore, an output signal from the storage unit cannot be obtained for the first 600 microseconds subsequent to the beginning of the signal storing operation or for the 75 microseconds following the advancement of the read-out distributor. These delays are necessary to permit the various circuit transients to subside and the circuits to reach a stable condition to assure reliable operation.

The alternate positive voltage conditions provided on leads 1912 and 1914 are used solely in this embodiment to compensate for the fact that the beam switching tube as a distributor has only 10 output stages whereas 20 signal storage channels are used which thereby requires that a decade selector be provided. As pointed out above, this circuit could be dispensed with in the event a 20 stage distributor is used.

The read-out scanner is provided with an input lead 1924 which is connected to the search register in FIGURE 10C. It will be recalled that the search register is a bi-stable circuit which is triggered by the sync pulse accompanying the coded signal indicating that the coded signal has been supplied to the second register storage stages 88 in FIGURES 10C and 10D. Upon reception of this sync signal, the search register transfers to its alternate condition thereby removing the inhibit voltage on the common cathode conductor 161 to the coincidence detector stage to permit a coincidence to be indicated as soon as the code wheel shaft 292 rotates to the proper position as determined by the particular code rod element to be selected. During the interval of time required for the shaft position coincidence detector circuit to indicate a coincidence and trigger the 2-millisecond gate generator which is effective to transfer the search register back to its no signal condition, a blanking pulse appears on lead 1924 to prevent the read-out scanner in FIGURE 19 from advancing the read-out distributor. When the trailing edge of the 2 millisecond pulse resets each of the second register stages 88 to their signal receiving position, the blanking pulse on lead 1924 to the readout scanner in FIGURE 19 is cut off to thereby permit the output distributor to advance to the next signal storage stage. Immediately when the next occupied signal storage stage is found, a read-out cycle occurs.

Referring now to FIGURES 15 and 18, the stored signals appear on leads marked 1, 2, 3, 4, 5 and 6

in the center of FIGURE 15 and are applied to correspondingly numbered leads along the top of FIGURE 18 to the inverter read-out stages which invert the positive going pulses provided on the output leads of the storage stages to negative going pulses which are applied to the input of the second register storage stages 88.

The No. 6 signal from this storage unit is the sync signal and this signal is applied to a 100 microsecond sync delay stage which comprises a one shot multivibrator and is shown in the lower lefthand side of FIGURE 18. The input signal is applied to lead 1930; the output signal is on lead 1932 and is applied as the sync signal to the read-out register in FIGURE 10C. By the time the sync signal arrives, the coded signals to the second register storage stages will have been received and have transferred those bi-stable circuits to a conduction condition representative of the particular coded signal being transmitted. The search register is then triggered by the incoming sync signal from the storage unit to thereby open the shaft position detection circuit to enable it to register a coincidence at a point of time when the code rod corresponding to the transmitted signal is in a position to be transferred by the appropriate code rod selection magnet.

PRINTER-REPERFORATOR ASSEMBLY

The organization of the assembled mechanical components of the printer-reperforator 58 is illustrated in FIGURE 1, to which reference will be made, as necessary, in the following specific description of the various elements. In FIGURE 1, it will be seen that the machine base portion 61 has the shape of a flat rectangular box with support pads 202 located at each of the four corners. Chad drawer 62 is disposed in the forward portion of the base 61 and an upper wall 204 of base 61 provides support for the selector 52, controller 54 and the printer-reperforator subassembly 58. This description will be based on a machine using the standard five-unit Baudot Code and having a $\frac{1}{8}$ inch wide paper tape recording medium (fan fold recommended). It is to be understood that codes of more or less than five units and other width paper tapes may be utilized in accord with the concepts and teachings of this invention.

Still referring to FIGURE 1, the paper tape 206 enters from the right-hand side of the machine, passes through the perforating and printing section and exits from the left-hand side of machine 50. A dust cover 208, illustrated in phantom lines, covers the upper components 52, 54 and 58 and is secured to the top plate 204 of base portion 61 by thumb screws 210. The front portion 212 of cover 208 is hinged along an upper horizontal edge 214 and includes a window 216 through which the message being printed on tape 206 will be visible to the operator. This hinged front portion 212 can thus be raised to enable access to the operating controls, for any necessary adjustments to the machine and also to enable the tape and ribbons to be serviced. Operator manipulated controls for this machine consist of a power on-off switch 220 and a button type manual tape feedout switch 222 located on a small panel at the right-hand front side of the reperforator 50. Installation operating controls, such as range, bias, mode selector, line current and fuses can be seen on the front wall of the upper box containing selector 52 and controller 54. These units have been described in the foregoing description pertaining to the electronic equipment.

Printer-reperforator assembly 58 is unitarily mounted on a solid base plate 230 which in turn is supported by shock mounts 232 on the machine base top wall 204.

All D.C. and A.C. regulated voltages are supplied through the upper portion of unit 50, i.e., the box which houses the selector 52 and controller 54. Adequate filtering, regulation and isolation are provided to insure reliable operation of the equipment under conditions of line voltage and frequency variations of from 90 to 125 volts A.C., and 50 to 60 cycles per second. Power am-

plifiers are also provided in unit 50 to operate four code rod selector magnets, two type wheel shift magnets, two ribbon feed clutch magnets and a signal bell magnet, as will be hereinafter described.

In accord with the foregoing description, the basic principle of operation for the mechanical punching, printing and feed functions of the reperforator 50 resides in rotation of thirty-two (32) code rods past a reference point (or points having a common time base). Each rod has the mark element or elements of its representative character machined in as interference flanges. To facilitate the high speed aspect, the thirty-two (32) code rods are separated and placed in two code wheels, although it is to be understood that all thirty-two (32) code rods could be utilized in just one wheel or in more than two wheels. However, in the illustrated mechanism, which uses two code wheels, there are sixteen (16) code rods per wheel. Within each code wheel the sixteen (16) rods are arranged in two groups, eight (8) code rods protruding from each end of each code wheel. The afore-mentioned four code rod selector magnets actually control latches for spring biased selector plungers, one for each group of eight (8) code rods. Each selector plunger is reciproable in a path parallel with the code rods and aligns with each code rod as the code rods are rotated past the plunger locations.

Each function (print, five-code punch assembly, feed hole punch, punch retraction and tape feed control) has mechanisms enabling operation by code rods in both of the two code wheels. A type wheel rotates above the print hammer, and the two code wheels and the type wheel rotate at 3750 r.p.m.

Whenever the electronic controller, through a received code signal combination, actuates one or the afore-noted magnets MM, MS, SS, SM, the associated selector plunger latch arm will be attracted by the magnet releasing the plunger which moves to an interference condition with the desired code rod. The pop-out plunger hammer moves into the path of the selected rotating rod just before it arrives at its reference or selection point. This causes an impact between the pop-out plunger hammer head and the code rod head experiencing an elastic impact between the two elements with the result that both will be driven away from each other. The pop-out plunger moves back to strike an energy absorbing arm where it will stop and its latch can drop into position holding the selector plunger ready for its next release. The impacted code rod will be driven into the wheel, a distance of 0.05 inch, and will be secured by an associated latch located within the code wheel. In this latched position, the code rod interference flanges engage intermediate transfer arms to operate associated function mechanisms including print hammer, code punches, code punch retractors and feed release pawl. As the rotating wheel carries the code rod on around its path, an internal cam pulls the code rod latch away from the code rod and a second cam shifts the code rod slightly out of the code wheel into a non-interference, normal position ready for another impact positioning operation. The cycle of afore-described functions of a code rod require one revolution of the code wheel.

Tape feed is realized through a sprocket feed wheel which is kept under continuous rotational bias from a motor driven pulley wheel operating through a friction clutch, and a torsion spring drive rod. The tape feed sprocket wheel itself is retained against rotation by a feed release pawl and whenever an operation occurs, the feed release pawl is removed permitting the tape feed sprocket to rotate under torsion spring bias. The movement of the feed release pawl is timed to occur in less time than that required by the sprocket feed ratchet wheel to move one tooth (one space of the tape). Therefore the feed release pawl is always back in a position to engage the next tape feed sprocket ratchet tooth before the tape has been fed past its next position.

The ink ribbon is carried on two spools and can be power driven in either direction through a reversing clutch mechanism. The reversing clutch is held in a drive position so long as message code units are being received by the electronic selector. Whenever signals are not received within a one second period, the ink ribbon feed is disengaged and the ribbon becomes stationary. A shift of ink ribbon feed from one direction to the other occurs through a limit switch arrangement whenever one spool is depleted.

Drive power for the code wheels, the type wheel, the coincidence selector, the tape sprocket feed and the ink ribbon feed is derived from an induction type 1/20th horse power, 115 volt, A.C., 60 to 50 cycle, 3450-2850 r.p.m. motor.

The afore-mentioned portion of this description provides a brief explanation of the mechanical operation of printer-reperforator 58 and a detailed description of the structure follows. FIGURE 20 illustrates the base plate 230 with most of the mechanical components removed. Toward the rear of base plate 230 a motor mounting bracket 234 is fastened by means of machine screws. The motor will be mounted with its shaft disposed horizontal and extending from front to rear. Located at the right-hand side of motor bracket 234 is a U-shaped bracket 236 used for mounting the coincidence selector 60 so its rotational axis will be disposed parallel to the motor shaft axis. Removable upper caps 238 on the vertical plates of the coincidence selector bracket 236 enable installation and removal of the coincidence selector 60 which has housing end bearings clamped securely in bracket 236.

Rigidly secured near the forward part of base plate 230 is a heavy, machined casting 240 having a thick base 242 and vertical front and rear walls 244 and 246, respectively. A portion of the casing base 242, which is located between the front and rear walls 244 and 246, is depressed to form an oil reservoir 248 for a purpose to be described. On each side edge of rear wall 246 is a half socket 250, similar half sockets 252 also being provided on the side edges of the front wall 244. Each of the two aligned sets of half sockets 250 and 252 receives the rear and front bearing retainers of a code selector wheel. Side retaining plates 245 which include matching half sockets are secured to the sides of the rear and front walls 244 and 246 by machine screws, as can be seen in FIGURE 1, to retain the code wheels in journaled position with their axes parallel to the motor shaft axis.

The rear wall 246 of the code wheel support also includes a pillow block portion 254 which mounts the tape feed sprocket assembly. This pillow block 254 has a removable cap 256 secured by machine screws. A somewhat similar arrangement provides a large top pillow block 258, with its cap 260 secured thereto by machine screws, to mount the type wheel assembly, as will be later described.

Still referring to FIGURE 20, two studs 264 and 266 project vertically in a front and rear aligned relationship adjacent the front and rear casting walls 244 and 246. These studs 264 and 266 are firmly secured in the base of casting 240 and provide mounting support for a shock absorber block 580 and the punch assembly 610, both of which will be later described.

The aforescribed oil reservoir 248 is located under the punch shock absorber block 580 and retains oil used in lubricating the code selector wheels. To accomplish this lubrication, two oil wicks 268 extend upwardly from the reservoir 248, diverge and pass under the positions which will be occupied by the code selector wheels. Oil wicks 268 are biased by leaf springs against a periphery of the code wheels in a manner to be later described and under each code wheel wick is located an oil drip plate 270. The lower ends of these two drip plates 270 are above the top of oil reservoir 248 and both ends include laterally spaced ears 271 through which is projected the shaft

of a crank 272 journaled in the front and rear support walls 244 and 246. Cranks 272 are rigidly secured at a mid-portion to the afore-mentioned leaf springs and, as shown in FIGURE 1, are biased by coil springs 274 in a direction which presses the oil wicks 268 against the peripheries of the code selector wheels. The afore-described wick arrangement can also be seen in FIGURE 57.

FIGURE 23 illustrates the power drive train and shows how rotational drive is imparted from the electric motor 280 to the right-hand code wheel 282, the left-hand code wheel 284, the type wheel 286, the coincidence selector 60 and the gearing for the two ribbon spools 288 and 290.

Each of the two code wheels 282 and 284 includes an axial shaft, the shaft 292 of code wheel 282 being longer than the shaft 294 of code wheel 284 (FIGURE 25). Code wheel shaft 292 is in direct alignment with shaft 296 of coincidence selector 60 (FIGURE 32) and is coupled thereto, as will be later described. A double sheave V-belt pulley 298 is non-rotatably secured on the rearwardly projected end of the right-hand code wheel shaft 292. A second double sheave V-belt pulley 300 is non-rotatably secured to the forwardly projected end of motor shaft 302. The two V-belt pulleys 300 and 298 are connected by a single V-belt 304. Front sheaves of the motor pulley 300 and the code wheel pulley 298 constitute a speed-step-up pulley drive from 3450 r.p.m. at the motor to 3750 r.p.m. at the code wheel; and the rear pulley sheaves can be used to constitute a speed-step-up pulley drive from 2850 r.p.m. at the motor shaft to 3750 r.p.m. at the code wheel shaft. Thus code wheel speed can be maintained at 3750 r.p.m. whether the motor is being operated on 60 or 50 cycle A.C. current merely by shifting V-belt 304 from one set of pulley sheaves to the other set. During free running of this equipment without signals being received, operation will be at 3750 r.p.m. However, as soon as signals are being received and printing, punching and other functions are occurring, the drag through the motor drive gearing will result in a code wheel rotation of approximately 3700 r.p.m.

Viewing the dual code wheel assembly from the front of the machine, as shown in FIGURE 24, the right-hand code wheel 282 will be rotating counterclockwise. The left-hand code wheel 284 rotates at the same speed but in a clockwise direction as indicated by the arrow in FIGURE 24. To accomplish this opposite rotation, a helical toothed gear 306 (FIGURE 23) is secured on the right-hand code wheel shaft 292 behind the support rear wall 246 and the left-hand code wheel shaft has secured thereto a second helical toothed gear 308 in meshed engagement with helical gear 306. Both code wheels must rotate in unison, at the same speed and in opposite directions.

In accord with the principle of operation of this machine, type wheel 286 must also rotate at the same rotational speed as code wheels 282 and 284. Type wheel 286 is secured for rotation to a shaft 310 (see FIGURES 64 and 65), which extends to the rear of casting rear wall 246 and has secured thereto a helical gear 312, having the same diameter and the same number of teeth as helical gears 306 and 308. Drive power is transferred from helical gear 306 through an idler gear 314 to the type wheel shaft gear 312.

Located on the front face of the motor pulley 300 is a round belt pulley sheave 314 which, through a round pulley belt 316 and pulley 318 which is secured to a feed sprocket drive shaft 320 through a friction clutch 322, provides a rotational drive biasing force to the tape feed sprocket 324. Actually, shaft 320 is a music wire torsion spring (FIGURE 63), as will be later described.

On the front face of code wheel shaft pulley 298 is a second round belt pulley sheave 330 which, through a round pulley belt 332 and pulley wheel 334, provides drive power for the ink ribbon feed mechanism. The drive ratio between pulley 330 and 334 is a 2 to 1 drive ratio. Pulley wheel 334 (FIGURE 76) is secured on a

worm gear shaft 336 having on its end a worm gear 338. Worm 338 meshes with a worm wheel 340 which drives a bead chain sprocket wheel 341 through a friction clutch 343. A bead drive chain 342 passes over wheel 341 and drives the driving member of a positive, tooth-jawed, bi-directional clutch 344 coaxially disposed on the ink ribbon shaft 346 which carries the two ink ribbon spools 288 and 290. Bead chain 342 is continuously driving the driving member of clutch 344 whenever motor 288 is operating. However, by mechanism to be described, ink ribbon feed action occurs only when clutch 344 is engaged, and such engagement is controlled by the receipt of the incoming signals in the electronic receiving mechanism.

As was previously described, the coincidence selector shaft 296 is positively connected to and is coaxial with the right-hand code wheel shaft 292 and, accordingly, the coincidence selector rotor (FIGURE 32) must rotate at the same r.p.m. as do code wheels 282 and 284. Hence, code wheel position reference signals, developed through the coincidence selector 60, will give positive indication of the rotational relationship of the two code wheels 282 and 284 and the type wheel 286, to any fixed reference point.

Still viewing FIGURE 23, on the rear of motor 280 are located an air pump 348 and a squirrel type blower 350. Pump 348 is a vane type rotary pump having its casing secured to the motor housing and its rotary element mounted directly to the motor shaft 302. Forced air is directed through the conduit 352 (FIGURES 29, 30 and 31) to the punch die block assembly and as the air passes over the die holes, it will pick up the punched chad and transport it through additional tubing into the chad drawer 62 (FIGURE 1). Blower fan 350, located 35 behind the air pump 348, is utilized to circulate cooling air under the unit cover 208.

Code wheels 282 and 284, their shafts, mounting components and gear assemblies are similar in detail, differing only in the shapes of the individual code rods and in that the right-hand code wheel shaft 292 is the longer shaft, as has been previously described. Accordingly, it is sufficient that only one code wheel be described in detail with reference to FIGURES 25 and 28. The schematic representation shown in FIGURE 24 shows the structural correlation between the two code wheels, the intermediate impact transfer arms and the punches, print hammer, tape feed mechanism and punch retractors.

Shown in FIGURE 25, the code wheel assembly includes shaft 292, the right-hand end of which has two ball bearing type, sealed bushings 358 and 359 retained against a shoulder 360 on shaft 292 by washer 362 and a split ring washer 364. A sleeve-like bearing retainer 366 is assembled from the rear of bearings 358 and 359 and provides a surrounding sleeve over both of the bearing assemblies.

The inner end of bearing retainer 366 has a smaller diameter bore 368 than the outer diameter of the bearings 358 and 359 and receives a cylindrical extension 370 of a front code wheel cam member 372. Cam member 372 has a flat formed on its end extension 370 which is disposed in bore 368, the cam member 372 being secured to the retainer sleeve 366 and non-rotatably maintained in position by a set screw 374 tightened against the flat. Retainer sleeve 366 fits into the half socket 252 located on the right-hand side of the front support wall 244 and is clamped in position, as shown in FIGURE 1. Code wheel 282 is secured to shaft 292 adjacent the cam plate 372, as will be described in more detail with reference to FIGURE 28 hereinbelow. To the rear of code wheel 282 is a second cam member 378 which has a cylindrical end extension 380 disposed in a bore 382 in a rear bearing retainer sleeve 384. The cam member 378 is non-rotatably secured in retainer bore 382 by a set screw 386. Rear retainer 384 also carries a sealed ball bearing bushing 388.

The rear bearing retainer 383 fits in the half socket 250 of the rear code wheel assembly support wall 246 and is clamped therein in a manner similar to that for the front bearing retainer 365. Independent rotational adjustment of either the front or the rear cam members 372 and 378 can be made after assembly by rotation of the retainer sleeves 366 and 384 within their respective sockets. Set screws (not shown) are provided in the front and rear walls for positively maintaining the rotational positioning of retainer sleeves 366 and 384, once the cam members 372 and 378 are adjusted. To the rear of bearing 388, a spacer sleeve 390 is disposed on the shaft 292 and the aforescribed helical gear 305 is placed on shaft 292 against spacer 390 and non-rotatably secured by set screw 392.

FIGURE 28 shows code wheel 282 as disposed on shaft 292 between and during operation will rotate free of the non-rotating front and rear cam members 372 and 378. The body of code wheel 282 is a cylindrical block 394 having two axially spaced diametrical bores 396 and 397 through which pins 398 can be driven into matching diametrical bores 399 and 400 in code wheel shaft 292 to non-rotatably secure the cylindrical code wheel block 394 to the drive shaft 292. Adjacent the peripheral portion of cylindrical block 394 are sixteen (16) axial through bores 402 spaced at 22.5° equi-angular positions. These axial bores 402 constitute code rod receptacles or carriers. Around the cylindrical surface of the code wheel block 394 are formed circular, radially directed, annular, combing grooves 404, 405, 406, 407, 408, 409, 410, 411 and 412. For purposes of correlation in the functioning of this apparatus, the first groove 404 (rear groove) will be termed the tape feed groove; the second groove 405 is the code punch retractor groove; grooves 406-411 are punch grooves, 408 being the feed punch groove; and groove 412 is the print hammer groove. Radially intersecting each of the axial code rod bores 402 are two radial bores 414 and 416. The larger bores 414 extend from the circumferential surface of the code wheel block 394 through to the axial shaft bore while the smaller radial bores 416 terminate just radially inward of the axial code rod bore 402 and serve as oil holes. Each of the larger radial bores 414 contains a code rod latch pin 418 which is biased outwardly by a coil spring 420 having one end abutting the code wheel shaft 292. Alternate code rod bores have the cross radial bores 414 and 416 located at opposite ends of the code wheel block 394, the reason being that alternate code rod bores 402 receive code rods inserted from opposite ends of the code wheel block to form two groups of eight (8) code rods, each of which rods will be located 45° apart.

Each end face of the code wheel block 394 has a coaxial axially directed circular groove which intersects each of the radial bores 414 located adjacent the respective end of the code wheel block. Front axial groove 422 provides a recess for an axially directed radial cam flange 426 carried by the front cam member 372. This axial cam flange 426 extends into recess notches 423 formed intermediate the ends of each of latch pins 418. The cam flange becomes thinner and the radial camming surface of axial cam flange 426 is formed to permit the latch pin 418 to move radially outward a distance sufficient to latch its associated code rod in impacted position whenever the code rod is shifted to an operative position. During a further phase of rotation of the code wheel block 394, during which the pins 418 pass around the cam flange 426, a thick camming surface of flange 426 coacts against the lower surface of the latch pin groove 428 withdrawing latch pin 418, against the bias of its spring 420, radially inward in the latch pin bore 414 to a position where latch pin 418 no longer interferes with its associated code rod. As the code wheel block 394 rotates through one complete cycle, each of the eight (8) code rod latch pins 418, which coact with the axial cam flange 426, is moved past the cam surface which, if

required, can withdraw the latch pins 418 from a latching position (see timing chart, FIGURE 22). A similar, axially directed radial cam flange 430 is located on the rear cam member 378 and extends into the radial end groove 424 on the rear face of the code wheel block 394. Cam flange 430 cooperates with the rear set of latch pins 418 in the same manner as that described between front cam flange 426 and the front set of latch pins 418. Note: the front axial cam flange 426 and front latch pins 418 coact with the eight (8) code rods which extend rearwardly from the code wheel block 394 whereas the rear axial cam flange 430 and rear latch pins 418 coact with the eight (8) code rods which project from the front face of the code wheel block 394.

FIGURE 29 is a scaled and dimensional drawing illustrating the exact dimensions of a code rod 440 from an operative example of this invention. There are thirty-two (32) of the code rods 440, each of which has a different permuted arrangement of annular flanges spaced axially along its length, made of surface hardened steel. Each of the code rods includes a beveled impact head 442, a narrow positioning limit flange 444 spaced slightly behind head 442, a front guide and interference land 446 and a rear guide land 448. Between the front and rear guide lands 446 and 448 are located a wide flange 450 adjacent land 446 and a second wide flange 452 adjacent the rear land 448. In equally spaced disposition between the front flange 450 and rear flange 452, there will be from one to six thin interference flanges 454, 455, 457, 458 and 459. The annular groove between the rear pilot land 448 and the rear wide flange 452 constitutes the code rod latch recess 460 into which an associated latch pin 418 will be biased by its spring 420 whenever a code rod is selected and shifted inwardly to an operative position in the code wheel block 394. Note: when a code rod is shifted to an operative position as illustrated by the lower code rod in FIGURE 28, the positioning flange 444 will abut the end face of code wheel block 394 and the latching recess 460 will be aligned with the latch pin bore 414.

Between the code rod impact head 442 and its positioning flange 444 is a grooved camming recess 462. A radially directed axial cam flange 464 formed on the front cam member 372 extends partially into the camming groove 462 of each of the eight (8) code rods 440 which have their heads 442 extending from the front face of the code wheel block 394. As is shown in the code bar timing chart of FIGURE 22, if a code rod 440 has been impacted into an operative position and latched by its associated latch pin 418, the latch pin 418 at a subsequent phase in the cycle of rotation of code wheel block 394 will be withdrawn from latching engagement by the axially directed radial cam flange 430 and immediately after this withdrawal of latch pin 418, an axially disposed cam rise on the radially directed cam flange 464 will engage the rear face of code rod head 442 to cam the code rod back to its inoperative normal position which will be determined by abutment of the positioning flange 444 against the rear face of the radially directed cam flange 464. The cam rise 466 on cam flange 464 can be clearly seen in FIGURE 38. Whenever a code rod 440 is in its normal inoperative position, its associated latch pin 418 cannot enter the recess 460 due to abutment of pin 418 against the surface of the rear code rod land 448. Such a relationship is illustrated by the upper code rod 440 in FIGURE 28.

Turning again to FIGURE 29, it will be seen that the code rod 440 therein illustrated includes all six (6) of the narrow interference flanges 454-459 disposed between the wide flanges 450 and 452. This constitutes a code representation for the "Letters shift" code signal combination from the Baudot Telegraph Code. If the "Letters" code rod 440 were visualized as taking the place of the lower code rod 440 shown in FIGURE 28, it will be seen that the rear portion of front pilot land 446 is in an in-

terference position in annular groove 404 of the code wheel block 394; the front wide flange 450 is in an interference position with the code wheel groove 405; interference flange 454 is in an interference position in groove 406; flange 455 interferes in groove 407; flange 456 interferes in groove 408; flange 457 interferes in groove 409; flange 458 interferes in groove 410; flange 459 interferes in groove 411; and the rear portion of wide flange 452 interferes in groove 412. The various interference portions of the front and rear code rods are reversed with respect to the code wheel grooves 404-412.

Seen in FIGURE 24 and as will be later described, a series of impact transfer lever arms ride in the manner of a comb in each of the grooves 404-412 of both of the rotating code wheel blocks 394 and the transfer levers correspond to the various functions noted for the series of grooves 404-412. If a code rod has been positioned to an operative position within the code block, any portion of that code rod which shifts into an interference position in an associated groove 404-412 will impact the lever which rides in that groove and cause the lever to transfer the impact power to some associated mechanism such as the code punches and the print hammer. If any specific lever must remain idle during the transfer of the code symbol represented by the selected code rod 440, then that portion of the code rod 440 which would normally move into interference with a combing groove, in which the lever not to be actuated is disposed, must be eliminated. This is accomplished by removing desired ones of the small interference flanges 450-459 or a rear portion of the front pilot land 446, for example, see the code rod in FIGURE 30 for the "Figures shift" code combination, wherein the interference portion of the front land 456 has been removed.

All of the thirty-two (32) individual and different code rods 440 are illustrated in FIGURES 30 and 31. In FIGURE 30, the code rods which have their head ends facing toward the left constitute the group of eight (8) code rods in the left-hand code wheel which project from the forward face of the code wheel and all of the code symbol combinations represented by these eight (8) code rods have the first two code impulses designated as "mark-mark." The eight (8) code rods in FIGURE 30 which have their head ends facing toward the right-hand side are disposed in the left-hand code wheel with their head ends projecting from its rear face and the code symbol combinations represented by these code rods have the first two characters starting with space-mark. In FIGURE 31, the code rods extending toward the left represent those eight (8) code rods which are located in the right-hand code wheel with their head ends extending from the forward face and represent the code symbol combination, the first two impulses of which are mark-space. The code rods in FIGURE 31 which face toward the right constitute those eight (8) code rods in the right-hand code wheel having their head ends extending from the rear face and represent code symbol combinations, the first two impulses of which are space-space.

Since the thirty-two (32) code rods 440 are divided into groups of eight (8) and each group is equally angularly spaced around a code wheel block, a device for determining eight (8) rotational phase positions can be used to determine a specific selection position (1) at the front of the left-hand code wheel, (2) at the rear of the left-hand code wheel, (3) at the front of the right-hand code wheel and (4) at the rear of the right-hand code wheel. Thus a single coincidence selector can provide simultaneous selection points for each of the four groups of code rods, and thus enable identification of all thirty-two (32) code rods as the code wheels rotate past the selection points. This rotational code wheel position identification is determined through the afore-mentioned coincidence selector 60 which is aligned with and mounted directly behind the right-hand code wheel 282.

In FIGURES 32-36, coincidence selector 60 is a rota-

tional phase position transmitter and includes a stator bell 470 and a rotor 472. The stator bell 470 has a coaxial circular boss 474 extending from its left-hand end. Boss 474 is rigidly secured in one of the arms of support bracket 236. The open end of stator bell 470 is closed by a cover plate 476 which has a second coaxial cylindrical boss 478 extending therefrom and clamped in the other arm of bracket 236. A coaxial bore extends through the circular boss 274 and receives an oil circulating bearing member 480. A blind bore in the end plate boss 478 also includes an oil circulating type bearing 482. Rotor 472 is non-rotatably secured to a shaft 484, one end of which is journalled in the stator end plate bearing 482 and the opposite end of which projects through front bearing 480 and terminates in shaft extension 296 which, as has been previously described, is directly aligned with and coupled to the right-hand code wheel drive shaft 292.

Axially formed in rotor block 472 are elongate slots 486 angularly spaced at 45° increments about the circumference of the rotor 472. Slots 486 extend the entire length of the rotor block 472 and provide receptacles for small permanent steel magnets 488a through 488(l). Magnets 488 are maintained in desired position by set screws 490. With reference to FIGURES 34, 35 and 36, it will be seen that magnets 488 are disposed in three axial groups on the rotor 472, magnets 488a, 488b, 488c and 488d being arranged in 90° spaced disposition within one group (FIGURE 36); magnets 488e, 488f, 488g and 488h being disposed in an intermediate angularly related group as indicated in FIGURE 35; and magnets 488i, 488j, 488k and 488(l) being disposed in a third angularly related group as indicated in FIGURE 34. The inner circumferential surface of stator 470, which surrounds the rotor 472, is provided with five (5) axially disposed grooves 492, 493, 494, 495 and 496, spaced at 45° increments within a 180° semi-circular portion of stator 470. These grooves 492-496 provide receptacles for mounting induction coil pick-up heads 500, 501, 502, 503, 504 and 505. Two pick-up heads are utilized for each group of four (4) permanent magnets arranged as indicated in FIGURES 34, 35 and 36. When pick-up heads 500-505 have been properly axially positioned, they are secured by a plastic material such as "epoxy resin" which is poured in the axial grooves 492-496 while in a liquid state to subsequently harden and maintain the heads in desired positions. The electric leads of all the pick-up heads 500-505 pass out through the rear of the coincidence selector 60 and are gathered in a junction box 503 mounted on top of the stator 470.

Because of the arrangement of the permanent magnets 488a through 488(l) grouped as described, there will be eight (8) different three-unit simultaneous code signal combination impulses corresponding to the eight 45° incremental positions of rotation of the two code wheels 282 and 284. Referring to FIGURE 5 and the chart of FIGURE 6, the eight (8) code signal combinations which develop in the induction pick-up heads as the rotor 472 rotates 360° are depicted. As has been described, the electronic controller 54 will determine when the one of the eight (8) code wheel angular positions, where the four (4) code rods having the last three code characters which correspond to the last three code characters of an incoming code signal received by the electronic converter 52 apparatus, is at a selection point. In FIGURE 2, the four (4) code rods representing "Letters," "X," "V" and "M" are simultaneously at the selection points of their respective groups of eight (8) code rods. In FIGURE 6, it will be seen that all of these four code representations have mark-mark-mark impulses as their last three impulses. Note also that the number 1 position is represented in FIGURE 5 where permanent magnets 488i, 488e and 488a induce current flow in the three (3) mark pick-up heads 504, 502 and 500. At the precise angular position when this signal coincides with the similar last

three-unit electrical code impulse signals in the controller 54, an input signal is applied to the "and" gates for all four (4) selector current amplifier circuits, as previously described. Note: the first two code impulse signals of the received code combination serve as another input to the "and" gate of the one and only one of the four (4) code rod selector magnets, and that will be the only selector magnet that is energized upon coincidence of the rotational phase of the code wheels with the corresponding last three (3) impulses of incoming received code signal combination. Therefore, even with four (4) different selection points, only one of the four magnets will be energized when the code wheel phase relationship matches the last three (3) impulses of a received code signal combination.

When the selected one-out-of-four code rod selector magnets MM, SM, MS SS is energized, a selector plunger is released just ahead of the rotational path of the impact head of the desired code rod. As illustrated in FIGURE 2, the front set of code rods in each code wheel is offset $22^{\circ} 30'$ from the rear group of code rods, and relative to the other groups in the other code wheel, the spacing between each of the four groups is $11^{\circ} 15'$. This offset actually does not constitute a problem insofar as the location of the code selector plungers is concerned, since that is only a mechanical problem of offsetting the magnets. Note: that all thirty-two (32) code rods in FIGURE 2 could be located in one wheel with each rod spaced $11^{\circ} 15'$ from its neighboring rods. Also all rods could be selected from the front or the rear of the code wheels if desired.

Referring now to FIGURES 37-43, the code rod selector plunger latch and magnet release mechanism will be described. Since all four (4) of the plungers, latches and magnets are essentially identical, only the assembly on the front side of the right-hand code wheel 282 will be described. The side plate 245 which is secured to the right-hand side of front wall 244 provides the mounting support for the "mark-space" code rod selector plunger 520. The three (3) other plungers are shown in the schematic representation of FIGURE 2, as "mark-mark" plunger 521, "space-mark" plunger 522 and "space-space" plunger 523.

Plunger 520 (FIGURE 42) is made of cold rolled steel, heat-treated and phosphate-coated before the hardened steel ball 526 is secured in end socket 528 by lightly spinning the edges of the socket. Ball 526 should spin freely within socket 528 and is the portion of plunger 520 which engages the impact head 442. The plunger 520 extends through an opening 530 inside the support plate 245 and is disposed parallel with the axis of rotation of code wheel 282 and in direct alignment with the circular path through which the code wheel rotates all of code rods 440. The opposite end 532 of plunger 520 is slightly convex to act as a recoil abutment surface, as will be described. Closely adjacent the convex recoil abutment end 532 is an annular groove 534 and an intermediate portion of rod 520 is formed with a deep annular latch receiving recess 536. Plunger rod 520 is guided for axial reciprocation in a plunger bearing 538, which is secured by means of an ear 540 and a screw 542 to the side plate 245. A notch 544, cut in the side of bearing 538, provides access for the latch end 546 of a plunger latch arm 548. When the end 546 of latch arm 548 extends through the notch 544 and is biased against the plunger 520, it will be disposed within the latch recess 536 and the plunger will be retained in the retracted position illustrated in FIGURE 39. A split ring fits within the annular groove 534 adjacent the convex abutment end 532 of plunger 520 and determines the operative limit position of plunger 520 when latch 548 is withdrawn from a latching position and a spring plate 550, which engages the abutment end 532 of plunger 520, biases the plunger into operative position, which, as previously described, will be just immediately in front

of and in the rotational path of the selected code rod impact head 442.

Latch arm 548 (see FIGURE 43) is pivotally secured to a support shaft 552 which extends through a structural member 554 secured to side plate 245. Shaft 552 is freely journaled within the structural member 554 but is prevented from any axial play by a locator stud 556 which in turn is locked in position by a set screw 558. The opposite end of shaft 552 has rigidly secured thereto a dog-legged member 560, the lower arm 562 constituting an anchor member for biasing spring 564 which is secured to a spring post 566 mounted on side plate 245. Biasing spring 564 creates a force tending to move latch 548 into engagement through the plunger bearing notch 544 with the latch recess 536 in plunger 520. The up-standing arm 568 of dog-leg 560 constitutes a stop abutting against a structural member and determines the limit of the release position of latch arm 548.

Rigidly secured on latch arm 548 is an armature disc

570 (see FIGURES 37 and 41) which is disposed imme-

diately in front of the pole face of an electro-magnet MS. Electro-magnet MS is clamped in position by mem-

ber 554 and end plate 572, both of which are secured

25 by machine screws to the side plate 245. As can clearly

be seen in FIGURE 37, when electro-magnet MS is en-

ergized, the armature disc 570 will be attracted to move

latch arm 548 in a clockwise direction removing latching

end 546 from the plunger recess 532 permitting the plunger

to move to an operative position under bias of spring 550,

30 as shown in FIGURE 40. Inasmuch as the electro-mag-

net is only momentarily energized, the armature disc 570

will be, in effect, immediately released and latch arm 548

immediately returns in a counterclockwise rotation under

force of the spring 564 so that, as soon as plunger 520

35 shifts to its inoperative position, as shown in FIGURE

39, the end 546 of latch arm 548 will immediately drop

into latching position and prevent return of plunger 520

to its operative position.

Insofar as is possible, the mass of plungers 520 is ap-

40 proximately equal to the mass of a code rod 440. When-

ever a plunger is released by a momentary signal to its

associated magnet, it will move into the path of the se-

lected code rod 440 just before that code rod arrives at its

reference selection point. The code rod impact head

442 will experience an elastic impact with the plunger

ball 526 and both will be driven away from each other

by reaction force. The plunger 520 rebounds until its

45 abutment end 532 pushes the spring plate 550 into engage-

ment with an energy-absorbing plate 574. The energy-

50 absorbing plate 574 is carried by a spring leaf 576 and

has a moment substantially equal to the mass of the plunger

520 so that it will absorb the rebound energy of plunger

520 causing the plunger 520 to stop, without a subsequent

55 rebound, to thereby permit the latch end 546 of latch

arm 548 to quickly drop into the plunger latch recess 536.

The energy-absorbing plate leaf spring 576 is secured to

56 a bracket 578 which is fastened by screws to the upper

magnet clamping block 572 and thereby also secures the

57 plunger spring plate 550 to the magnet clamping end

58 plate 572. Member 575 is a position limit stop for plate

59 574.

MECHANISMS OPERATED BY A SELECTED CODE ROD

65 The general organization of the two oppositely rotating code wheels 282 and 284 with the relative relationship of the other printing and perforating components is clearly shown in the somewhat schematic showing of FIGURE 24. Therein it is seen that the two code wheels are arranged with their axes parallel and in side-by-side relationship. Between the circumferential portions of the two code wheels 282 and 284 is disposed a block shaped shock absorber assembly 580. Disposed slightly above the shock absorber block 580 is a dual assembly of intermediate transfer arms, the duplicate components of which

provide identical combing and interference coaction with both of the code wheels 282 and 284.

Turning now to FIGURES 44 and 45, the means by which transfer of the code representations from any selected code rod 440 in either code wheel 282 or 284, to the various mechanisms such as punches, feed release mechanism, punch retractors and print hammer will be now described in detail.

With brief reference back to FIGURE 20, it will be recalled that two vertical parallel studs 264 and 266 are disposed between the front and rear walls 244 and 246 of the code wheel support casting 240. These two studs 264 and 266 are shown in FIGURE 44 and provide support for the block shaped shock absorber assembly 580 which includes front and rear vertical bores 581 and 582 (FIGURES 26 and 27) enabling the shock absorber assembly 580 to be slipped down over the two studs 264 and 266. Shock absorber block assembly 580 is maintained in elevation by set screws 583 which rigidly secure block 580 on the two mounting studs midway between the two code wheels 282 and 284. The shock absorbing functions and details of shock absorber 580 will be described hereinafter in relation to functional operation of the apparatus. Note: that the two studs 264 and 266 (FIGURE 45) project a considerable distance vertically above the shock absorber block 580. The purpose of such projection is to enable the stud to also provide a means for mounting the punch block assembly which will be later described.

FIGURES 24, 44 and 45 illustrate the relative arrangement of the dual groups of intermediate transfer levers. Each group of levers is pivotally disposed on a respective horizontal shaft 584 or 586. The left-hand shaft 584 carries intermediate transfer levers which cooperate with the left-hand code wheel 284, whereas the right-hand shaft 586 carries levers which cooperate with the right-hand code wheel 282. The two shafts 584 and 586 are spaced on either side of the shock absorber block 580 and extend over portions of their associated code wheels in fore and aft relationship with the shaft axes parallel to the code wheel axes. The two shafts 584 and 586 have their rear ends spigoted in appropriate bores 587 in the rear casting wall 246 while the front ends of the shaft project into suitable bores in the front casting wall 244 and are maintained in rigidly secured disposition by set screws 588.

Reading backwards, i.e., from rear to front, the intermediate transfer levers are designated by reference characters 590 (tape feed release), 591 (punch retractor), 592 and 593 (numbers 1 and 2 code punches), 594 (feed hole punch), 595, 596 and 597 (numbers 3, 4 and 5 code punches), and 598 (print hammer). These intermediate transfer levers have duplicate counterparts on both of shafts 584 and 586 and the same reference numeral will serve to identify each corresponding intermediate transfer lever as this description proceeds. All of the intermediate transfer levers 590-598 include downwardly depending arms, some of which vary in shape, as will be later described, which ride in the corresponding combing grooves of the associated code wheels 284 and 282, such grooves being identified for the appropriate functions in the preceding description pertaining to FIGURE 28. The transfer levers 590 and 592-598 each have laterally extending arms projected over the shock absorber block 580, the arms of opposite identical intermediate transfer levers being slightly spaced apart above the shock absorber block 580, as seen in FIGURE 44. The shock absorber assembly 580 includes a plurality of shock absorber units to be later described, one of which is disposed under and engaged by the adjacent ends of the aforesaid intermediate transfer arms 590 and 592-598. The left-hand transfer arm shaft also serves to pivotally mount a tape feed release pawl 600 which cooperates with both of the tape

feed release intermediate transfer levers 590, as will be more fully described hereinafter.

PUNCH BLOCK ASSEMBLY

In FIGURE 24, it will be seen that the punches 616-621 and a plunger 660 for operating the print hammer (648, 654) are disposed immediately above the ends of the horizontal arms of the intermediate transfer levers 592-598 in a punch block assembly 610 which includes the punch retractor and print hammer, as will be described.

Punch block assembly 610 consists of a machined base member 612 with two vertical bores 614 provided adjacent the front and rear edges, the rear bore being shown in FIGURE 49. Punch block assembly 610 is mounted with upper portions of front and rear studs 264 and 266 extending through punch block bores 614 (see FIGURES 20 and 49), and is secured in position by set screws. Carried in the punch block base member 612 for vertical reciprocatory movement are six (6) tape punches 616, 617, 618, 619, 620 and 621. Punch 618 is the feed hole punch whereas punches 616, 617 and 619-621 are the five (5) code hole punches. Punches 616, 618 and 620 are provided with heavy shank portions extending to an intermediate point on the punches and guided through bores in an intermediate wall 622 of the punch block base 612. These three (3) punches 616, 618 and 620 have light compression coil springs 624 disposed above the intermediate wall 622 and the punch stripper plate 626 in which the cutting ends of all punches are disposed. Coil springs 624 abut the underside of stripper plate 626 and have their other ends disposed on small washers resting on the shoulders at the upper ends of the heavy shank portions just above the intermediate wall 622. The other three (3) punches 617, 619 and 621 have shorter shank portions which are piloted in the lower guide wall 628 of punch block base 612 and coil springs 625 are disposed on these punches between the intermediate wall 622 and small washers abutting the shoulders at the upper ends of the short shank portions. These coil springs 624 and 625 are not retraction springs but merely create a bias force to maintain the punches in a retracted position whenever they are not being selected and reciprocated. The different alternating shapes of the punches enable compact arrangement of all six (6) punches with appropriate sized biasing coil springs of sufficient strength to withstand the high speeds of operation of the apparatus. The lower ends of all punches are provided with laterally flanged heads 629 (FIGURES 52 and 54).

Secured to the punch block base 612 above stripper plate 626 is a hollow die block 630, the lower wall of which includes the die holes 632 aligned immediately above the punch guide holes in stripper plate 626. A chamber 634 within the die block 630 is formed by a lateral blind bore having an opening at the front side of the die block assembly. A nipple (FIGURE 52) is inserted in the front end of chamber bore 634 and slipped over the nipple 636 is one end of a resilient tube 638, e.g., made of plastic, which passes through a split clamp 640 secured on the block base 612. As shown in FIGURE 1, the plastic tube 638 curves downwardly and is secured to an inlet fitting 641, in the top wall 204 of the machine base portion 61, opening into the chad drawer 62. A lateral intersecting bore 642 in the rear side portion of the die block 630 intersects the die block chamber bore 634. Secured over the opening of the lateral cross bore 642 is the end of the aforescribed conduit 352 which leads from the vane-type air pump 348. During machine operation the motor drives the air pump 348 which forces a flow of air through conduit 352, into bore 642, through chamber 630 above the die holes 632, picking up any chad which has been punched from a tape and blowing the chad out through plastic tube 638 and down into the chad drawer 62.

Pivots secured on the inner side of the front vertical wall 646 of the punch block base 612 below stripper plate 626 is a print hammer arm 648 which is made of nylon. The left-hand end of print hammer arm 648 is pivotally mounted on the enlarged shank of a bolt 650 which projects through wall 646 and is secured thereto by a nut 652. Print hammer arm 648 extends horizontally under the die stripper plate 626 and, at its free end, carries a hammer head 654 which can be seen in FIGURES 49, 51 and 65. Details and operational characteristics of the print hammer will be described hereinafter. A coil spring 656 (FIGURE 51) is anchored on post 658 at one end and secured at its other end to the print hammer arm 648 to bias the print hammer arm to its retracted position.

Longitudinally aligned with and in front of the tape punches 616-621 is a vertically disposed print hammer operating plunger 660. The lower end head 662 of hammer plunger 660 is disposed at the same level as the heads 629 of punches 616-621, whereas the upper end of hammer plunger 660 is disposed in vertical alignment with and under the print hammer arm 648.

Also aligned with the tape punches 616-621 and disposed rearwardly thereof is a spring loaded plunger type shock absorber 664 which, as will be later described, is engaged by and provides a shock absorbing function for the tape feed release pawl 600.

Extending between and rotatably journaled in the punch block base front and rear walls 646 and 670 are two punch retractor operating shafts 672, one disposed to the left and one disposed to the right of the punches and hammer plunger. Secured to the lower side of each of shafts 672 by rivets 673 are punch retracting bails 674 which extend horizontally to a position adjacent the shanks of punches 616-621 and print hammer plunger 660 and overlying the flanged heads 629 and 662 of all punches and the print hammer plunger. The front edge of each bail 674 is formed with a forwardly extending ear 676 constituting an anchor for a coil spring 678, the other end of the spring being anchored to an associated spring post 680 secured in the front side of front wall 646. The two coil springs 678 bias the bails 674 against the lower punch block wall 628 whenever punch retraction is not occurring. A cylindrical steel sleeve 682 is non-rotatably secured, by set screw 683, to the rearwardly projected end of each of shafts 672. A short portion of each sleeve 682 is provided with an actuating notch 684 shown in FIGURES 50, 54 and 59. When the punch block assembly 610 is secured in position on the two mounting studs 264 and 266, the notches 684 in sleeve 682 of the retracting shafts 672 will cooperate with portions of the associated intermediate transfer levers 591, as will be more fully described hereinafter with respect to the schematic FIGURE 59.

TRANSFER LEVERS

With reference to FIGURE 53, one form of an intermediate transfer lever 592 is illustrated. All of the punch operating intermediate transfer levers 592-597 and the hammer plunger intermediate transfer lever 598 are shaped identically to the lever shown in FIGURE 53. These levers 592-598 include a short depending arm 688 and a horizontally projected arm 690 which extends under the head 629 of an associated punch 616. Identical opposed pairs of these intermediate transfer levers have arms 690 extending under the same associated head of the associated punch 616. As has been previously noted, the ends of these horizontal arms 690 of intermediate transfer levers 592-598 are also disposed in rest position on top of upper plungers 692 of individual shock absorbers in the shock absorber block 539. The depending arms 688 of the punch and print hammer transfer levers 592-598 ride in the combing grooves 406 through 412 (FIGURE 28) of the associated code wheels 282 and 284.

Note: that the rearmost intermediate transfer lever 590

(FIGURES 55 and 60) includes a horizontally extending arm 694 essentially the same shape as horizontal arm 690 on transfer lever 592. The ends of the two opposed horizontal arms 694 of the pair of transfer levers 590 rest over the head of an associated shock absorber plunger 692 and (see FIGURES 44 and 45) disposed immediately above the two opposed arms 694 is a horizontally bent, forwardly projected end 696 of the horizontal actuating arm 698 on the tape feed release pawl 600. As shown in FIGURE 45, feed release pawl 600 has an inclined upper arm 700 terminating in a pawl end 702. The tape release pawl 600 itself does not have a depending arm. However, the tape release intermediate transfer levers 590 do have depending arms 704, shown in FIGURE 55, which are slightly longer than the depending arms 688 of transfer levers 592-598.

FIGURE 54 illustrates the punch retractor transfer levers 591. The horizontally extending arms 708 of retractor transfer levers 591 are relatively short and do not extend over a shock absorber, instead they merely rest on the top of the shock absorber block 539. These retractor transfer levers 591 have elongated depending arms 710 with a small cam rise 712 situated toward the lower end of arm 710. The upper end portion of retractor transfer levers 591 have notches 714 formed in their peripheral edge and a notch 714 of each lever cooperates with the notch 684 provided in the associated retractor bail shaft sleeve 682 (FIGURES 50 and 51). Accordingly, with reference to FIGURE 54, whenever the left-hand lever 591 is pivoted a slight amount counterclockwise, the notch 714 cooperates with notch 684 to rotate the retractor shaft 672 in a clockwise direction. Looking at FIGURE 51, this movement will rotate the left-hand retractor bail 674 downwardly, engaging the upper surface of the punch heads 629 and the print hammer plunger head 662 thereby shifting them to a retracted position. The bias of springs 678 (FIGURE 51) tends to force the depending arms 710 of the retractor intermediate transfer levers 591 into the associated grooves 405 of the two code wheels. The right-hand retractor lever 591 and bail 674 operate similarly but in opposite directions from the left-hand lever and bail.

Whenever a selected code rod 440 is driven into the wheel 282 or 284 by one of the code rod selector plungers 529-533 and secured therein by the associated latch pin 418 located inside the code wheel, appropriate interference flanges on the code rod 440, as indicated in FIGURES 29, 30 and 31, move into the interference position in combing grooves 404-412 in which the intermediate transfer levers are riding. Any selected code rod 440 excepting the "Space" and "Figures" code rod has an interference flange which shifts into the comb groove within which the print hammer intermediate transfer lever 598 is riding. Hence, for every code rod selection excepting the "Space" and "Figures" selection, an interference flange on the code rod rotates into engagement with the depending arm 688 of the hammer transfer lever 598. Similarly, if the code combination represented by the selected code rod 440 includes mark impulse representations which are represented by flanges moved into the combing grooves 406, 407, 409, 410 and 411, these interference flanges will engage the depending arms 688 of the code punch intermediate transfer levers 592, 593, 595, 596 and 597. Every one of the thirty-two (32) code rods includes an interference flange which, when the code rod is selected, shifts into combing groove 408 enabling the interference flange to engage the feed hole punch intermediate transfer lever 594.

Turning now to FIGURES 56 and 57, the arrow with the legend "selection point" indicates the angular position on the left-hand code wheel at which the selector plunger 521 controlled by the MM magnet engages and drives the selected code rod into the code wheel. As the code wheel 284 continues to rotate clockwise, the selected code rod print hammer and punch interference flanges will engage the depending arms 688 of the selected code

punch transfer levers, the feed punch transfer lever, and the print hammer transfer lever, imparting in essence a camming action against the engaged intermediate transfer levers causing them to rotate counterclockwise. Note: if the code rod which is selected were on the right-hand wheel 282, the code rods would be rotating in a counterclockwise path and would engage the associated transfer levers to shift them in a clockwise pivotal movement.

Still viewing FIGURE 56, the camming force of the interference flanges of the selected code rod against the intermediate transfer levers is transferred through the horizontal arms 690 of the transfer levers to the underside of the heads 629 and 662 of the selected punches 616-621 and the print hammer plunger 660, driving such selected punches and the print hammer plunger in an upward direction. The selected punches 616-621 drive through and punch the tape tape 206 while the print hammer plunger 660 (FIGURES 65 and 66) impacts the underside of the nylon print hammer arm 648 causing an elastic impact reaction forcing the print hammer arm 648 up into abutment against the underside of the die stripper plate 626. The head 654 of the print hammer could be secured solidly to the tip of the hammer arm 648, in which case, the abutment between the hammer arm 648 and the die stripper plate is not needed and the hammer will rebound after striking the type wheel. However, to prolong ink ribbon life, the hammer head 654 is made as a loose fitting aluminum plunger inserted in a bore in the end of the hammer arm 648. When the hammer arm 648 engages a solid stop, the underside of die stripper plate 626, the light weight aluminum plunger 654 over-travels approximately .015 inch pressing the paper tape 206 and an ink ribbon, which will be later described, against the face of the rotating type wheel 286. It has been found that a minimum mass for plunger head 654 to obtain a good legible impression is 0.12 grams. This mass is kept to a minimum to keep the impression time as low as possible to minimize lateral rubbing and wear between the type wheel and the ink ribbon. As has been previously described, the type wheel is in accurate, direct, rotational register with the code wheels through appropriate gearing, and therefore the correct character will be in position above the front edge of tape 206 and above the hammer head when the print hammer arm 648 is actuated.

As seen in FIGURE 58, the tape is physically punched approximately six (6) character spaces ahead of but simultaneously with the printed character. Punching of the tape occurs during a stationary portion of tape feed which is accomplished by mechanism to be hereinafter described. However, since the code wheels 282 and 284 and the type wheel 286 revolve continuously at a rate of between 3700 and 3750 r.p.m. the selected character is printed while the type wheel is moving.

Returning again to FIGURE 56, it will be seen that as the code rod 440 rotates ten (10) degrees beyond punch and print actuation position, a retractor interference flange in groove 405 strikes the slight cam rise 712 on the retractor bail intermediate transfer arm 591 (all code rods have an interference flange for the retractor bail intermediate transfer arm). Camming action by such interference flanges on the retractor intermediate transfer arm 591 causes rotation of the retractor bail 674 creating a bias tending to pull the six (6) punches 616-621 and the print hammer plunger 660 to retract position. As shown in the timing chart of FIGURE 22, this retraction force is occurring just before the punch actuation flanges pass their interference levers and retraction thus immediately follows the punch actuation. The long lower end 713 of the retractor transfer lever arms 591 serves to momentarily hold the bail and the punches and hammer plunger in retracted position. Even so, the punches and the print hammer plunger, as a result of this rapid retraction action, strike their associated intermediate transfer arms. To completely prevent any rebound move-

ment and assure positioning of the members for a subsequent operation, the energies from these moving masses are absorbed in the shock absorber assembly 580.

Turning to FIGURES 46-48, the shock absorber assembly 580 contains individual shock absorber units 715 for each of the intermediate transfer arms excepting the retractor transfer arms 591. Each shock absorber unit 715 is identical and, accordingly, details of only one (FIGURE 48) will be described.

Block 580 includes a series of vertical bores 716, constituting enclosure cylinders for each shock absorber unit 715. Located at the bottom end of each bore 716 is a small metal plunger 718 which rests on top of a spring finger 720. There is one of these spring fingers 720 under each of the shock absorber unit bores 716 and all spring fingers 720 are integral with a spring plate 721 (FIGURE 57) which is secured by rivets 722 to an auxiliary plate 724 secured on one side of the shock absorber block 580 by screws 726 and 727. The upper edge of plate 724 has a horizontal flange 728 which extends a slight amount over the aligned bores 716 to be disposed freely in a wide notch 730 provided under the heads of each shock absorber unit top plunger 692, thus permitting a slight amount of vertical play for each top plunger 692 yet also retaining the plungers in the shock absorber assembly 580.

In the embodiment shown in FIGURE 48, between the upper and lower plungers 692 and 718, a group of steel balls 732 and 733 are loosely packed into the bores 716. The diameter of the larger balls 732 is slightly greater than one half the diameter of bore 716, thus causing the group of balls 732 to engage each other and the side wall of bore 716 in point-to-point contact. Yet the balls 732 cannot wedge between each other and the wall surface 716. The smaller balls 733 are of such a diameter as to contact the surfaces of upper and lower larger balls 732. Whenever the punches and the print hammer plunger are retracted and strike the intermediate transfer arms, which in turn strike the heads of upper plungers 692, the resulting kinetic energy will be completely dissipated through the numerous point-to-point engagements between balls and side walls of bore 716 causing the punches and the print hammer plunger to be immediately settled down with no rebound and ready for another operation. The spring fingers 720 serve to impart a small flexing action to the pile of balls assuring that they remain loose after an energy absorbing function.

FIGURES 48A and 48B illustrate a different manner of stacking the steel balls in the bore 716a of the shock absorber block 580a. In this embodiment, which is preferred, the ball stack consists of a layer of three (3) large balls 732a alternated with a layer consisting of one small ball 733a. The three (3) large balls are of identical size, fitting slightly loose in a horizontal plane within bore 716a and the smaller ball 733a nests in the center of and between the layers of three (3) balls. Variations in diameter of the balls in both embodiments will vary the amount of impact which can be absorbed.

Inasmuch as sequential code rod selection, under certain character selection sequences, can occur up to 160 times per second, it will be realized that no rebound of any punch or print hammer plunger can be tolerated. Hence, the need for these highly effective shock absorber units.

Turning again to FIGURE 56, as the code rod 440 travels another 5°, an interference flange strikes the depending arm 704 of the sprocket feed release intermediate transfer arm 590 (all code rods have an interference flange for the sprocket feed release intermediate transfer arm). The camming impact force transferred to feed release intermediate transfer arm 590 is immediately transferred to the sprocket feed pawl 600 (FIGURE 60) which releases the pawl end 702 from a sprocket ratchet 794 to permit tape feed movement, as will be later described.

Note: the reciprocatory cycle of movement of the pawl end 702 of feed pawl 600 will occur in a space approximately one milli-second. This value is of importance in conjunction with feed sprocket movement which is torsionally biased to move the feed sprocket and tape feed wheel one step in from two to three milli-seconds. Therefore, when the feed release pawl 600 is removed from engagement with a tooth of a ratchet wheel connected to the feed sprocket, it must be back in position to engage the next tooth of the tape feed ratchet wheel before the tape has completed movement to its next stop position. The pawl 600 is pulled back into place by a restoring spring. Actuating energy imparted to pawl 600 and its intermediate transfer lever 590 by the code rod impacts is dissipated by the shock absorbing plunger 664 (FIGURES 50 and 52) and coil spring associated therewith. Rebound movement of pawl 600 and the intermediate transfer arm 590 is absorbed by one of the energy absorbing plungers 692 and they are thereby settled down ready for the next operation.

TAPE FEED

The mechanism for accomplishing feed of the message tape is illustrated in FIGURES 60-63. Even though operation of this printer reperforator occurs at ultrahigh speeds, it must provide step-by-step feeding of the perforated tape because the tape should be stationary when the punching operation occurs.

To accomplish this feed operation, the paper tape is transported by a rotating toothed feed wheel 324 step-driven by momentary release of torsional bias energy from a length of music wire 320 shown in FIGURE 63. The feed sprocket assembly 736 is a unitary subcombination, as shown in FIGURE 63, assembled on a mounting sleeve 738. Sleeve 738 includes a large diameter portion 739 and an extended length 740 of smaller diameter. The larger diameter portion 739 includes a coaxial bore 742 intersecting a smaller bore 744 which extends completely through the reduced diameter portion 740 of mounting sleeve 738. The through bore 744 is disposed slightly eccentric to the axis of sleeve extension 740 for a purpose which will presently be described.

Momentarily turning to FIGURES 1 and 20, it will be seen that the tape feed sprocket assembly 736 is mounted on the rear wall 246 of the code wheel support, in pillow block 254. The reduced diameter extended end 740 of sleeve 738 is disposed in the pillow block 254 and secured therein by the cap 256. A collar 746, FIGURES 61 and 63, is secured on the reduced diameter portion of sleeve 738 by a set screw and clamps snugly against pillow block 254 thereby maintaining the feed assembly mounting sleeve 738 in a fixed axial position. A sleeve 748, made of hardened steel drill rod has one end disposed within the large bore 742 of mounting sleeve 738 and secured therein by set screw 750. The extended end of the hard steel sleeve 748 serves as a journal stud supporting a cylindrical bearing sleeve 752. The driven sprocket feed pulley 318 is journaled for rotation on the bearing 752. A flanged hollow shaft 754, also made of hardened drill rod, has a reduced diameter portion projecting coaxially through the fixed steel sleeve 748 and includes a radial intermediate flange 756 which abuts the projected end of journal stud 748 and axially abuts the bearing sleeve 752. The smaller diameter end of hollow shaft 754 which projects through the journal stud 748 has a clip and washer 758 fixed thereto engaging the inner end of the hollow journal stud 748 to axially maintain the hollow shaft 754 in rotatably journaled relationship within the hollow journal stud 748.

To the rear of the flange 756, hollow drive shaft 754 is provided with exterior axial splines 760 and its end has exterior threads 762. In radially spaced concentric relationship from drive shaft 754, the driven pulley 318 includes an axially directed annular flange 764 which

includes several axial slots 766. The axial flange 764 of pulley 318 constitutes a driving member of a friction disc clutch 322 while the hollow shaft 754 is the driven member of the friction clutch. Friction clutch 322 constitutes driving discs 768, made of phosphor bronze, and driven discs 770 engaging the splines 760 separated from the driving discs 768 by a series of felt discs. Driving pressure on the friction clutch 322 is controlled by a compression spring 772 having an adjustable bias controlled by the position of a threaded nut 774 on the end 762 of driven shaft 754. Nut 775 can be turned either way to adjust the compression force of spring 772 on the friction clutch discs and once the desired slipping torque is obtained, nut 774 is secured by means of a set screw 776.

Spigoted into the open end of driving shaft 754 is a split collet 778, made of hardened drill rod, gripping a rectangular cross section length of music wire 320. Collet 778 is clamped tight on the end of music wire shaft 320 by means of the set screw 776. Music wire shaft 320 extends from collet 778 through the center of drive shaft 754, through the bore 744 in mounting sleeve 738, and has a free rotational fit within a sleeve-like hardened steel journal stud 780 secured in the eccentric bore 744 by a set screw 782. The projected end of journal stud 780 is formed with a small radial flange 784. The music wire shaft 320 extends beyond the end of journal stud 780 and is bent at right angles to extend radially beyond the periphery of end flange 784 as a short drive lug 786.

The tape feed wheel 324 is a small unitary assembly of several parts which is rotatably mounted on the journal post 780 between flanged end 784 of the journal post and the end surface of the mounting sleeve extension 740. Tape feed wheel 324 has a phosphor bronze sleeve-like hub which has an axial flange 788 projecting forwardly over and beyond the end flange 784 of journal stud 780. Hub sleeve flange 788 has diametral slots 790, one of which is engaged by the bent end lug 786 of the music wire shaft 320. The phosphor bronze bearing sleeve 788 carries a feed wheel sleeve 790 having steel pins 792 circumferentially disposed in proper spaced relationship to the desired tape feed spacing. A cold rolled steel, hardened sprocket toothed wheel 794 is non-rotatably secured to the feed wheel sleeve 790 and maintained on the phosphor bronze bearing sleeve 788 by spinning over the hub end 796. The bearing sleeve 788, feed wheel 790, toothed sprocket 794 and feed pins 792 rotate as a unit on the journal stud 780 and constitute the tape feed sprocket wheel 324.

Rotation of the feed pulley 318 drives, through the friction clutch 322, the drive shaft 754 which in turn drives the music wire shaft 320 by means of the collet 778. The bent end 786 of music wire shaft 320, in engagement with the slot 790 in the end of feed sprocket bearing 788, imparts a rotational bias to the feed wheel assembly 324 which is held against rotation by the feed release pawl 702. The friction clutch is adjusted to slip when the music wire shaft 320 is twisted approximately one-half of a turn. Friction clutch pulley 318 is continuously belt-driven at approximately 1100 r.p.m. from the electric motor. The spacing between feed pins 792 is a requisite $\frac{1}{10}$ inch. To adjust the spacing of sprocket wheel 324 relative to the code punches, a slight rotation of the mounting sleeve 738 within its pillow block 254 will move the feed sprocket relative to the code punch block because of the eccentricity of bore 738.

Since the high speed of operation requires that the feed mechanism operate satisfactorily at a rate of at least 160 operations per second, it was necessary that the total mass of the feed sprocket be accelerated and moved from standstill during each feed step within three (3) milliseconds. Accordingly, the torsion wound straight wire shaft 320 and the lightweight tape sprocket feed wheel 324 was devised. Thus, the only mass experienc-

ing acceleration upon release of ratchet wheel 794 was the very lightweight sprocket and ratchet assembly 324. By this arrangement, a lapsed time for a full step feed displacement of the paper tape was reduced to 0.002 to 0.003 second.

As has been previously described (see FIGURE 60), the tape feed sprocket assembly 324 is maintained against being rotated by the torsionally wound spring shaft 320 by a feed release pawl 690 which is spring biased into engagement with a tooth of the sprocket wheel 794. Feed pawl 690 is removed from engagement with sprocket wheel 794 immediately after punch retraction (FIGURE 22) every time any one of the code rods 440 is shifted into selected position. The time required for movement of feed release pawl 690 out of engagement with sprocket wheel 794 and back into position to engage the next tooth is 0.001 second. Therefore, the sprocket wheel 794 can only move one tooth space for each operation of the feed release pawl 690.

Looking now at FIGURES 61 and 62, the tape feed sprocket 324 is disposed under the tape 206 which passes from right to left over the sprocket wheel 324 and down onto the top of a tape feed die plate 796. A tape guide chute 798 is secured to guide plate 796 and includes a cut-out portion 799 enabling visual reading of the printed message along the front edge of tape 206. The guide plate 796 is secured to a base block 800 which in turn is rigidly secured to a clamp member 801 fastened to the code wheel support casting 240. Secured to the top of guide plate 796 is a tape pressure foot 802 which is spring biased to maintain the tape in contact with the feed hole engaging teeth 792 of feed wheel 324, in a conventional manner. The pressure foot 802 can be released by the thumb release arm 804.

TYPE WHEEL ASSEMBLY

The complete type wheel assembly including its shifting mechanism is illustrated in FIGURES 64 and 65 with details illustrated in FIGURES 66-72. The base structure for the type wheel assembly 803 consists of a machined casting 810 having a cylindrical sleeve portion 812 (FIGURE 69) which is disposed in the pillow block 258 and maintained on the code wheel rear support wall 246 by the pillow block cap 260 (FIGURE 64).

The aforescribed type wheel drive shaft 310 is rotatably mounted within the cylindrical sleeve 812 in sealed bearing units 814 and 816. The axial position of shaft 310 relative to the cylindrical sleeve 812 is determined by a shaft flange 818, washers 820 and nut 822. The rear end of shaft 310 projects from the rear of cylindrical housing 812 and in assembly will have the aforescribed type wheel helical gear 312 non-rotatably secured thereto and disposed behind the rear wall 246 of the code wheel support structure. The forward portion 824 of shaft 310 is of square cross section, projects over the tape feed chutes and terminates in a short cylindrical stud 826.

When the type wheel assembly base structure 810 is secured in pillow block 258, the cylindrical sleeve 812 projects rearwardly a sufficient distance to serve as a mounting boss for an idler gear arm 828 which is clamped on the cylindrical sleeve 812 by means of a split end of arm 828 and a clamping screw 830. The end of the idler gear arm 828 has rigidly secured therein a journal shaft 832 which rotatably carries the helical idler gear 313. Gear 313 includes within its hub an internal bearing assembly (not shown). In FIGURE 68, two spacer blocks 834 are disclosed as being secured to the top edge of idler gear arm 828. These spacer blocks 834 support a curved splash guard 836 extending in protective relationship around the type wheel idler gear and the type wheel drive gear 312. Note that the type wheel helical drive gear 312 has not been included in FIGURES 64, 65 or 69 but is illustrated by phantom lines in FIGURE 68.

The type wheel 286 is a rim made of hardened steel with two rows of type: standard teletypewriter upper case letters in one row and figures and symbols in the second row. In this machine all characters are printed on the paper tape 206 in a single straight line. In order to accomplish this straight line printing, the type wheel 286 is shifted from the "Letters" row to the "Figures" row and vice versa under control of the electronic controller mechanism. To accomplish this function, the type wheel assembly is cammed back and forth between two limit positions on the square shaft portion 824 and maintained in these limit positions by a detent arrangement.

Shown in FIGURE 70, type wheel 286 is attached to a nylon sleeve 840 by a metal plate 842 and machine screws 843. Plate 842 has a cylindrical concentric hole 844 which fits over the cylindrical end stud 826 on the square shaft portion 824. The coaxial hole 846 through the nylon sleeve 840 is formed with a square cross section to slidably fit over the square shaft portion 824 in a driving arrangement. Attached to the rear end of nylon sleeve 840 is a metal abutment plate 848.

When the type wheel 286 is in its rearward position as determined by abutment of the nylon sleeve end plate 848 against the shaft flange 818, the front or "Letters" row of characters on type wheel 286 will rotate above the print hammer (FIGURE 64). In this rearward position a spring loaded detent ball 850, located in a radial bore 852 within nylon sleeve 840, has passed just over center of the edge of a notch 854 in the square shaft portion 824. The spring bias force against the detent ball 850 maintains the nylon sleeve in its rearward position. The spring and ball 850 are retained in the bore 852 by a wire clip 856 disposed in a groove 858 around the nylon sleeve 840. The ends of the spring clip 856 are bent in and can be sprung into radial bores 860 in sleeve 840 to retain the spring clip in position during rotation of the type wheel. In the forward shift position of the type wheel and sleeve assembly, the rear line of characters on type wheel 286 will be in position above the print hammer. In this position the nylon sleeve 840 is shifted forward until the type wheel front retaining plate 842 abuts a stop washer 862 secured axially on the end of the cylindrical stud 826 by a spring clip 864. In this position, the detent ball 850 has just passed over center beyond the edge of a second notch 866 in the square shaft portion 824 whereby the spring bias force tends to maintain the type wheel assembly in its forward position.

As was previously noted, the forward and rear shift of the type wheel assembly is achieved by a camming mechanism, and to this end, the nylon sleeve 840 has two cam grooves machined into its exterior surface. The "Letters" shift cam groove 870 is located rearwardly (left-hand groove, FIGURE 70) on the nylon sleeve 840 while the "Figures" shift cam groove 872 is the forward groove (right-hand groove, FIGURE 70). The two grooves are designed so that the non-camming portion is spread out over a large circumferential portion of the wheel periphery so the rebound force of shifting can be effectively dissipated. Furthermore, a computed non-camming entry slope (FIGURE 71) enables the sleeve shifting plunger 876 or 877 to de-accelerate without rebound from its kinematic energy of movement into the camming groove so it smoothly descends down into the groove itself. As shown by the left-hand "Figures" plunger 876 in FIGURE 71, the plunger will not bottom in the camming portions of grooves 870 or 872. By providing a relatively circular non-camming dwell portion after the shift of the type wheel assembly, a positive detent locking of the type wheel in the new position is assured. As the end rise portion of each cam groove rotates into engagement with the plunger its speed will tend to flip the plunger back into a latched position (see right-hand "Letters" plunger 877 in FIGURE 71).

In FIGURES 64 and 65, the type wheel frame 810 in-

cludes two forwardly projected side beams 874 and 875, each beam carrying a respective shift plunger 876 and 877. Both of the plungers 876 and 877 are located on a horizontal diametral plane intersecting the axis of rotation of the type wheel assembly 286, plunger 876 being located toward the front of the type wheel assembly whereas plunger 877 is located toward the rear. Toward the rear of the side arms 874 and 875 is a vertical member 878 and secured on top of member 878, extending horizontally forward above the type wheel nylon cam sleeve 840, is 10 a horizontal support plate 880 carrying two electro-magnets E-4 and E-5. At the front end of the upper plate 880 is a small depending plate 884. A left-hand latch plate 885 is pivoted to the rear support member 878 on a pivot pin 886. The right-hand latch plate 883 is pivoted to the front vertical member 884 on a latch pin 889. Each 15 of latch plates 885 and 883 has a depending arm 890 extending down into close proximity with associated shift plungers 876 and 877 and both of the latch plates 885 and 883 are spring biased so the ends of arms 890 will engage an annular groove in the association plunger pin 876 and 877 to maintain the plunger pins back out of engagement with the nylon type wheel cam sleeve 840. Coil tension springs 892, attached at one end to a latch plate, are secured at their other ends on appropriate 20 anchor plates fastened to the side beams 874 and 875.

Each type wheel shifting plunger assembly includes a leaf spring 894 fastened at its upper end to the horizontal plate 880 by screws. Leaf spring 890 engages the heads of plungers 876 and 877 creating a spring bias force urging them inward toward the associated cam grooves 870 and 872 in the nylon cam sleeve 840, although movement is prevented by engagement of the two latch arms with the annular grooves in the shift plungers. As was before described, after a shift plunger drops into its cam groove, the tail end of the groove is inclined to kick the plunger radially outward. This movement drives the plunger 876 against its leaf spring 894 causing the spring to abut an energy absorbing plate 896, which has a moment substantially equal to the plunger, mounted by a thin leaf spring to the same upper plate 880 as are leaf springs 894.

The upper end of each of latch plates 885 and 883 carries an armature disc 898 disposed a short distance below the pole faces of associated magnets E-4 and E-5. Upon energization of "figures" shift magnet E-4, the latch plates 885 will be pivoted a slight amount counterclockwise, as viewed in FIGURE 64, pulling the end of latch arm 890 out of the groove in the associated plunger 876. At this point, the leaf spring 894 immediately shifts the plunger 876 into engagement with the nylon sleeve ahead of and aligned with the entry portion of camming groove 872, causing a shift of the type wheel and sleeve assembly forward into a "Figures" position. As before described, when the latch plunger 876 is kicked back it is 50 related by the latch plate 885. In a similar manner, "Letters" electro-magnet E-5 when energized will attract the armature disc 898 on latch plate 883 releasing its associated plunger 877 permitting it to be spring biased into the entry portion of cam groove 870 in cam sleeve 840 causing a shift of the type wheel and sleeve assembly back to a "Letters" printing position. The electro-magnets E-4 and E-5 are energized by amplified signals from the electronic controller whenever a "Figures" or a "Letters" signal code combination is received. The timing 55 between the selection pulse and actual shift is shown in FIGURE 73.

It will be seen that the "Figures" shift cam groove 870 is placed exactly side by side with the "Letters" shift cam groove 872. However, the two shifting plungers 876 and 877 are disposed 180° apart and therefore the rotational position during a "Figures" shift function will be 180° away from the rotational position during a "Letters" shift function. Inasmuch as the shift signals to magnets E-4 and E-5 are derived from the electronic control simul-

taneously with the selection of the "Figures" or "Letters" code rods the 180° rotational difference between type wheel shift positions must be followed through in the positioning of the "Letters" and "Figures" code rods in the code wheel (see FIGURE 26) and the "Letters" and "Figures" positions on the type wheel.

RIBBON FEED AND REVERSE MECHANISM

The ink ribbon 904 passes beneath the type wheel 286 parallel to the axis of type wheel rotation (see FIGURES 23 and 78), and moves at a continuous rate whenever electrical code combination signals are being received by the electronic convertor 52. As has been described, whenever electric code combination signals have not been received in the convertor 52 for a period of one second, ink ribbon 904 becomes stationary. Electronic circuitry for controlling this method of ribbon drive is described in the initial sections of this specification devoted to electronic functioning. This section describes the mechanical structure and operational features of the ink ribbon feed. As previously described, ribbon spools 288 and 290 are rotated on spool shaft 906 through a sprocket and bead chain 242 deriving power from the machine motor 280. A worm 238 and worm wheel 240 speed reducer 25 drives the bead chain 242 through a felt friction clutch 908, which slips only if the ink ribbon 904 becomes tangled or blocked.

Shown in FIGURES 74, 75 and 76, the ribbon feed and reversing mechanism is a unitary subassembly 902 which 30 includes a base plate 912 by which the subassembly is removably mounted on the main base plate 230 just to the right of the code wheel support casting 240 (see FIGURE 1). Secured on the top of the subassembly base plate 912 are two upstanding support arms 914 and 915, 35 the upper ends of which are shaped as pillow blocks 916 with securing caps 918. The long screws 920 which secure the caps 918 to arms 914 and 915 pass through spacer sleeves 922 and also secure an elongate message tape, inlet guide plate 924 above and between the vertical arms 914 and 915 in alignment with the upper surface of the punch assembly stripper plate 626, seen in FIGURE 1. The message tape will enter the machine and pass up over the downwardly curved end 925 of guide plate 924 from whence it passes straight over the extended left-hand portion 926 and into the punch assembly 610.

Depending from either side of the tape guide plate extended portion 926 are two mounting ears 927 and 928, 50 respectively carrying two micro-switches S-1 and S-2 used in connection with the electronic controller to actuate a bi-stable circuit which determines direction of ribbon feed travel as has been described. The mechanical details of the means to operate these switches S-1 and S-2 will be described hereinafter.

Ribbon spool shaft 906 (FIGURE 77) is mounted in the two pillow blocks 916 on top of support arms 914 and 915, by means of bearing sleeves 930 which enclose the two driven members 931 and 932 of a reversible inclined tooth, side face, jaw clutch 344. Thrust bearings 935 are disposed between each of the bearing sleeves 930 and the radial flange of each driven member 931 and 932 of the jaw clutch. The clutch members 931 and 932 are independently rotatably mounted on shaft 906. An enlarged diameter, intermediate portion of shaft 906 slidably and rotatably supports the clutch driving member 937 and provides shoulders which maintain the driven clutch members 931 and 932 in axially spaced-apart relationship. Driving clutch member 937 has two side faces 938 and 939 each with inclined driving teeth adapted, upon 60 sliding movement of driving member 937, to engage the inclined teeth on one or the other of driven clutch members 931 and 932. The clutch driving member 937 also can assume a neutral position between the two driven members whereat it will not be engaged with either driven member. Drive force between clutch jaws is transmitted

through the inclined faces of the teeth and if the driving member is not positively held in a drive engaging position, the inclined teeth will cam the driving member to its neutral position.

Driving member 937 is formed as a spool with one spool flange 940 having a bead chain sprocket wheel 941 non-rotatably secured to its periphery. A clutch shift trunnion member 942 is rotatably mounted between thrust bearings on the driving member 937 adjacent the sprocket wheel 941, and includes diametrically disposed trunnion pins 944.

The two ends of ink ribbon spool shaft 906 project beyond the sides of support arms 914 and 916 and rotatably carry ribbon spool hubs 945 and 946 which are drive-connected to respective clutch driven members 931 and 932. Hubs 945 and 946 are axially maintained in drive engagement with clutch driven members 931 and 932 by spring clips 947 on the ends of shaft 906. Each hub 945 and 946 has integrally fastened thereto a conventional spool drive yoke 948 which can be seen in FIGURES 74 and 75, wherein the ribbon spools are omitted for clarity.

The lower rear portions of vertical support arms 914 and 915 carry a horizontal rod 950 (FIGURE 74), the projected ends of which pivotally carry the lower ends 951 of two ribbon spool retainer and pressure fingers 952. These fingers are spring biased in a conventional manner to press between the side flanges of a ribbon spool and on the ink ribbon wound on the spool to create tension on the ink ribbon and to prevent axial displacement of the spool from its position on the associated hub.

Mounted on the inner side of support arm 915 is a bead chain idler wheel support block 954 carrying an inclined idler wheel axle 955. The upper and lower ends of axle 955, rotatably mount two bead chain idler sprocket wheels 956 and 957 which enable a change in the path of the bead chain 342 from horizontal to vertical. The hubs of each wheel 956 and 957 contain bearings (not shown).

Idler wheel mounting block 954 is centrally slotted as at 958 and the portion of axle 955 which passes across slot 958 pivotally carries a clutch shift lever 960 by means of a short sleeve 961 secured to an intermediate part of the lever 960. The upper end 962 of lever 960 is yoke shaped with slots in the yoke arms that engage the trunnion pins 944 on the clutch shift trunnion member 942. The lower end 964 of lever 960 is also yoke shaped and carries a disc shaped electro-magnet armature 965 disposed in spaced relationship between the facing pole faces of two electro-magnets E-1 and E-2 secured in respective support legs 914 and 915 by clamp plates 966.

As viewed in FIGURE 75, energization of electro-magnet E-1 will shift armature disc 965 and the lower end 964 of lever 960 to the right, causing the upper end 962 of lever 960 to shift and hold the clutch driving member against the teeth of driven member 930 to drive the rear ribbon spool 290 in a ribbon winding direction. Energizing electro-magnet E-2 will shift the armature disc 965 and the lower end of lever 960 to the left (FIGURE 75) to clutch the driven member 931 and drive the front ribbon spool 288 in a ribbon winding direction.

The afore-described ribbon reversing limit switches S-1 and S-2 are under the stretches of ink ribbon 904 which will extend from spools 288, 290 parallel to the tape guide 924. Each stretch of ribbon passes over a spool shaped guide roller 968, one roller being journaled on each end of a rod 970 which is axially fixed through the depending tape guide ears 927 and 928. Tape sensing rollers 971 and 972, rotatably mounted on dog-leg levers 973 pivotally supported on ears 927 and 928, press the stretches of ink ribbon 904 against the guide rollers 968. Dog-leg levers 973 have lower arms 974 which engage the push rod 975 of the associated micro-switch S-1 or S-2. Each micro-switch S-1 and S-2 is adjustably mounted by screws on its associated mounting ear 927 or 928.

so it can be shifted to a position where its actuating rod is slightly pressed toward its actuated position to thereby place a slight spring bias on sensing roller arm 974.

The ribbon 904 is threaded from a full spool on the ribbon guide 990 (FIGURE 78) and thus passes over the guide rollers 968 and under the end of the ribbon sensing arm rollers 971 and 972 and onto the empty spool. Ribbon 904 has two eyelets (not shown) secured near each end of the ribbon. When the ribbon comes to an empty spool condition, the eyelets in the ribbon will pass under the sensing arm roller 971 or 972, raising the lever 973 and actuating the associated micro-switch S-1 or S-2. Operation of one or the other micro-switch will, through an electronic circuit which has been described, shift a bi-stable voltage control circuit from one electro-magnet E-1 to the other E-2 thereby causing ribbon control to energize the electro-magnet which shifts the clutch 344 into drive engagement with the empty spool. Unless the bi-stable control circuit is again shifted by the other micro-switch the ribbon clutch is always actuated by the same electro-magnet.

With reference to FIGURE 23, it will be recalled that drive power for ribbon feed is from the motor 289 through pulley belt 332 and ribbon feed pulley 334 to a worm 338 and worm wheel 340, the worm wheel 340 driving the bead chain 342 through a friction clutch 343 and a bead chain sprocket wheel 976. Turning to FIGURES 75 and 76, the worm drive is mounted on a block base 977 secured on the ribbon assembly base plate 912, the worm shaft 336 being journaled in two legs 978 and the worm wheel mounting shaft 979 being secured in and projecting from the upper side of block base 977.

Bead chain 342 is maintained in taut condition by two idler rollers 980 and 981 engaging the rear stretch of bead chain as viewed in FIGURE 75. The pin 982 which journals roller 980 is secured in an angle bracket 983 fastened by screws to the top of base block legs 978. Pin 982 also pivotally supports a lever 984 having a stud 985 in its lower end to rotatably carry the second idler roller 981. Roller 980 is on a fixed axis and is disposed above bead chain 342 while roller 981 is on a shiftable lever, is offset from roller 980 and is disposed under bead chain 342. The upper end of lever 984 is spring loaded to raise roller 981 against the bead chain 342 to maintain the chain taut.

As has been described, ribbon spool drive force is through the inclined faces of the clutch teeth. When the incoming line signals stop for one second, the energizing current to the desired clutch magnet decays and the controlling electro-magnet E-1 or E-2 is de-energized, releasing the armature 965 and permitting the clutch driving member 937 to selfcenter into an unengaged position.

The ribbon guide 990 (FIGURE 78) receives the loop of ink ribbon 904 extending between the two ribbon spools and guides the ribbon to a position directly under the type wheel and parallel to the type wheel axis of rotation. Guide 990 consists of a block 991 which is laterally shiftable mounted on two rods 992 secured on the punch block assembly 610. Block 991 and a sheet metal ribbon guide plate 995 secured thereto by screws 993 can be slidably adjusted toward and away from the type wheel position by loosening a thumbscrew 994 which clamps against one of the rods 992. The ribbon loop passes in parallel stretches over the top of the guide plate 995 and around ribbon guide loops 996, each of which enables a 90° change in the ribbon path. The short stretch of ribbon between guide loops 996 passes under the type wheel 286 and above the message tape 206. When the print hammer strikes the tape 206 from below, it presses the tape 206 against the ink ribbon 904 and the ink ribbon 904 against the rotating type wheel 286.

If the type wheel is placed below the tape and the

hammer and ribbon above the tape, the ink ribbon would not receive wear from being pressed against the moving type wheel. However, such a construction is not considered desirable primarily because it places too many components above the tape and tends to obscure the printed message.

There is a signal bell 1000 (FIGURE 74) mounted on the rear side of the ribbon feed subassembly 902. This bell 1000 has a clapper 1001 powered by an electromagnet E-3. Whenever the code signal combination for "Figures" is received, followed by the signal for the character "S," the bell magnet E-3 will be momentarily energized to raise and then release the clapper 1001 to cause the bell 1000 to ring.

LUBRICATION

Lubrication of this high speed equipment is very important. Because of the ultra high speed of operation, oil dissipation from some components is very rapid, requiring a systematic lubricating procedure. The code wheels 282 and 284 and the code rods 440, the intermediate transfer arms 590-598 and the punches 616-621 are self-lubricating. This is accomplished by the oil wicks 268 (see FIGURE 57) which wipe against the two code wheels 282 and 284. The code wheels pick up oil from the wicks 268 and centrifugally throw it to all of the aforementioned components. Oil will drip down or be thrown off of the code wheels and be caught by the oil shields 270 which are shaped to drain such excess oil back into the reservoir 248 where it is soaked up by the felt oil wicks 268. This oil reservoir 248 (FIGURES 20 and 24) has an external oil cap 960 through which the oil supply may be conveniently replenished.

All other moving parts, such as latches, code selector plungers, tape feed sprocket wheel ratchet and the type wheel shift mechanism, should be oiled periodically. All bearing units, being sealed, are lubricated for the extent of their life. The code rod restoring cam members 372 and 378 should receive a few drops of oil each day the equipment is operated.

All gears (see FIGURE 23), namely, the four machine gears 292, 306, 312 and 313 and the ribbon drive worm 338 and worm wheel 340 should be greased periodically. All pivot points and rotating shafts and rollers of the ribbon feed mechanism should also be oiled periodically. The coincidence selector 60 has oilite bearings with a re-circulating oil system. There are oiling holes on the motor end bells and on the air pump. The two felt friction clutches 322 and 343, one on the sprocket feed and one on the ribbon drive, should not be allowed to dry out. Nevertheless, they retain oil for relatively long periods of operation.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A tape printer-reperforator receiving apparatus comprising: an electronic data indicative electrical code signal group receiving and apparatus controlling device including electronic circuit means for receiving code signal groups and electronic circuit means for controlling the mechanical operations of the apparatus; a mechanical printer-reperforator device with selectively operable means, including continuously rotating recording means, capable of 4500 cyclic printing, punching and tape step feeding operations per minute; and coordinating means between said electronic and mechanical devices enabling

controlled selection of the character of operations performed by said selectively operable means.

5 2. A tape printer-reperforator receiving apparatus comprising: an electronic data indicative electrical code signal group receiving and apparatus controlling device including electronic circuit means for receiving code signal groups and electronic circuit means for controlling the mechanical operations of the apparatus; a mechanical printer-reperforator device with selectively operable means, including continuously rotating recording means, capable of 4500 cyclic printing, punching and tape step feeding operations per minute and means for actuating and cyclically operating at least a part of said operable means by an elastic impact reaction force; and coordinating means between said electronic and mechanical devices enabling controlled selection of the character of operations performed by said selectively operable means.

10 3. A message medium recorder and receiving apparatus comprising: an electronic data indicative electrical code signal group receiving and apparatus controlling device including electronic circuit means for receiving code signal groups and electronic circuit means for controlling the mechanical operations of the apparatus; a mechanical recorder device with selectively operable means, including continuously rotating recording means, capable of 4500 cyclic recordings and message medium step feeding operations per minute and means for actuating and cyclically operating at least part of said operable means by an elastic impact reaction force; and coordinating means between said electronic and mechanical devices enabling controlled selection of the character of operations performed by said selectively operable means.

15 4. A device operative when actuated to produce a visual permanent recordation of a message received in the form of unit data indicative electric signal groups comprising: power operated recording means with continuously repetitive cycles of operation; means for converting any received signal group to a plurality of simultaneous output signals corresponding to the signals of each received signal group; first means for selecting and registering a first portion of said output signals in accord with the individual permuted characteristic of said first portion; second means of selecting and registering a second portion of said output signals; coincidence means correlating phases of cyclic operation of said recording means with said second selection and registering means; and means responsive to output signals from said first and second selecting and registering means for controlling and actuating a specific recordation selecting device in said power operated recording means corresponding to a received signal group.

20 5. Telegraph apparatus for receiving electric code combination data indicative signal impulse groups and creating visual recorded manifestations of such code combination signal groups at rates up to at least 4500 operations per minute, comprising: electronic means for receiving incoming data indicative electrical signal impulse groups and converting each such impulse group to an individual output control signal; a mechanical recorder including power means and independent character representative recording actuation elements corresponding to each data indicative representation of the received signal groups, and continually rotated by said power means; means to select one of such elements, while rotating, in accord with the output control signal from said electronic means; and operative means adapted to be actuated by such selected element for creating the visual recorded manifestation representative of the incoming signal combination capable of at least a maximum of 4500 operations per minute.

25 6. Telegraph apparatus for receiving electric code combination signal impulse groups and creating visual recorded manifestations of such code combination signal groups at rates up to at least 4500 operations per minute comprising: electronic means for receiving incoming elec-

trical signal impulse groups and converting such impulse groups to individual control signals; a mechanical recorder including power means, rotatable means rotated by said power means, and independent character representative recording actuation elements corresponding to each code combination representation of the received code signals carried and rotated by said rotatable means; means, including a rotational phase transmitter directly related to the positions of said elements in said rotatable means for transmitting rotational phase coincidence signals to said electronic means, to cause a control signal from said electronic means to select one of said actuation elements in accord with the signal impulse group received in said electronic means; and operative means in said mechanical recorder adapted to be actuated by such selected actuation element for creating the recorded visual manifestation representative of the incoming combination signal impulse group capable of at least a maximum of 4500 operations per minute.

7. Telegraph apparatus for receiving electric code combination signal impulse groups and creating punched and printed manifestations of such code combination signal groups on a message tape, comprising: electronic means for both receiving incoming electrical signal impulse groups and converting such impulse groups to individual output control signals; a mechanical printer-reperforator including power means, and rotatable independent character representative recording actuation elements, corresponding to each code combination representation of the received code signals, connected to be continually rotated by said power means; means to select one of such rotating elements, while rotating, in accord with a single output control signal from said electronic means; and operative means adapted to be actuated and operated by such selected element for punching and printing manifestations representative of the incoming signal combination group.

8. Telegraph apparatus for receiving electric code combination signal impulse groups and creating visual punched manifestations of such code combination signal groups at rates up to at least 4500 operations per minute on a message tape, comprising: electronic means for both receiving incoming electrical signal impulse groups and converting such impulses to individual control signals; a mechanical tape reperforator including power means, a tape feed wheel, friction clutch means drive connecting said tape feed wheel and said power means, independent character representative recording actuation elements corresponding to each code combination representation of the received code signal groups and including means to actuate and operate mechanisms to accomplish reperforator function; rotating drive means connected between said power means and said elements to continuously rotate said elements; means to select one of such code elements, while rotating, in accord with a control signal from said electronic means; and operative mechanism adapted to be actuated by such selected code element for creating the recorded visual manifestation representative of the incoming signal combination capable of averaging at least 4500 operations per minute and for permitting said tape feed wheel to rotate to step feed the tape one step for each operation.

9. A high speed reperforator telegraph receiver comprising: an electronic unit for receiving combinational electrical impulse groups of code signals and converting such signals to simultaneous plural output channels equal in number and corresponding to the received code combination impulses; an electronic controller device connected to said channels and including search register means for dividing the impulses from each code combination group received on said channels into two distinct groups; a recorded message tape; a high speed mechanical reperforator for punching messages in said message tape including individual code represented elements corresponding to each code combination of the code being utilized by the receiver, said code elements being divided into a

plurality of groups, and power means for moving all of said code elements; means for correlating said groups of code elements with matching permuted representations of one of said groups of impulses in said search register means; means for selecting one of said code elements from within any desired group of code elements in accord with a signal derived from the other of said groups of impulses in said search register means; a message tape feed assembly; said recorder also including mechanical means operated as a result of elastic impact forces derived from a selected code element for punching a corresponding code representation in said message tape, and permitting said message tape feed assembly to feed one step, and retracting all operating mechanisms; said power means which provides kinetic energy to all of said code elements, also providing a bias force tending to operate said tape feed assembly.

10. A high speed recording telegraph receiver comprising: an electronic unit capable of receiving combinational electrical impulse groups of electrical code signals and converting such signals to simultaneous plural output channels equal in number and corresponding to the received code combination impulses; an electronic controller device connected to said channels and including search register means for dividing the impulse in each code combination group received on said channels into two distinct groups; a recorded message medium; a high speed mechanical recorder for recording messages on said message medium including individual code represented elements corresponding to each code combination of the code being utilized by the receiver, said code elements being divided into a plurality of groups, and power means for moving all of said code elements; means for correlating said groups of code elements with matching permuted representations of one of said groups of impulses in said search register means; means for selecting one of said code elements from within any desired group of code elements in accord with a signal derived from the other of said groups of impulses in said search register means; said recorder also including mechanical means operated as a result of elastic impact forces derived from a selected code element for punching a corresponding code representation on said message medium.

11. A high speed printer-reperforator telegraph receiver comprising: an electronic unit capable of receiving combinational electrical impulse groups of electrical code signals and converting such signals to simultaneous plural output channels equal in number and corresponding to the received code combination impulses; an electronic controller device connected to said channels and including search register means for dividing the impulses in each code combination group received on said channels into two distinct groups; a recorded message tape; a high speed mechanical printer-reperforator for printing and punching a message on said tape including individual code represented elements corresponding to each code combination of the code being utilized by the receiver, said code elements being divided into a plurality of groups, and power means for moving all of said code elements; means for correlating said groups of code elements with matching permuted representations of one of said groups of impulses in said search register means; means for selecting one of said code elements from within any desired group of code elements in accord with a signal derived from the other of said groups of impulses in said search register means; a message tape feed assembly; said recorder also including mechanical means operated as a result of elastic impact forces derived from a selected code element for punching a corresponding code representation in a message tape, printing the corresponding character designation on said message tape, permitting said message tape feed assembly to feed one step and retracting the printing, punching and tape feed release operating mechanisms; said power means which provides kinetic energy to all of said code elements, also provid-

61

ing a bias force tending to operate said tape feed assembly.

12. A receiver as defined in claim 11, wherein the means for printing includes a rotatable type wheel, an ink ribbon passing adjacent said type wheel, and an ink ribbon feed device; controllable and reversible means to drive said ink ribbon feed device adapted to be drive connected to said power means; and control means for drive connecting said ink drive means including means in said electronic controller for providing a decaying ink ribbon control operating electric signal initiated by a received code signal group.

13. A high speed rotating type wheel printing telegraph receiver comprising an electronic unit capable of receiving combinational electrical impulse groups of electrical code signals and converting such signals to simultaneous plural output channels equal in number and corresponding to the code combination impulses; an electronic controller device connected to said channels and including search register means for dividing the impulses in each code combination received on said channels into two distinct groups; a high speed mechanical rotary type wheel printer including individual code represented elements corresponding to each code combination of the code being utilized by the receiver, said code elements being divided into a plurality of groups, and power means for rotating all of said code elements in direct 1:1 ratio with the type wheel; means for correlating said groups of code elements with matching representations of one of said groups of impulses in said search register means; means for selecting one of said code elements from within any desired group of code elements in accord with a signal derived from the other of said groups of impulses in said search register means; a recorded message medium; a message medium feed assembly; mechanical means operated as a result of elastic impact forces derived from a selected code element for pressing the record medium against the type wheel and printing the corresponding character designation on said message medium, permitting said message medium feed assembly to feed one step and retracting all operating mechanisms, said power means which provides kinetic energy to all of said code elements, also providing a bias force tending to operate said message medium feed assembly.

14. In a high speed receiving and recording apparatus, an electronic control device for receiving electrical code signal combination impulse groups and splitting each combination group of impulses into two groups, one of which groups has four different impulse combination conditions and the second of such groups having eight different impulse combination conditions; a mechanical message recorder comprising a power unit, a rotatable means, driven by said power means, including a plurality of coded elements representative of all received code signal impulse combinations, said code elements being divided into four simultaneously rotating groups, each group containing eight of said code elements spaced equiangularly apart; a selector means for each of said four groups of code elements capable of placing one of the eight code elements from its associated group into a selected position at a specific reference point in a 360° rotation cycle; means connecting said four selector means to said electronic controller enabling said first group of impulse signals in said controller to determine which of said four selector means can be rendered operative; a coincidence device correlating the rotational angle phase of all of said four groups of code elements with said controller; said controller including means for determining which of the eight angular positions of said groups of code elements corresponds to the distinct one out of eight code signal combination condition of said second group of impulse signals in said controller and enabling operation of said previously determined selector means at the appropriate time when the code element corresponding to the received combination group of code impulses

62

passes the selection point of the determined one selector means; and means operated by the selected code element for creating a visual recorded representation on a message medium.

15. In a receiver and recorder as defined in claim 14, a coincidence selector for generating and transmitting signals correlating rotational selection points from the rotatable means of said mechanical recorder with electrical coded signal impulses received in the electronic control device comprising: a rotor member driven by said power means in a direct 1:1 drive ratio with said code elements, said rotor carrying three axially spaced planar groups of four permanent magnets angularly spaced from each other in multiples of 45°; a stator carrying three planar groups of two induction pick-up heads disposed adjacent the paths of rotation of said three planar magnet groups and angularly spaced from each other in different multiples of 45° whereby the cycle of rotation of the planar groups of magnets is divided into eight equiangular signal positions with a different three-unit code signal generated for each of the respective eight positions.

16. In combination in a high speed printer-reperforator receiving apparatus: an electronic control device for receiving electrical code signal combination impulse groups and splitting each combination group of impulses into two groups, one of which groups has four different impulse combination conditions and the second of such groups having eight different impulse combination conditions; a mechanical printer-reperforator comprising: a power unit, a rotatable means driven by said power means including a plurality of coded elements representative of all possible received code signal impulse combinations, said code elements being divided into four simultaneously rotating groups, each group containing eight of said code elements spaced equi-angularly apart, a selector means for each of said four groups of code elements capable of placing one of the eight code elements from its associated group into a selected position at a specific reference point in a 360° rotation cycle; means connecting said four selector means to said electronic control device enabling said first group of impulse signals in said control device to determine which of said four selector means can be rendered operative; a coincidence device correlating the rotational angle phase of all of said four groups of code elements with said control device; said control device including means for determining which of the eight angular positions of said groups of code elements corresponds to the distinct one out of eight code signal combination condition of said second group of impulse signals in said control device and enabling operation of said previously determined selector means at the appropriate time when the code element corresponding to the received combination group of code impulses passes the selection point of the determined one selector means; and means operated by the selected code element for creating a printed and punched code representation on a message tape.

17. A receiving and recording telegraph apparatus comprising: an electronic controller section; a mechanical recording section including a continuously rotating code element carrying body containing thirty-two different selectable and shiftable code elements; combined means, including electronic means in said controller section and electrical-mechanical means on said recorder section, providing a coincidence tie-in between said electronic section and the rotational position of said body in said mechanical section; said electronic controller having means by which a five-unit Baudot Code can be split into two groups of impulses, one group having four possible different two-unit impulses and the second group having eight possible different three-unit impulses; said combined means correlating a one-out-of-four registration of the first two units of the five-unit Baudot Code with a one-out-of-eight matching phase selection of the last three units of the five-unit Baudot Code in accord with a rota-

tional position of said rotating code element carrying body in said mechanical section to select and cause shifting of one of said thirty-two code elements corresponding to a specific Baudot Code combination group received by said controller section; and means in said recording section to record a representation of such specific code combination group, actuated by said selected code element.

18. A receiving and recording telegraph apparatus comprising: an electronic controller section; a mechanical recording section including a continuously rotating code element carrying body containing a plurality of different selectable and shiftable code elements corresponding in number to the number of different permutation arrangements of the electrical impulses in a multiple impulse signal code; combined means, including electronic means in said controller section and electrical-mechanical means in said recorder section, providing a coincidence tie-in between signal representative impulses in said electronic section and element rotational positions in said mechanical section; said electronic controller including means for splitting each code group of multiple impulses into two groups of impulses constituting one group of a predetermined number of plural unit impulses less in number than said multiple unit group impulses and a second group of a predetermined number of plural impulse groups from the multiple impulse groups not used in said first group; said combined means correlating a registration of one of the possible permutation combinations of said first group with a one of the possible permutation combinations of said second group which is matched with a rotational position of said rotating code element carrying body in said mechanical section to select and cause shifting of one of said plurality of code elements corresponding to a specific combination group of the code received by said controller section; and means in said recording section to record a representation of such specific code combination group actuated by said selected code element.

19. A receiver printer-reperforator telegraph apparatus comprising: electronic receiving and control components; electrical-mechanical printing and punching components; a continually operating electric motor powering said electrical-mechanical components; said electrical-mechanical components comprising rotatable means powered by said electric motor including a plurality of selectively shiftable code rods each of which includes a mechanical code combination representation and all of which are in continuous rotation, and selectively operable recording mechanisms actuated and operated by a selected code rod; means coordinating the positions of said code rods in said rotatable code rod carrying member with the electronic receiving and control components comprising an electronic coincidence circuit and four electro-mechanical code rod selectors disposed adjacent the path of rotation of said code rods adapted when energized to select and shift a code rod to its operative position; said electronic coincidence coordinator and said electronic receiving and control components coordinating a one out of four possible registrations corresponding with the possible permutation arrangements of the first two code units of a received Baudot Code group with a one-out-of-eight selection determined by coincidence comparison between the last three units of the received Baudot Code group and one-out-of-eight equi-angular rotational positions of said rotating member to generate a control impulse signal to one selector at a specific time phase in the rotational cycle of the code rods to cause selection of a designated code rod corresponding to the specific received Baudot Code signal.

20. A telegraph receiving printer-reperforator comprising: power means; rotatable cylindrical code wheel means drive connected to said power means and containing a plurality of axially spaced apart circular annular combing grooves; thirty-two code rods carried in said code wheel

means and intersecting said combing grooves, each of said rods including an impact head projecting from the code wheel means and a plurality of axially spaced interference flanges forming a specific code signal combination representation and machine function operators, said rods being axially shiftable so said interference flanges move to and provide interference portions in associated combing grooves; means to select and engage the impact head of a desired code rod corresponding to a received code signal combination to cause an elastic reaction force on said code rod shifting it into operative position in said code wheel means; means contained in said code wheel means associated with each of said code rods to latch any selected code rod in its shifted operative position; means cooperating with said code wheel means operable during a portion of rotation of the code wheel to sequentially withdraw said latch means and then shift the said operatively positioned code rod back to its inoperative position; pivotally mounted transfer lever means combing each of said combing grooves in said code wheel means and pivotable upon engagement with any interference flange on said selected code rod disposed in its associated combing groove during rotation of said code wheel means; a plurality of code punches and a feed punch operated to punch position by pivotal movement of certain ones of said group of transfer lever means; a print hammer; operator means adapted to engage and actuate said print hammer, operated to cause print hammer actuation by the pivotal movement of at least one of said transfer lever means; retractor bail means, engaging the said punches and said print hammer operator to move them back to retract position, operated by pivotal movement of at least another one of said transfer lever means; a tape feed release pawl rendered cyclically operative through a reciprocatory feed release cycle by pivotal movement of at least another one of said transfer lever means; rebound impact shock absorber means disposed to substantially completely absorb all energy of retraction contained in the punches, hammer operator and transfer lever means; a message tape feed device driven by said power means including a friction clutch, a tape feed wheel and holding sprocket and a shaft connecting said friction clutch to said tape wheel feed and holding sprocket, said sprocket being held against rotation beyond a predetermined torque rate determined by said friction clutch by engagement of said tape feed release pawl with said sprocket wheel; and a rotatable type wheel disposed above the message tape and said print hammer, rotatable in a direct 1:1 ratio with rotation of said code wheel means by said power means.

21. A telegraph receiving reperforator comprising: power means; rotatable cylindrical code wheels mounted on side-by-side parallel axes, having means drive connected to said power means so that said two code wheels rotate at the same speed but in opposite directions, and each code wheel containing a plurality of axially spaced apart circular annular combing grooves in its cylindrical surface; sixteen code rods carried in each code wheel disposed parallel to the code wheel axis of rotation, equiangularly spaced in and closely adjacent the rim of the associated code wheel and intersecting said combing grooves, each of said rods including an impact head projecting from an end face of its associated code wheel and a plurality of axially spaced interference flanges forming a specific code signal combination representation and machine function operators, said rods being axially shiftable so said interference flanges move to and provide interference portions in associated combing grooves; means to select and engage the impact head of a desired code rod corresponding to a received code signal combination to cause an elastic reaction force on said code rod shifting it into an operative position in said code wheel; means contained in said code wheels associated with each of said code rods to latch any selected code rod in its operative position; means cooperating with each code wheel operable during a portion of rotation of the code wheel to

sequentially withdraw said latch means and then shift the said operatively positioned code rod back to its inoperative position; pivotally mounted transfer lever means combing each of said combing grooves in both of said code wheels and pivotable upon engagement with any interference flange on said selected code rod disposed in its associated combing groove during code wheel rotation; a plurality of code punches and a feed punch operated to punch position by pivotal movement of certain ones of said group of transfer lever means; retractor bail means, engaging the said punches to move them back to retract position, operated by pivotal movement of others of said transfer lever means; a tape feed release pawl rendered cyclically operative through a reciprocatory feed release cycle by pivotal movement of others of said transfer lever means; rebound impact shock absorber means disposed to substantially completely absorb all energy of retraction contained in the punches and transfer lever means; and a message tape feed device driven by said power means including a friction clutch, a low mass tape feed wheel and holding sprocket and a wire torsion shaft connecting said friction clutch to said tape wheel feed and holding sprocket, said sprocket being held against rotation beyond a predetermined torsion rate determined by said friction clutch by engagement of said tape feed release pawl with said sprocket wheel.

22. A telegraph printer-reperforator comprising: power means; rotatable cylindrical code wheels mounted on side-by-side parallel axes, having means drive connected to said power means so that said two code wheels rotate at the same speed but in opposite directions, and each code wheel containing a plurality of axially spaced apart circular annular combing grooves in its cylindrical surface; sixteen code rods carried in each code wheel disposed parallel to the code wheel axis of rotation, equi-angularly spaced in and closely adjacent the rim of the associated code wheel and intersecting said combing grooves, each of said rods including an impact head projecting from an end face of its associated code wheel and a plurality of axially spaced interference flanges forming a specific code signal combination representation and machine function operators, said rods being axially shiftable so said interference flanges move to and provide interference portions in associated combing grooves; means to select and engage the impact head of a desired code rod to cause an elastic reaction force on said code rod shifting it into an operative position in said code wheel; means contained in said code wheels associated with each of said code rods to latch any selected code rod in its operative position; means cooperating with each code wheel operable during a portion of rotation of the code wheel to sequentially withdraw said latch means and then shift the said operatively positioned code rod back to its inoperative position; dual sets of similar, pivotally mounted transfer lever means, each set combing associated said combing grooves in a different one of said code wheels and each lever means being pivotable upon engagement with any associated interference flange on said selected code rod disposed in its associated combing groove during code wheel rotation; a plurality of code punches and a feed punch operated to punch position by pivotal movement of certain ones of said transfer lever means; a print hammer; operator means adapted to engage and actuate said print hammer, operated to cause print hammer actuation by the pivotal movement of either one of another set of said transfer lever means; retractor bail means, engaging the said punches and said print hammer operator to move them back to retract position, operated by pivotal movement of either one of another set of said transfer lever means; a tape feed release pawl rendered cyclically operative through a reciprocatory feed release cycle by pivotal movement of either one of another set of said transfer lever means; rebound impact shock absorber means disposed to substantially completely absorb all energy of retraction contained in the punches, hammer operator and transfer lever means; a message tape feed device driven by said power means including a friction clutch, a low mass tape feed wheel and holding sprocket and a wire torsion shaft connecting said friction clutch to said tape feed wheel and holding sprocket, said sprocket being held against rotation beyond a predetermined torsion rate determined by said friction clutch by engagement of said tape feed release pawl with said sprocket wheel; a rotatable and axially shiftable type wheel disposed above the message tape and said print hammer, rotatable in a direct 1:1 ratio with rotation of said code wheels by said power means and having two rows of character printing elements disposed around its cylindrical surface, means to shift said type

holding sprocket and a torsion shaft connecting said friction clutch to said tape wheel feed and holding sprocket, said sprocket being held against rotation beyond a predetermined torsion rate determined by said friction clutch by engagement of said tape feed release pawl with said sprocket wheel; a rotatable type wheel disposed above the message tape and said print hammer, rotatable in a direct 1:1 ratio with rotation of said code wheels by said power means; an ink ribbon passing between the type wheel and said message tape; and automatic means to feed and reverse the feed movement of said ink ribbon.

23. A telegraph receiving printer-reperforator comprising: power means; two rotatable cylindrical code wheels mounted on side-by-side parallel axes, having means drive connected to said power means so that said two code wheels rotate at the same speed but in opposite directions, and each code wheel containing a plurality of axially spaced apart circular annular combing grooves in its cylindrical surface; sixteen code rods carried in each code wheel disposed parallel to the code wheel axis of rotation, equi-angularly spaced in and closely adjacent the rim of the associated code wheel and intersecting said combing grooves, each of said rods including an impact head projecting from an end face of its associated code wheel and a plurality of axially spaced interference flanges forming a specific code signal combination representation and machine function operators, said rods being axially shiftable so said interference flanges move to and provide interference portions in associated combing grooves; means to select and engage the impact head of a desired code rod corresponding to a received code signal combination to cause an elastic reaction force on said code rod shifting it into an operative position in said code wheel; means contained in said code wheels associated with each of said code rods to latch any selected code rod in its operative position; means cooperating with each code wheel operable during a portion of rotation of the code wheel to sequentially withdraw said latch means and then shift the said operatively positioned code rod back to its inoperative position; dual sets of similar, pivotally mounted transfer lever means, each set combing associated said combing grooves in a different one of said code wheels and each lever means being pivotable upon engagement with any associated interference flange on said selected code rod disposed in its associated combing groove during code wheel rotation; a plurality of code punches and a feed punch operated to punch position by pivotal movement of either lever means in certain sets of said group of sets of transfer lever means; a print hammer; operator means adapted to engage and actuate said print hammer, operated to cause print hammer actuation by the pivotal movement of either one of another set of said transfer lever means; retractor bail means, engaging the said punches and said print hammer operator to move them back to retract position, operated by pivotal movement of either one of another set of said transfer lever means; a tape feed release pawl rendered cyclically operative through a reciprocatory feed release cycle by pivotal movement of either one of another set of said transfer lever means; rebound impact shock absorber means disposed to substantially completely absorb all energy of retraction contained in the punches, hammer operator and transfer lever means; a message tape feed device driven by said power means including a friction clutch, a low mass tape feed wheel and holding sprocket and a wire torsion shaft connecting said friction clutch to said tape feed wheel and holding sprocket, said sprocket being held against rotation beyond a predetermined torsion rate determined by said friction clutch by engagement of said tape feed release pawl with said sprocket wheel; a rotatable and axially shiftable type wheel disposed above the message tape and said print hammer, rotatable in a direct 1:1 ratio with rotation of said code wheels by said power means and having two rows of character printing elements disposed around its cylindrical surface, means to shift said type

wheel to place one or the other row of characters above the print hammer print point responsive to a receipt of a "Figures" or "Letters" signal combination, and means to hold the type wheel in a selected shift position; and an ink ribbon passing between the type wheel and said message tape and said print hammer; means to feed and automatically reverse the feed movement of said ink ribbon power driven by said power means and including means to continuously feed said ribbon in its appropriate direction so long as electric code combination signals are being received and to cause cessation of ink ribbon feed for any period when signals are not received for a time lapse of one second or more.

24. An operating means for a telegraph message recorder comprising: a rotatable block having a plurality of axially spaced, annular grooves in its peripheral surface; a plurality of axial bores equi-angularly spaced through said block at equal distances from the block axis, adjacent its outer periphery and intersecting said annular grooves; a mechanically coded rod axially shiftably disposed within each of said axial bores; latch means disposed adjacent one end of each of said axial bores adapted to move into latching engagement with the associated code rod in said axial bore whenever said code rod is axially shifted in one direction; non-rotatable means adjacent said rotatable block having means cooperating with all of the said latch means for moving all latch means away from latching engagement with associated code rods at a predetermined angular phase during each cycle of rotation of said rotatable block; second non-rotatable means adjacent said rotatable block cooperating with each of said code rods and operable to oppositely shift any previously selected and shifted code rod a slight distance outwardly of its axial bore during each rotation of said block immediately subsequent to the unlatching movement of the latch means associated with such shifted code rod; and each of said code rods further including a plurality of axially disposed interference members each of which corresponds to a specific one of the annular grooves in the block and which members, in the normal positions of said code rod, are disposed away from intersection with said associated annular grooves and when said code rod is selected and axially shifted into said block, are disposed in intersecting relationship within said associated annular grooves.

25. An operating means for a telegraph printer-reperforator comprising: a rotatable cylindrical block having a plurality of axially spaced, annular grooves in its cylindrical peripheral surface, a plurality of axial bores equi-angularly spaced through said block adjacent its outer periphery and intersecting said annular grooves, a radial bore adjacent one end of each of said axial bores intersecting said axial bore; a mechanically coded rod axially shiftably disposed within each of said axial bores and including a recess shiftable into radial registry with said radial bore associated therewith; a spring biased latch device disposed in each of said radial bores radially inward of the associated code rod and adapted to shift radially outwardly into latching engagement with the recess in the end of the associated code rod whenever said code rod is axially shifted into said block so said recess is in registry with said radial bore; non-rotatable means adjacent said rotatable block having means cooperating with all of the said latch devices for moving any of said latch devices radially inward away from latching engagement with said recess in an associated said code rod at a predetermined angular phase during each cycle of rotation of said block; second non-rotatable means adjacent said block cooperating with each of said code rods and operable to shift any previously selected and shifted code rod a slight distance outwardly of its axial bore during each rotation of said block immediately subsequent to the withdrawal of the latch device associated with such shifted code rod; each of said code rods further including a plurality of radial interference mem-

bers each of which corresponds to a specific one of the annular grooves in said block and which members in the normal position of said code rod are disposed away from intersection with said associated annular grooves and when said code rod is selected and axially shifted into said block, are disposed in intersecting relationship within said associated annular grooves.

26. An operating means for a telegraph printer-reperforator comprising: a rotatable cylindrical block having a plurality of axially spaced, annular grooves in its cylindrical peripheral surface, a plurality of axial bores equi-angularly spaced through said block adjacent its outer periphery and intersecting said annular grooves, a radial bore adjacent one end of each of said axial bores intersecting said axial bore, alternate ones of said axial bores having the associated radial bores at opposite ends; a code rod with an impact head end axially shiftably disposed within each of said axial bores, alternate rods being disposed in associated bores in opposite directions, and each rod including a recess shiftable into radial registry with the associated said radial bore, a spring biased latch pin disposed in each of said radial bores radially inward of the associated code rod and adapted to shift radially outwardly into latching engagement with the recess in the end of the associated code rod whenever the head of said code rod is impacted to axially shift the respective rod further into its axial bore so said rod recess is in registry with the associated said radial bore; non-rotatable means adjacent each of the end faces of said rotatable block having means cooperating with all of the said latch pins adjacent the corresponding end face for moving any of said latch pins radially inward away from latching engagement with an associated said recess in said selected code rod at a predetermined angular position during each cycle of rotation of said block; second non-rotatable means mounted adjacent each end face of said block cooperating with each of said code rods and operable to move any previously selected and inwardly shifted code rod back out of its axial bore to a normal position during each rotation of said block immediately subsequent to the withdrawal of the latch pin associated with such shifted code rod; each of said code rods further including a plurality of annular radially directed interference flanges each of which flanges corresponds to a specific one of the annular grooves in the rotatable block and which flanges in the normal position of said code rod are disposed away from intersection with said associated annular grooves and when said code rod is selected and axially shifted into said block, are disposed in intersecting relationship within said associated annular grooves.

27. In the operating means as defined in claim 26, each code rod being made of hardened steel having a surface hardened impact head on one end, piloting lands adjacent each end for axial piloting action within a said axial bore in said block, a retractor shoulder adjacent said head adapted to be engaged by said second means, said latching recess being an annular groove adjacent the opposite end from said head, and a plurality of said interference flanges being spaced between said piloting lands, the axial positioning of various ones of said interference flanges constituting a permuted code signal combination, and others of said flanges constituting printer-reperforator function operators.

28. For use in a code signal recorder selecting code wheel: a code rod made of hardened steel having a surface hardened impact head on one end, piloting lands adjacent each end, a retractor shoulder adjacent said head, a latching recess adjacent the opposite end from said head, and a plurality of interference flanges spaced between said piloting lands, the axial positioning of various ones of said interference flanges constituting a code signal combination, and others of said flanges constituting recorder function operators.

29. For use in a code signal recorder selecting code wheel: a code rod made of hardened steel having a sur-

face hardened impact head on one end, annular piloting lands adjacent each end, an annular retractor shoulder adjacent said head, an annular latching recess adjacent the opposite end from said head, and a plurality of annular interference flanges in axially spaced relationship between said piloting lands, the axial positioning of various ones of said interference flanges constituting a permuted code signal combination, and others of said flanges constituting recorder function operators.

30. For use in a printer-reperforator selecting code wheel: a code rod made of hardened steel having a surface hardened impact head on one end, piloting lands adjacent each end, a retractor shoulder adjacent said head, a latching recess adjacent the opposite end from said head, and a plurality of interference flanges spaced between said piloting lands, the permuted omission and/or presence of a group of five of said interference flanges constituting a specific code combination condition from the five-unit Baudot Code, wherein any flange which is present constitutes a punch selector and operator for a "mark" condition of the specific code signal combination and the absence of an interference flange represents the "space" condition of the specific code signal combination, another of said plurality of flanges constituting a print hammer operator, another of said plurality of flanges constituting a feed punch operator, another of said plurality of flanges constituting a punch retractor operator, and another of said plurality of flanges constituting a tape feed actuation controller.

31. For use in a type wheel telegraph printer, a print hammer device comprising: a hammer lever having means adjacent one end for pivotally mounting said lever on a fixed pivot member, means intermediate the ends of said hammer lever for receiving an operating impact force from a hammer operator, and a cross bore in the other end of said lever, said cross bore being disposed so that it is substantially tangent to an arc of circular path traversed by lever movement about its said pivoted end; a low mass hammer head having an elongate portion extending through said hammer lever end bore longer than the length of said bore to permit a slight axial shift of said hammer head relative to said lever and means on the opposite end of said hammer head portion preventing axial displacement of said hammer head from said bore in the end of said hammer lever; and an abutment portion on the upper surface of said hammer lever adapted to engage a stop upon reaction movement of said hammer lever resulting from an operating impact whereupon said hammer head will continue movement relative to the hammer lever due to inertia.

32. A print hammer device as defined in claim 31, wherein said hammer lever is made from non-metallic material and said hammer head is made from metallic material.

33. A print hammer device as defined in claim 31, wherein said hammer lever is made from nylon and said hammer head is made from aluminum.

34. For use in a type wheel telegraph printer, a print hammer device comprising: a plastic hammer lever having means adjacent one end for pivotally mounting said lever on a fixed pivot, a cross bore located in the other end of said lever, said cross bore being disposed so that it is substantially tangent to an arc of circular path traversed by lever movement about its said pivoted end; a low mass aluminum hammer head having a shaft portion extending through said hammer lever end bore longer than the length of said bore to permit slight axial free shift of said hammer head relative to said lever and means on the opposite end of said hammer head shaft preventing axial displacement of said hammer head from said bore in the end of said hammer lever; and an abutment portion on said hammer lever adapted to engage a stop upon operative movement of said hammer lever about its pivot end whereupon the low mass head will

5 continue movement in a direction along the axis of said bore, relative to said hammer lever, due to inertia, the limit of said inertia movement of said head being determined by engagement against said lever of said means on said opposite end of said hammer head shaft.

35. For use in a type wheel telegraph printer, a print hammer device comprising: a hammer lever having means adjacent one end for pivotally mounting said lever on a fixed pivot; a low mass hammer head; means mounting said head for limited free shift in a reciprocal path transverse to the elongate extent of said lever and substantially tangential relative to an arc of movement of said lever about its pivot axis, on the other end of said lever; and an abutment portion on said hammer lever 10 adapted to engage a stop upon operative movement of said hammer lever about its pivot end whereupon the low mass head will continue a limited movement, along said reciprocal path relative to said lever, due to inertia.

36. For use in combination with a message tape telegraph apparatus wherein the message tape has a plurality of successive feed holes therein, a tape feed apparatus comprising: a power drive; a friction clutch, one side of which is drive connected to said power drive; a low mass tape feed and holding member journaled 15 for rotation essentially parallel and substantially coaxial to the rotational axis of said friction clutch; a torsion bias storage shaft capable of storing sufficient kinetic energy in torsional twist to rotate said feed member a distance at least equal to one tape feed step, drive connected between the driven side of said friction clutch and said low mass tape feed and holding member; a positive holding means cooperating with said holding member to prevent rotation of said tape feed and holding member whereby said friction clutch imparts a torsional bias through said torsion shaft to said low mass tape feed and holding member; and means for cyclically releasing said holding means and replacing it back to a holding position within the time period required for bias stored in said torsion shaft to overcome the inertia of 20 the low mass tape feed and holding member and to rotate it through an angle resulting in tape feed movement equal to a linear distance of one tape feed space.

37. A tape feed apparatus as defined in claim 36, wherein said torsion shaft is a low mass music wire.

38. A tape feed device as defined in claim 37, wherein in said holding member is a toothed ratchet wheel and said holding means is a cyclically operable lever with a pawl end adapted to engage successive teeth on said ratchet wheel.

39. For use in combination with a message tape telegraph apparatus wherein the message tape has a plurality of successive feed holes therein, a tape feed apparatus comprising: a power drive; a power driven friction clutch; a low mass unitary tape feed wheel and holding member journaled for rotation substantially coaxial 55 to the rotational axis of said friction clutch; a torsion bias storage shaft capable of storing sufficient kinetic energy in torsional twist to rotate said feed wheel a distance at least equal to one tape feed step, drive connected between said friction clutch and said unitary tape feed wheel and holding member; a selectively releasable holding device cooperating with said holding member to enable step by step tape feed movement of said tape feed wheel and holding member under torsional bias through 60 said torsion shaft.

40. For use in combination with a type wheel printing telegraph apparatus, a rotatable and axially shiftable type wheel assembly comprising: a rotatable driving shaft; a cylindrical sleeve axially slidably disposed on 70 and non-rotatably secured to rotate with said rotatable driving shaft and including at least one axial shifting cam groove formed in its exterior cylindrical surface; a type wheel with a double row of print characters; shifting means including a spring biased sleeve shifting plunger, biased in a direction toward disposition into

said cam groove in said sleeve; a latch device spring biased toward cooperative engagement with said plunger to maintain the plunger against its spring bias away from cooperation with said sleeve; an electro-magnet adapted to momentarily attract and shift said latch device against its spring bias out of cooperation with said plunger upon energization of said electro-magnet by a momentary signal; and said cam groove having means permitting smooth entry of said shifting plunger into said camming groove and tail end means on said cam groove for kicking said plunger back to a position where said latch again occupies a latching relationship with said plunger.

41. An axially shiftable type wheel assembly as defined in claim 40, wherein said sleeve includes two camming grooves, two cooperating shift plungers, two latches and two latch operating magnets, each set of components being utilized to shift said sleeve in opposite directions.

42. An axially shiftable type wheel assembly as defined in claim 40, wherein said driving shaft has a square cross section with two detent notches, said camming sleeve is non-metallic; and a spring biased detent plunger is contained in said sleeve to cooperate with one or the other of said notches depending upon its shifted position.

43. A rotary type wheel telegraph receiving and printing apparatus including a receiver control device and an operating recording mechanism comprising: power means; rotatable cylindrical code wheel means having means drive connected to said power means, said code wheel means containing a plurality of axially spaced apart circular annular combing grooves; thirty-two code rods carried in said code wheel means, each of said rods including an impact head and a plurality of axially spaced interference flanges forming a specific code signal combination representation and machine function operators, said rods being axially shiftable so said interference flanges move to and provide interference portions in associated combing grooves; means to select and engage the impact head of a desired code rod which corresponds to a code signal combination received in said receiver control device to cause an elastic reaction force on said code rod shifting it into operative position in said code wheel; transfer lever means combing said combing grooves in said code wheel means and shiftable upon engagement with any interference flange on said selected code rod disposed in its associated combing groove during code wheel rotation; a print hammer; operator means adapted to engage and actuate said print hammer, operated to cause print hammer actuation by the pivotal movement of another one of said transfer levers; a rotatable and axially shiftable type wheel disposed above the message tape and said print hammer, rotatable in a direct 1:1 ratio with rotation of said code wheel means by said power means and having a "Letters" row and a "Figures" row of character printing elements disposed around its cylindrical surface in exact correlation with the angular disposition of said code rods in said code wheel means; means to shift said type wheel to place one or the other row of characters above the print hammer print point responsive to a receipt of a "Figures" or "Letters" signal combination, the means to shift from the "Letters" to "Figures" row initiating and completing the shift while the type wheel is rotating past the print position for the "Figures" code and the means to shift from the "Figures" to "Letters" row initiating and completing the shift while the type wheel is rotating past the print position for the "Letters" code.

44. For use in combination with a rotary type wheel printing telegraph apparatus having a continuously rotating type wheel and an ink ribbon feed and reverse mechanism comprising: two coaxial ribbon spools; rotating power means; a bead chain type drive train driven by said power means, including a bead chain sprocket wheel disposed between said two coaxial ribbon spools; a positive inclined tooth reversible clutch with a neutral

position, said feed sprocket wheel being secured to the driving member of said inclined tooth clutch and two driven members of said clutch being rotatably disposed coaxially with and on each side of said driving member and each of said driven members being drive connected to an associated one of said ribbon spools; means for shifting said clutch driving member into and maintaining engagement with either one of said driven members, reaction force of drive engagement between the teeth of said driving and driven members creating a neutral positioning force on said driving member whenever said driving member is not positively held into engagement with a driven member, and means to reverse the drive operable when either spool is the non-winding spool and becomes substantially unwound.

45. Printing telegraph apparatus for receiving electric code impulse groups and including means for effecting the printing of the received signal characters having an electronic controller unit for separating the signals of impulse groups into two portions, and gate means for registering a coincidence for the one character manifested by each group of impulses, circuit means responsive to a case shift impulse group signal for energizing an electromagnetic coil for effecting a case shift of the printing apparatus.

46. Printing telegraph apparatus for receiving electric code impulse groups and including means for effecting the printing of the received signal characters having an electronic controller unit for separating the signals of impulse groups into two portions, and gate means for registering a coincidence for the one character manifested by each group of impulses, circuit means including a plurality of "and" gates responsive to a figures "shift" signal and to a predetermined subsequent letter character to energize an electromagnetic coil for ringing a bell signal.

47. For use in combination with a rotary type wheel printing telegraph apparatus having a continuously rotating type wheel and an ink ribbon feed and reverse mechanism comprising: two ribbon spools; rotating power means; a drive train driven by said power means, including a rotatable driven member; a positive, inclined tooth, reversible clutch with a neutral position, said power driven rotatable driven member being secured to rotate the driving member of said inclined tooth clutch and two driven members of said clutch being rotatably disposed coaxially with and on each side of said clutch driving member and each of said driven members being drive connected to an associated one of said ribbon spools; means for shifting said clutch driving member into and maintaining engagement with either one of said driven members, reaction force of drive engagement between the inclined faces of the teeth of said clutch driving and driven members creating a neutral positioning force on said driving member whenever said driving member is not positively held into engagement with a driven member, and means to reverse the drive operable when either spool is the nonwinding spool and becomes substantially unwound.

48. In an ink ribbon feed and reverse mechanism as described in claim 47, said shifting means comprising: two electro-magnets, one to shift the driving member in one direction and the other to shift the driving member in the other direction upon selective energization of the associated magnets, and drive power being transmitted through said clutch only when one of said magnets is energized.

49. The ink ribbon feed and reversing mechanism as defined in claim 48, wherein an electronic ribbon feed control is provided and comprises: a bi-stable control circuit alternately connected to one or the other of said electro-magnets; ribbon feed directional control means for switching said bi-stable circuit to control the electro-magnet causing the clutch to drive one ribbon spool momentarily actuated when the ink ribbon is substantially unwound from said one spool.

50. The ink ribbon feed and reversing mechanism as defined in claim 49, wherein means are provided in said feed control for always energizing the electro-magnet designated by said bi-stable control circuit during receipt of electrical code signal impulses, and permitting de-energization of said designated electro-magnet whenever the time delay between received code signal impulses exceeds a pre-set time period.

51. Telegraph apparatus for receiving electric code combination data indicative signal impulse groups and creating visual recorded manifestations of such code combination signal groups, comprising: means for receiving incoming data indicative electrical signal impulse groups and converting each such impulse group to an individual output control signal; a mechanical recorder including power means, a rotatable type wheel and independent character representative, mechanical recording actuation elements corresponding to each data indicative representation of the received signal groups, and means continually rotating both said type wheel and said recording actuation elements in a 1:1 drive ratio by said power means; means to select one of such elements in accord with the output control signal from said receiving means at a rotational position prior to its recording actuation function; and operative means adapted to be actuated by such selected element and including means coating with said continually rotating type wheel during a time interval which is constant for actuation by every element for creating the visual recorded manifestation representative of the incoming signal combination.

52. Telegraph apparatus for receiving electric code combination signal impulse groups and creating printed manifestations of such code combination signal groups on a message tape, comprising: means for receiving incoming electrical signal impulse groups and converting such impulses to individual control signals; a mechanical tape recorder including power means, a tape step feed means, means drive connecting said feed means and said power means, a plurality of independent character representative, mechanical recording actuation elements, each element corresponding to a specific code combination representation of the received code signal groups and each element including means to actuate and operate mechanisms to accomplish recorder function, said elements being rotatable in direct 1:1 relationship and individual elements passing a predetermined angular position during different angular increments in a cycle of rotation, a rotatable type wheel with a plurality of character printing faces on and spaced around its periphery to pass a second predetermined position coincidence with corresponding recording actuation elements passing said predetermined angular position; rotating drive means connected between said power means and said plurality of elements and said type wheel, to continually rotate said elements and said type wheel in a 1:1 drive ratio; means to select any one of such code elements in accord with a corresponding control signal from said receiving means prior to said selected element passing said predetermined angular position; and operative mechanism adapted to be actuated by any such selected code element as it passes said predetermined angular position and having means coating with a said character printing face corresponding to the selected element during a time interval subsequent to said character printing face passing said second predetermined position for creating on a tape the recorded visual manifestation representative of the incoming signal combination and for permitting said tape feed wheel to rotate to step feed the tape one step for each operation, said time interval being constant for each recording operation.

53. A printer-reperforator receiving apparatus comprising: an electronic data indicative electrical code signal group receiving and controlling device; a mechanical printer-reperforator device with selectively operable means, including rotating recording actuation elements,

capable of 4500 cyclic printing, punching and record step feeding operations per minute; and coordinating means between said electronic and mechanical devices enabling controlled selection of the character of operations performed by said selectively operable means, including at least one magnetically operated assembly comprising a spring biased reciprocable impact plunger shiftable into the path of a rotating recording actuation element, latch means holding said plunger against spring bias away from the path of rotation of the recording actuation elements, an electromagnet momentarily energized by a control signal to attract and release said latch means, the impact reaction between said plunger, when released, and a selected recording actuation element causing selection movement of the selected recording actuation element and a rebound of said plunger to related positions.

54. A recorder receiving apparatus as defined in claim 53, wherein the means to select a recording actuation element further comprises a shock absorbing damper device engaged by said plunger upon its rebound movement to assure relatching at the termination of plunger rebound movement.

55. A recorder receiving apparatus as defined in claim 53, wherein said impact plunger has an impact end formed as a socket and a hardened steel impact ball is carried in said socket.

56. A device operative when actuated to produce a visual permanent recordation of a message received in the form of unit data indicative electric signal groups comprising: power operated recording means; means for converting any received signal group to a plurality of simultaneous output signals corresponding to the signals of each received signal group; first means for selecting and registering a first portion of said output signals in accord with the individual permute characteristic of said first portion; second means for selecting and registering a second portion of said output signals; coincidence means correlating phases of cyclic operation of said recording means with said second selection and registering means; means responsive to output signals from said first and second selecting and registering means for controlling and actuating a specific recordation selecting device in said power operated recording means corresponding to a received signal group; and a first-in, first-out storage means connected between said converting means and said first and said second selecting and registering means for momentarily storing signal groups whenever the sequential arrangement of such signal groups cannot be immediately processed by the mechanical recorder.

57. A device operative when actuated to produce a visual permanent recordation of a message received in the form of unit data indicative electric signal groups comprising: power operated recording means; means for converting any received signal group to a plurality of simultaneous output signals corresponding to the signals of each received signal group; means responsive to output signals from said converting means for controlling and actuating a specific recordation selecting device in said power operated recording means corresponding to a received signal group; and a first-in, first-out storage means connected between said converting means and said controlling means for momentarily storing signal groups whenever the sequential arrangement of such signal groups cannot be immediately processed by the mechanical recorder.

58. A device operative when actuated to produce a visual permanent recordation of a message received in the form of unit data indicative electric signal groups comprising: power operated recording means; means for converting any received signal group to a plurality of simultaneous output signal corresponding to the signals of each received signal group; means for selecting and registering said output signals; means correlating phases of cyclic operation of said recording means with said selection and registering means; means responsive to out-

put signals from said selecting and registering means for controlling and actuating a specific recordation selecting device in said power operated recording means corresponding to a received signal group; and a first-in, first-out storage means connected between said converting means and said selecting and registering means for momentarily storing signal groups whenever the sequential arrangement of such signal groups cannot be immediately processed by the mechanical recorder.

UNITED STATES PATENT OFFICE
CERTIFICATE OF CORRECTION

Patent No. 3,150,235

September 22, 1964

Edward F. Kleinschmidt et al.

It is hereby certified that error appears in the above numbered patent requiring correction and that the said Letters Patent should read as corrected below.

Column 4, line 59, strike out "a" second occurrence;
column 9, line 51, for "differen" read -- different --;
column 21, line 64, for "detented" read -- detected --;
line 16, for "syn" read -- sync --; column 42,
line 17, for "constittues" read -- constitutes --; column 47,
column 55, line 56, after "member", first occurrence, read -- paper --;
-- 937 --; column 56, line 49, for "secnod" read -- second --;
column 59, line 69, for "diviiding" read -- dividing --;
column 67, line 29, for "predeterminned" read -- predeter-
mined --.
